UNITED STATES PATENT OFFICE

CUTLER D. KNOWLTON, OF BEVERLY, MASSACHUSETTS, ASSIGNOR TO UNITED SHOE MACHINERY CORPORATION, OF PATERSON, NEW JERSEY, A CORPORATION OF NEW JERSEY

FORMING MACHINE

Application filed April 12, 1923. Serial No. 631,491.

This invention concerns machines for forming material, and more particularly relates to the procedure and type of apparatus disclosed in Letters Patent of the United States granted in my name on January 24, 1928, and numbered 1,657,015, and in the division of the application resulting in such Letters Patent, filed September 6, 1921, Serial Number 498,682. As in these cases, the machine illustrated herein is especially adapted for the production of clicking dies by automatically bending a strip of die-stock into conformity with a templet or pattern.

In the previous machine, the forming effect is obtained by either of two members respectively acting upon opposite sides of the material, when that is heated by a current of electricity flowing through the member in use, and through the material and the movement-restricting means or abutments between which said material is presented by feeding mechanism for its formation and with which the members are in constant co-operation. The forming action of the members begins only after an interval during which the current has exerted its softening effect upon the material. When there is not an abrupt change of form, as when a curved portion of the die, rather than an angle, is to be bent, the application of heat to establish a proper condition for bending is unnecessary, since the material may be operated upon without injury when cold. In this connection, therefore, the use of heat involves a loss of time, during which the current is acting before the bend is started, and there is also a waste of electrical energy. Moreover, during the heating, scale may form upon the heated stock by oxidation, and this is transferred to the bending member, building up a high-resistance coating, which, by the localized heating, tends to burn and pit the material and thus impair the quality of the product. To lessen this effect, the bending members must be changed frequently. To overcome these difficulties is an object of my invention, and for this purpose I provide a plurality of mechanisms, each including a bending member, any one of which may be brought into initial co-oper-

tion with the restricting means in an operating position common to all, and which may be caused to operate under different conditions. That is, the formation of the material may take place while it is heated and under the influence of one mechanism, or when cold, under the influence of another mechanism. By such an arrangement, the application of heat may be confined to the operations at those portions of the pattern where, if cold-bending were practised, the material would be strained. To facilitate the selective utilization of the mechanisms, I prefer to mount them upon a carriage movable with reference to the restricting abutments with which the forming mechanisms co-operate. This carriage may be under the control of the operator by some such means as treadle mechanism. Upon the carriage I may still mount another forming mechanism, as that by which the bent portion is severed from the body of the strip of material from which it has been produced. To avoid interference in bringing the forming mechanisms into operative relation to the restricting means, they are preferably movable upon the carriage from an inactive to an active position, in the latter of which the forming movement proper may be initiated. The movement of the carriage and of the forming mechanisms upon the carriage, and the same is true of the actuation of the apparatus generally, is best accomplished by fluid pressure, rather than by the application of power through shafting and gearing, as in the earlier machine. Hydraulic or liquid pressure, as that of oil, supplies heavy forces promptly started and stopped, and controllable with precision as to intensity and rate. It is also extremely flexible in its application. The control of these actuating forces I prefer to exercise pneumatically, the fluid in this instance being air. The arrest of movement of the forming members, as that with the carriage, is limited by a yieldable member, with which is associated means acting in this yield to vary the resistance to movement, as to increase this resistance. This gives an effective cushioning action, and prevents injury to the elements. Damage to the machine by

movement of the mechanisms into position for operation under the control of the operator might occur were the carriage shifted at a time when an operating mechanism, as one either for bending or cutting, was so raised as to strike the material or abutments. Such injury is prevented by locking against actuation the means through which the operator exerts control. This lock may be applied under the influence of movement of an operating mechanism, or may be dependent upon the active or inactive condition of the fluid-pressure mechanism which exercises automatic control over the action of the machine.

The use of two bending or forming members arranged for respective contact alternately with opposite sides of the material tends to cause interference of the inactive member with the stock which is being bent toward it by the active member. In connection with the present organization, having independent mechanism movable into and out of operating position, as has just been outlined, two members also increase the difficulty in removing these from the path of the associated mechanism when the change from one to the other is made. To improve these conditions and to generally increase the efficiency and certainty of action of a forming mechanism is a further object of the invention. To this end, I leave a side of the material opposite that at which the forming member is acting free to receive the bent material, and reduce the bulk of the parts which must be shifted when another forming member is brought into use. This is accomplished by causing a bending member to contact with opposite sides of the material by a compound movement in intersecting planes, so that it produces deflection in both directions to establish conformity with the pattern. Such a bending member, operating selectively upon opposite sides of the stock, is herein disclosed only in connection with the hot-bending mechanism. The improved mechanism which returns the forming member to a position ready for the succeeding operation, after it has operated upon one side of the material to an extent determined by the mechanism which controls it, as under the influence of a pattern, may stop the member at a predetermined point. This, in the normal progress of formation, may be just clear of the material in its advance by the feeding mechanism, so that the forming member is ready to act promptly. Or if automatic control of the machine is discontinued, this point may be at its extreme inactive position, at which it will not cause interference if another forming mechanism is to come into action. At all times when the forming member is in the line of advance of the material, such advance is prevented to guard against breakage of the parts. The forming member is actuated at

different rates by mechanism for moving it, the speed being relatively great, for the sake of economy in time, when it is removed from the material, and being reduced as it approaches the material, to avoid the shock of contact. The force exerted upon the material by the forming member is preferably increased after contact when bending commences. In the present embodiment of the invention, these controlling actions are obtained by variations in the flow of fluid which actuates the moving mechanism.

An additional object of the invention is to furnish a forming mechanism, as herein disclosed that for bending material when cold, which, in addition to being compact, efficient and readily movable into and out of operating position, acts without undue deforming pressure upon the cooperating abutments or other means which restricts the movement of the material, and permits a forming action by the advance of the material in contact with the forming members, as well as by the movement of the members themselves. For this purpose, I may employ separated bending members operating at opposite sides of the material and revoluble into contact therewith, they being so mounted as to permit them to yield together transversely of the restricting means during the bending action. This forming device, whether it consist of one or two bending members, is arranged to reciprocate into and out of forming position, the latter relation providing for the bringing into action of other forming mechanisms. In its active position, it is oscillated to cause the bending of the material. When separated bending members are utilized, they may be caused to recede and approach each other. The former movement is to facilitate their co-operation with or withdrawal from the material, and the latter to adapt them for the bending action. The various movements, except the lateral self-accommodation, are preferably chiefly caused by fluid pressure. To determine these operations of the forming members, the application of power is governed both by means under the control of the operator and by automatic means. As herein illustrated, a manual valve controls the raising and lowering of the forming members, while their oscillation or bending movement is under the influence of an automatic valve in the forming operation, or such automatic valve may be governed through the manual valve to position the members for initial engagement with the material. To prevent over-action of the forming device, it may be moved at different rates, such rates depending upon the extent of separation between the material and pattern and being greater as the distance between the material and pattern increases.

In machines of the character of that herein described, a very considerable force is neces-

sary to advance the material during the forming operation. If rotatable rolls are used for this purpose, they must be pressed together so strongly as to tend to deform the material. It is, moreover, difficult to transmit the necessary power through such devices as gearing and clutches. Still another object of the invention is to furnish a feeding mechanism capable of applying ample power without injury to the material. For this purpose, 10 I utilize fluid-pressure mechanism, preferably an hydraulic or liquid-containing cylinder with its piston connected to a feeding member. There is illustrated a plurality of pairs of feeding members, in the form of reciprocating jaws. These jaws present to the material so large an area of contact that their pressure does not change its form, while the hydraulic action gives all the force necessary, 15 and, as already pointed out, lends itself to ready application and control. The jaws are so operated as to provide for a continuous feed of material, either toward or from a forming mechanism, at the will of the operator. In the present machine, continuity of 20 feed is obtained by an overlap in the reciprocation of the pairs of jaws, the idle pair traveling more rapidly than those which are active. Economy of operation is gained by the use of a lower pressure to produce the idle 25 movement. With the feeding mechanism are associated independent means for starting and stopping the feeding movement and for changing the rate thereof, as by separate 30 valves in the conduit which supplies the fluid pressure. Over these valves control is exercised automatically, as by pneumatic mechanism, in the forming operation.

A further object of the invention is to provide an efficient automatic controlling means. 40 This is adapted to govern a plurality of forming mechanisms, as those for hot- and cold-bending. The connection of this controlling means depends upon the particular mechanism to be governed which is positioned for 45 operation, and may be determined by a valve in the fluid-pressure controlling means, this valve being actuated in the movement of the carriage upon which the operating mechanisms are mounted. Under the influence of 50 the controlling mechanism, all the automatic operations previously outlined for the operating mechanisms are carried on. As in the earlier apparatus, there is a controlling or 55 form-determining member which co-operates with the pattern. To this member is connected a valve arranged for oscillation to govern the fluid pressure to the forming mechanisms. Preferably, this control is not direct; 60 there instead being a single valve member controlling a plurality of valves, which are actuated to produce the desired results, either at the various operating mechanisms or in the controlling mechanism itself. The form 65 of valve-system which I consider preferable

involves a valve-segment governing a plurality of leak-openings, which, when varied, cause the movement of leakage-valves. The primary valve or segment is shown as effecting its control through movement in paths at an angle to each other, as by oscillation and reciprocation. The former movement may be under the influence of the pattern, while the latter I have provided for in a plurality of ways, depending upon the manner in which the material is being formed, as in the production of internal and external angles by the hot-bending mechanism. Lag produced by the chain of connections between the form-determining member and the valve, and tending to delay the controlling effects upon reversal of movement of the form-determining member, may be compensated for by means acting in anticipation of the reversing movement. This means, in the present instance, 70 consists of fluid-pressure mechanism governed by the valve to move said valve in a direction producing this anticipating effect. Associated with the primary controlling valve is a secondary valve, and by the co-operation of these valves, or in some other suitable manner, there is obtained, by the form-determining or other member movable under the influence of the pattern, a control 75 of an operating mechanism in three zones, in each of which the forming and feeding mechanisms are differently affected. This is of peculiar utility in connection with the control of the cold-bender, different rates of movement of the bending members being combined with different feeding effects to meet the conditions existing as to the relation between the 80 material and pattern.

It is also an object of the invention to include in the machine a cutting mechanism 85 organized to best co-operate with the associated forming means and to be effective in the performance of its functions. In the attainment of this object, the cutting mechanism is normally removed from a portion 90 of the forming means, as that furnished by the abutments, it preferably being mounted upon the carriage with the hot and cold-bending mechanisms. Upon the cutting mechanism acts means to move it into proximity to the forming means and to produce 95 its actuation to sever the formed material at the termination of this movement. This organization allows the operations of the bending mechanisms while they are associated 100 with the abutments to be performed without interference, and the cutting mechanism to be made promptly effective at the completion of the bending action. To permit it to adapt itself to the position of the 105 material, the cutting mechanism is arranged to yield during its operation. In the form herein disclosed, the cutting mechanism includes a pair of blades mounted upon a carrier movable toward and from the abut- 110

ments, these blades being normally separated to lie at opposite sides of the abutments and being closed in the movement of the carrier, when they are in proximity to the abutments, to sever the material. As in the other mechanisms making up the machine, fluid pressure preferably causes the positioning and operating movements of the cutting mechanism. This fluid pressure I have shown as applied through a valve under the control of the operator, which valve is preferably closed by the action of the fluid, so that when the cutting operation ceases the mechanism returns to normal as soon as released by the operator. To prevent injury to the cutting mechanism, its movement into co-operation with the forming means best takes place at a reduced rate, as the end of its travel is approached, to lessen the shock caused by the stopping of the movement. This change of rate I have shown as effected by gradually diminishing the area of an opening through which the actuating fluid is delivered. The reverse movement of the cutting mechanism may be without this resistance, the flow through the fluid-pressure connections being limited in this manner in one direction only.

Other objects of the invention, including improvements in the movement-resisting abutments and in the material-supporting means, will become evident upon consideration of the following description in connection with the accompanying drawings, the latter illustrating a single embodiment of the invention. In these drawings,

- 60 *Principal elements of the machine and their manner of utilization*

The general relation of the chief elements of this machine best appears in Figs. 1, 2, 3, 4, 34, 67 and 119 of the drawings. I have 65 chosen to illustrate the apparatus as applied

to the production of a clicking die from a strip of stock A of the usual tapered cross-section, the contour of the finished die being in accordance with that of a templet B (Figs. 37 and 133), which guides the machine in its 70 operation. The templet may be attached to the stock, as in the previously mentioned cases, by clips C extending over and beneath said stock and passing through openings in the templet. The stock, carrying the templet 75 to move freely with it, is preferably advanced for formation between separated abutments D, D mounted upon a main frame E. These abutments restrict the stock against lateral movement without stopping its travel, which is effected by feeding mechanism F having pairs of alternately acting stock-gripping members. The action of the feeding mechanism during the bending of the stock about the templet is continuous, save when control 80 is exercised by the machine at certain times, or at the will of the operator. At or near the point of emergence of the stock from the abutments, it may be acted upon, as determined by the operator, by a hot-bending mechanism G, cold-bending mechanism H or cutting mechanism I. These three forming 85 means, of which the abutments may be considered a co-operating element, are shown as mounted upon a slide or carriage J movable 90 across the frame beneath the forward extremities of the abutments to bring the chosen instrumentality into proximity with the stock as it is presented between said abutments, control over the carriage being exercised by 95 the operator through treadle mechanism K. Elevation and depression of the three mechanisms of the carriage, for the purpose of moving them from normally inactive 100 positions into or out of cooperation with the stock, may be produced automatically in the case of the hot-bender, and manually only with respect to the cold-bender and the cutters. The hot-bending mechanism G is preferably employed at points where there is an abrupt 105 change in direction of the die-contour, it including a member coming into contact selectively with either the right or left side of the stock adjacent to the ends of the abutments to bend said stock one way or the other across 110 their extremities. Heat is applied, as by electric current of large volume flowing through the hot-bender and stock, to soften said stock and facilitate its formation. The current, both as to the initiation of its application and its cessation, is automatically controlled, as 115 may be the rate of movement of the hot-bender into engagement with the stock and the degree of its pressure thereon. The cold-bending mechanism H is of greatest utility where the extent to which the stock is bent is less than that for which the hot-bender is used, as for curves of not extremely small radii. This cold-bender includes separated 120 members, which may be revolved either in a 125

clockwise or anti-clockwise direction into contact with opposite sides of the stock to form it by the action of the members alone, or in conjunction with the advance of the stock by the feeding mechanism. While cold-bending is taking place, feed of the stock goes on under certain conditions, unless interrupted by the operator, while under other conditions it ceases. The rate of movement of the cold-bender under such circumstances may be different. Both the hot- and cold-bending mechanisms functionate under the control of feeler or form-determining mechanism L, this contacting with the advancing stock and templet and responding to departures of the former from coincidence of contour with the latter to cause such action of the particular bending mechanism at that time in use as to again bring them into conformity. This mechanism L also controls the feeding mechanism F. As the forming operation thus proceeds, other clips are applied to the stock and templet to maintain the relation which the benders have established, and finally the formed stock arrives opposite the end initially applied to the templet. Feed is continued until these meeting ends overlap. Then the carriage J is moved to position the cutting mechanism I beneath the stock, and the operator causes the elevation and action of the cutters, as the last forming operation of the machine, to sever the die from the strip of stock projecting between the abutments. The formed die is separated from the templet by the removal of the clips, and the adjacent extremities welded together in any suitable manner. Because of the magnitude of the forces made available, the flexibility of application and the ease of control, I prefer to actuate the various mechanisms by hydraulic means and govern them pneumatically. Hereinafter, when such terms as fluid-pressure mechanism or device are employed, it is to be understood that both actuation and control, either by a liquid, as oil, or a gas, as air, are thereby comprehended.

The particular procedure above outlined and the means hereinafter described in detail for carrying it out are simply illustrative, and my invention is not to be considered as limited thereto.

Stock-restricting, feeding and supporting means

Figs. 2, 4 and 119 best illustrate the abutments D, D. These abutments, though spaced from each other by a stock-receiving channel 149, may be formed integrally or connected below the channel and mounted upon an upwardly extending wall 150 carried by a plate 152 adjustable upon ways 151 at the top of the frame E. The abutments are held in place against vertical displacement on the wall by a co-operating tongue and groove 154, and are fixed thereto by screws 156 passing through slots in the wall

and into the side of the abutment member. A pair of screws 158, 158, threaded through the wall 150 in directions inclined to the longitudinal axis of the abutments and into the abutment member, may be positioned to vary the point at which the forward extremities 160, 160 of the abutments lie. This adjustment is effected by loosening one screw of the pair and tightening the other, the former permitting the movement and the latter producing it. The screws 156 are, of course, temporarily loosened to permit this. The abutment-extremities 160 are rounded horizontally, these furnishing the surfaces over which the stock is formed by the benders, and the reduced width at these points permitting said benders to act to form the stock in relatively acute angles. Since these portions 160 are worn away or become distorted in use and must be reformed, the adjustment by the screws 158 allows the normal relation between the abutment-ends and the benders to be established at such times. Variation of the position of the abutments transversely may be effected by movement of the plate 152 by push-and-pull screws 153, 153, carried by a bracket fixed to the frame and engaging one end of the plate. Setscrews 155, threaded through an edge of the plate, hold this normally in place. The channel between the abutments is shown as curved laterally at 162 from the straight line presented by the remainder. When the stock is thrust forward by the feeding mechanism, this curvature produces a bend in said stock as it emerges from the abutments, deflecting it to one side, as appears in Fig. 119 of the drawings. By attaching the templet to the side of the stock away from which it is thus bent, greater lateral space may be had for its formation. Certain types of dies may be most efficiently operated upon with a curvature in one direction, others with the curvature in the opposite direction, and still others when the stock emerges straight, without change in its form until acted upon by the benders. Consequently, I arrange the plate 152 with the abutment-supporting wall so that they may readily be removed and others substituted, in which the angle of inclination is in harmony with the particular conditions which are to be met.

Projecting rearwardly from the right-hand end of the frame, as viewed from the operator's position (Fig. 4), is a frame-portion 170, upon which the feeding mechanism F is supported. The angle of the frame-portion with relation to the main frame corresponds to the particular inclination given the abutments. The feeding mechanism is most fully illustrated in Figs. 5 to 21, inclusive. Mounted to reciprocate upon the frame-portion 170 in longitudinally extending ways 172 are two similar carriers 174, 174. At the opposite sides of each carrier beneath over-

hanging portions 176 rise pairs of opposite walls 178, 178. Arranged to slide upon the upper surface of the carriers and transversely thereof between the walls 178 are 5 pairs of jaws or stock-gripping members 180, 180, each of which is recessed at 182 (Fig. 18) to correspond to the contour of the side of the die-stock, these recesses being of such depth that the jaws may engage the stock and hold 10 it firmly, without contact with each other over the surfaces above and below the recesses. The area presented by each jaw for engagement with the stock is so great that heavy pressure may be exerted without mutilation. 15 Between each jaw and the corresponding wall 178 is a cam member 186 having a plane lower extremity resting upon the carrier and being elliptical in horizontal section. At the opposite ends of the minor diameter of the 20 elliptical body are vertical recesses, the inner being engaged by a projection 184 upon the corresponding jaw 180, while entering the outer is a projection 188 upon the adjacent wall 178. When longitudinal feeding 25 movement is imparted to the jaws in either direction, the cam members slide upon the carrier and are turned about vertical axes by the engagement of the projections 184 and 188, thus increasing the diameter between 30 their opposite sides at the pressure-surfaces contacting with the jaws and walls, and exercising a toggle-effect, which causes the jaws of each pair to move toward each other to grip the stock between them. The action 35 is best illustrated in Fig. 17, where the axes of what amount to toggle-arms are indicated by dash and dot lines. The cam members are reversible, exerting their toggle-effect at both sides of the projections. Obviously, the 40 greater the force exerted to move the jaws with the stock between them in the direction in which feed is occurring and against resistance encountered, the greater will be the pressure exerted by the toggles upon the 45 stock, and the firmer the grip of the jaws. In outward extensions 190 from the jaw members are depressions to receive the lower ends of vertical arms 192 fixed upon a pair of shafts 194, 194 journaled at the outer upper portions of the carriers 174. Fixed to 50 each shaft is an upwardly extending arm 195, which enters an opening in the under side of a cylinder 196 supported upon the corresponding carrier, these two cylinders being 55 in longitudinal alinement, and the arms within the cylinders having pins projecting into vertical slots in double pistons 198, 198. Each piston is of such length that the requisite travel within its cylinder is permitted to 60 impart the gripping action to the jaws through movement of the arms 192. Fluid pressure, as that of air from an unillustrated source outside the machine, is applied to the cylinders through pipes 200, 200 connected to the 65 right-hand ends, as viewed in Fig. 5 of the

drawings, or through pipes 202, 202 to the opposite or left-hand ends to shift the toggle-effect of the cams 186 from one side of the intermeshing projections and depressions to the other. This causes the pairs of jaws to 70 grasp the stock during the reciprocation of the carriers 174 either to feed it forwardly between the abutments D, D, or rearwardly from said abutments. Each shaft 194 has, extending outwardly from it, a generally 75 horizontal arm 204. These arms are joined by links 206 to an equal-armed lever 208 fulcrumed upon the top of one of the overhanging portions 176 of a carrier 174. The pistons 198, 198 are consequently, save for what 80 spring and lost motion there may be in these connections, caused to move together. This gives a simultaneous effect upon the jaws 180 when the feed is reversed. The slack and spring in the connections permit one of the 85 pair of jaws to grip the stock, while the other releases it at the time they are traveling oppositely. The control of the fluid pressure and the gripping action of the jaws will later be made clear. 90

To cause the reciprocation of the carriers 174 in opposite directions, so that the jaws 180, 180 of one are gripping the stock to move it in one direction or the other, while the companion carrier is traveling oppositely with 95 its jaws slipping idly over said stock, each carrier is joined by pairs of links 210, 210 to the short upper arms of levers 212 turning on a shaft 214 fixed in the frame-portion 170. The depending long arms of the levers 100 are united by links 216, 216 to a head 218 fixed at the outer extremity of a horizontally extending piston-rod 220. Each rod, at its opposite end, is secured to a piston 222 movable within a cylinder 224 supported in the lower portion of the frame-section 170. The cylinders for the two carriers are arranged side by side, preferably in the same horizontal plane, with the piston-rods extending oppositely from them to join the levers 212. 110 Carried above each of the cylinders 224 is a valve 226, shown as of the piston type, having four reduced portions between heads or flanges fitting cylinders 228. Ports 230, 230 (Fig. 4) connect the opposite ends of each 115 cylinder with the central portion of the valve-casing, while midway between these cylinder-communicating-ports is an admission-port 232 for oil or other suitable fluid under relatively high pressure. This oil may 120 be delivered to the machine through a main supply-pipe 231 (Fig. 35). Ports 236, 236, each nearer the ends of the valve-casing than are the cylinder-ports 230, serve alternately for the admission and exhaust of oil, connecting through a cylinder 238 of a reversing valve 240 to either a source of oil under relatively low pressure, by way of ports 242, 242, or to exhaust at atmospheric pressure 125 through a port 244. The discharge from this 130

exhaust-port is received by exhaust-piping 245. To shift the valves 226, 226 for effecting the alternate opposite reciprocation of the pistons 222 and connected carriers 174, each head 218 cooperates with a valve-actuating lever 246 fulcrumed at 248 upon the frame. At one side of the fulcrum, the end walls of a slot in a link 250 pivoted upon the head may engage a pin 252 projecting from the side of the adjacent end of the lever 246. At the other side of the fulcrum there is a rod 254, extending from the head in the same general direction as the link 250 and having frictional engagement with the lever 246 by means of a pair of blocks 256, 256, which contact with opposite sides of the rod and are held between divided portions of the lever. This lever carries a spring 258 surrounding a rod 259 projecting from it at one side through slots in the blocks, rod and opposite side of the lever. One end of the spring contacts with a sleeve 257 movable about the rod through an opening in the lever-wall and resting against one of the blocks, and the other end abuts against a nut and lock-nut 261 threaded upon the rod. This spring, adjusted to the proper tension by the position of the nuts upon the rod 259, so forces the blocks into such engagement with the rod 254 that the lever 246 may be either turned about its fulcrum thereby, or the friction will slip to permit an oscillation of the lever by the contact of an end of the slot in the link 250 with the pin 252. Each lever 246 is connected to the valve which it is to actuate by links 260. Through aligned openings in the levers 246, 246 passes a rod 262 mounted to slide longitudinally in the frame and having fixed upon it, at opposite sides of each of the levers, pairs of blocks or contact members 264, 264. The adjacent ends of each pair of blocks 264 are spaced from each other, so that some travel of the levers between them is permitted before contact occurs.

To trace the general action of the feeding mechanism for the advance of the stock between the abutments D, D, and referring first to Fig. 14, the piston 222 at the lower portion of this figure is shown as just completing its forward or feeding stroke under the influence of high-pressure oil supplied by the port 232 of its valve 226, this supply being through a pipe 266 (Fig. 5). At the same time, air passes through a vertical pipe 270, a manual reversing valve 272, opposite horizontal pipes 274 and delivery-pipes 200 to the right-hand extremities of the jaw-actuating cylinders 196. This fluid pressure exerted upon the pistons 198 rocks the arms 192 in a clockwise direction (Fig. 16), forcing the jaws rearward and, through the engagement of the projections 184 with the cam members 186 and the retention of said cam members 186 against bodily movement by the wall-projec-

tions 188, turning these members to produce their toggle effect, and camming the jaws together into engagement with the stock. The movement of the jaws of the carrier 174, which is being advanced by the travel of the piston 222 acting through its lever 212, is in such a direction that the toggle-action of the jaws is effective to advance the stock. The opposite or upper piston 222 is shown in Fig. 14 as having completed its reverse or idle travel to the point at which it is prepared to take up the feeding action. During this return, the relative movement between the stock and jaws of the idle carrier is such that said jaws slide ineffectively over the stock, although held in firm contact with it by pressure upon the corresponding piston 198. This maintenance of engagement during the idle movement serves to prevent the reversal or displacement of the toggle under the influence of the drag of the stock. As the lower piston 222 is traveling forward, as just described, the oil at the opposite end from that connected to the high-pressure port 232 is exhausting through its port 230 and the port 236 into the low-pressure system by way of the valve 240, this low-pressure system being at the time connected with the end of the upper cylinder 224, which is producing the return travel of this piston. The opposite side of the upper piston is joined through the corresponding port 236 and the valve 240 to the exhaust-port 244, from which the oil escapes freely. As will hereinafter more clearly appear, the movements of the pistons 222 in opposite directions differ in character. The rate of flow of the high-pressure oil, which gives ample power for the feed of the stock, is such as to produce a relatively slow movement of the piston actuating the feeding jaws, the rate of admission of the low-pressure oil, giving the idle stroke for the companion piston and jaws, is more rapid, with the expenditure of much less power, it bringing the idly moving piston to the end of its return stroke before the working stroke of its companion has been completed. There said idle piston awaits the valve-movement which causes it to take up the work.

At the beginning of the working stroke of the lower piston 222, the pin 252 of its lever 246 is at the left-hand end of the slot in the link 250 (Fig. 14). As the link travels to the left, the pin first passes without action along the slot, and during this time the frictional engagement of the rod 254 with the blocks mounted upon the lever 246 swings this lever upon its fulcrum so that the valve 226 of the upper piston 222 is carried to the position illustrated in Fig. 14. Now, the low-pressure oil is admitted to the left-hand end to cause the return movement of its carrier 174. This upper valve 226 is brought to rest in the position illustrated by contact of the lever 246 with the left-hand stop 264. Toward

the end of the stroke of the lower piston 222, or as appears in Fig. 14, the right-hand end of the slot in link 250 strikes the pin 252. This turns the lever 246 in a clockwise direction about its fulcrum, the friction at 256 slipping and the lever now being carried against the right-hand stop 264. The oscillation of the lever causes the upper valve 226 to assume the position at the right for control of the working stroke of the upper piston 222, this corresponding to the illustrated relation of the lower valve. As the upper piston 222 proceeds in its feeding movement, starting this before the advancing action of 15 the associated piston has ceased, and thus overlapping to insure continuous feeding, it operates, through its head 218 and associated elements acting upon the left-hand lever 246, to reverse the lower valve 226 so that the idle 20 return stroke of the lower piston 222 results.

To reverse the feed of the stock, which may be desirable, for example, if it has been advanced too far initially between the abutments for the attachment of the templet, the 25 valve 272 is turned through 90 degrees by a hand-rod 280 (Fig. 5), which extends to the front of the machine in a position convenient to be grasped by the operator. This valve is of the plug type, with passages and ports precisely as is illustrated in Figs. 25 and 26 of the drawings, though the valve here shown serves another purpose. It is a four-way valve, having four ports in its casing separated successively by 90 degrees, and two 35 arcuate passages through the plug, which, when turned as just stated, reverse the connection of pressure and exhaust from two opposite pipes to the intermediate pipes. In the valve 272, by the movement of the rod 280, an 40 upper exhaust-port 282 is joined to the pipes 200, which have previously been connected to the pressure-pipe 270, while the pipes 202, which had been joined to the exhaust-port, now receive pressure. This supplies air simultaneously to the left-hand ends of the 45 cylinders 196, 196 (Fig. 5), and at the same time the pressure of this fluid is admitted to a corresponding pipe 284, which opens into the end of a cylinder 286 supported in the lower 50 part of the frame above the cylinders 224 (Fig. 10). During the previous stroke, the pressure was delivered to the opposite end of the cylinder 286 by a companion pipe 284. Within this cylinder 286 is a double piston 55 ton 288 (Fig. 19), and articulated to this is an arm 290 secured to a shaft 292 journaled transversely of the frame-portion 170 and rising through a slot in the under side of the cylinder. Fast upon the 60 shaft 292 is a double arm 294, joined by links 296, 296 to the reversing valve 240. Depending arms 298 upon the shaft 292 are pivotally connected to the stop-rod 262. Upon the reversal of pressure to the cylinder 286, 65 the reversing valve 240 is carried to the oppo-

site extreme of its cylinder, or to the left as viewed in Fig. 14 of the drawings, while the stop-rod 262 is oppositely moved. The new position of the valve 240 unites the low-pressure oil to the right-hand port 236 of the valves 226, instead of to the left-hand ports, and joins the exhaust to atmospheric pressure through ports 244 to the left-hand port 236. The contact-blocks 264 are moved to the right to be effective in positioning the valves 226 under the influence of their levers 246 for the opposite travel of the pistons 222 and connected carriers 174. The reversal of pressure in the cylinders 196, when the transfer is made from the pipes 200 to the pipes 202, causes the toggle-effect of the cam-rolls 186 to be applied oppositely to the stock, so that the jaws 180 now grip the stock for feed in a reverse direction, or from the abutments rearwardly.

In the pipe 266, by which oil under high pressure is supplied to the feed mechanism, are included a controlling valve 310, by means of which the movement of the stock may be started or stopped, as a result of the opening or closing of the passage through the pipe, and a valve 312 arranged to throttle the flow to a greater or less degree to vary the rate of feed. The valve 310 (Figs. 5 and 6) is shown as of the globe type, the valve-portions 314, 314 being carried into and out of engagement with their seats in the outer casing by a vertically movable stem 316, upon which they are mounted. Acting upon the valve-portions 314 to seat them are springs 318, 318 extending between a transverse rod 320 fixed to the valve-stem and the casing, preferably at the latter points engaging screws 322 by which their tension may be adjusted. Supported above the casing of the valve 310 is a cylinder 324 to receive an actuating medium, as air, for the valve-portions 314. Within this cylinder is a piston 326, the rod of which is articulated to the valve-stem through the rod 320, to which the valve-seating springs are connected. Air-pressure may be supplied to this cylinder 324 in two ways, either below the piston through a pipe 328 to raise it and the valves 314 against the tension of their springs 318 and open the pipe 266 for the flow of oil, or above the piston by a pipe 330, this acting in the same direction as the springs and counteracting the effect of the air introduced through the pipe 328 to allow the pipe 266 to remain closed. In the pipe 328 is a three-way cock 332, which may be set either to permit a flow through this pipe beneath the piston 326 to cause temporarily a continuous feed of the stock, or to divert the flow through a pipe 334 to permit an intermittent operator-controlled feed. There is also a connection to this pipe giving control in the automatic action of the machine. Both of these controls exercised through the pipe 334 are to provide for the desired feed of the stock to meet the par-

- ticular conditions existing; see the air-diagram of Fig. 132.
- The manual control is preferably exerted through a leakage-valve 336 included in the pipe 334, and governed by air admitted through a pipe 338. This leakage-valve, of which a number are used in the machine, may be understood from an inspection of Figs. 84, 86 and 91 of the drawings, in which is illustrated in detail one of these devices associated with the feeler mechanism. A casing 340 contains a valve-plunger or piston 342 having two heads of different diameter and fitting in corresponding bores. A port 344 admits air pressure at all times between the heads of the valve, while a port 346, connected to the device to be controlled, may be joined, in opposite positions of the valve, either to the port 344 or to an exhaust-port 348.
- Through the extremity of the casing, outside the larger of the two heads, is a leakage-port 350. Were this valve to be inserted in the system at 336, the port 344 would receive air through the pipe 334, the port 346 would communicate with the three-way cock 332, while the leakage-opening 350 would be joined to the pipe 338. In any case, the exhaust-port 348 is through the casing to the atmosphere. The fit of the larger head in the casing is such that there is a continuous leakage permitted by it, this being provided for past the head of the valve over the leakage-passage 350 by transverse grooves, as is best illustrated in Fig. 91 of the drawings. Since the area of this larger left-hand head is greater than that of the associated head, the pressure of the air through the port 344 will maintain the valve at the left as long as this leakage is permitted to escape through the port 350. This relation maintains the air pressure supplied by the pipe 328 cut off from the pipe leading through the three-way cock to the cylinder 324 below the piston 326, and this under side of the piston connected to the exhaust-port 348. If, however, the leakage-port 350 is closed, as by means of some valve device included in the pipe 338, the leakage-pressure becomes effective upon the outer side of the left-hand head of the valve, which, added to the force upon the inner side of the right-hand head, causes movement to the right, this applying air pressure from the pipe 328 to the under side of the piston 326 to raise this and open the valve 310. To balance the lateral thrust of these leakage-valve plungers, and thus increase their sensitivity, I prefer to form about the peripheries of their heads spiral grooves 351. These tend to distribute the flow of air uniformly about the valves and to minimize the frictional resistance to movement. A finger-piece 353 projecting from the plunger 342 permits the leakage-valve to be opened and closed manually to facilitate testing the system. To control the leakage through the pipe 338, there is situated for ready access by the operator, as upon a rail 352 protecting the front of the machine (Fig. 129), a valve 354 terminating the pipe. This valve includes a hand-lever 356 having mounted upon it a projecting closure 358 cooperating with a seat to which the pipe 338 is joined, and being held out of contact with it by a spring 360. As long as the pipe 338 is open at the valve 354, so that leakage exists, the valve 336 is closed, pressure is withheld from the under side of the piston 326, the valve portions 314 are seated, and the feeding mechanism remains inactive, as far as control from this source is concerned. If, however, the operator actuates the lever 356 to close the pipe 338, the valve 336 opens, admitting air through the pipe 328 and opening the valve 310 to cause feed of the stock.
- Automatic control of the feed takes place through a pipe 362 connected to the pipe 334 through a double-check valve 366. The application of air-pressure to the cylinder 324 above the valve 310 to cause feed will be hereinafter explained. The double-check valve is to allow pressure to be applied to the cylinder 324 from either of two directions—under the influence of manual control through the pipe 334 or automatic control through the pipe 362—without escape of this pressure through the companion inlet. It preferably takes the form of a piston-valve, of which others are utilized at various points in the machine and of which one appears in section at 367 in Fig. 50. Within the outer casing is a movable valve-plunger 368, which is actuated by pressure admitted through either of the opposite heads to connect this pressure-supply passage with a lateral port joined to the device to be actuated. At the same time, the plunger, in its travel, shuts off the admitted fluid from the alternate pressure-passage at the opposite extremity of the plunger. Exhaust is permitted, as well as supply, through the active passage. In the valve 366, the supply is through either the valve 336 and pipe 334 or the pipe 362, while the lateral outlet is to the pipe 328 by way of the other section of the pipe 334. The supply of air through the pipe 330 to the cylinder 324, to add its effect to the springs 318 in maintaining the valve 310 closed, is controlled by a valve 370, illustrated in detail in Fig. 9 of the drawings. In the casing of this valve operates a plunger 372, normally raised by a spring 374 to cause a central reduced portion to unite ports from which lead a pipe 376, to air pressure controlled at the feeler mechanism, and the pipe 330, to the top of the valve-controlling cylinder 324. This pressure to the pipe 376 is applied, in connection with either right or left bending of the stock, through a double-check valve 377 (Figs. 131 and 132). The application of pressure above the piston 328 acts with the

springs 318 to prevent the feed of the stock, in absence of other control, by holding the valve 310 closed. At certain times in the operation of the machine, however, it may be desired to nullify this effect of the air above the piston 326 in stopping the feed, and this may be accomplished automatically by admitting air through a pipe 378 above the plunger 372 of valve 370. This forces down the plunger against the spring 374 until the inlet-pipe 376 is closed and the supply-pipe 330 to the cylinder 324 is open to exhaust through a port 379 in the valve-casing. This leaves the valve 310 seated by the action of the springs 318 only, so that the pipe 266 may be opened upon the application of air pressure beneath the piston 326.

To recapitulate as to the feed-control, I provide, by a position of the three-way cock 332 which opens the pipe 328 straight through, for continuous feed of the stock by the admission of air below the piston 326 to hold the valve 310 open, this being useful when there is to be a considerable length advanced, as when a new piece is introduced and is fed beyond the abutments for the attachment of the templet. The alternate position of the cock 332 gives valve-opening pressure beneath the piston 326, controlled by the leakage-valve 336 under the influence of the operator-actuated device 354, to cause relatively short initial feed, as when a new templet is to be applied to the stock, or to advance said stock for the final cutting-off operation. It also supplies air for automatic control through the pipe 362. The feed effected through this last-mentioned pipe may be prevented by air introduced through the pipe 376 and the valve 370, as normally raised by its spring, this being governed by the feeler mechanism, and this prevention of feed under feeler-control may be nullified for certain conditions in cold-bending, by air introduced by way of the pipe 378 to act upon the valve 370 to lower it against its spring, cutting off the connection of the pipe 376 to the cylinder 324.

At times in the operation of the machine, it may be preferable to feed the stock more slowly than the normal rate, governed either manually or automatically. A means for effecting this end is furnished by the valve 312. This, as illustrated in Fig. 8, has a plug 380, through which are two transverse openings 382, 382, which may be turned into registration with ports joined to the high-pressure oil-pipe 266. Opposite these inlet-ports are supply-ports, to which are connected separate pipes 383, 383 leading to the ports 232, 232 of the valves 226 controlling the movement of the feeding pistons 222. (Fig. 14). Fixed at the upper extremity of the plug 380 is an arm 385, from which a rod 384 passes through an opening in a bracket 386 secured to the right-hand end of the main frame E

(Fig. 4). The outer extremity of this rod 384 lies at a point at which it may conveniently be manipulated by the operator. Fast upon the rod, at opposite sides of the bracket, are collars 388, 388 spaced from the bracket 70 and held in position by set-screws, so that their locations may be varied. Between the bracket and the collar toward the valve is a relatively short spring 390, and between said bracket and the opposite collar is a longer 75 spring 392. The spacing of the collars with respect to the bracket permits the tension of these springs to be varied. Another spring 394 exerts its tension upon the arm 385, this aiding the longer spring 392. The combined 80 action of the three springs is such as to hold the valve-arm between a stop-surface 396 upon the valve-casing, which, when the arm is against it, holds the valve most widely open, and an opposite stop-surface 398, with 85 which may contact a screw 399 threaded through the arm. This surface 398 determines variably, in accordance with the adjustment of the screw, the degree of maximum closure of the valve. The intermediate point 90 at which the spring-action normally maintains the valve-arm is one in which the opening of the ports allows such a rate of flow of the oil through the pipe 266 as to produce a normal feed of the stock. If the operator wishes the stock to advance more rapidly, as in bringing it initially into the templet-affixing position, he may draw the rod toward him, compressing the shorter spring 390. The resistance of this, acting against the force of the springs 392 and 394, combined with the friction in the valve-plug and its connections, is such that during a certain portion of the oscillation of the arm 385 the valve 95 will remain in the position in which it is thus set, so that the operator may release the rod 384 to perform other acts, and may return the valve-arm to its normal position, at which it is balanced by the springs, by thrusting the rod in the opposite direction. Supported upon the casing of the valve 312 is a horizontally disposed cylinder 400, in which operates a piston 402, the rod of which is joined by a link 404 to the arm 385. Air pressure may be admitted to a pipe 406 opening through the head of the cylinder opposite the valve-arm, this being under the control of the feeler mechanism. When the piston 402 is moved toward the right, as viewed in Fig. 115 5 of the drawings, by the feeler-air, the screw 399 comes in contact with the stop-surface 398, bringing the plug 380 to rest at such an angle that the flow of oil through the pipe 266 will be throttled to cause the stock to be fed more slowly. This may be of utility on such occasions as the producing of abrupt corners by the hot-bending mechanism. When the air-pressure through the pipe 406 120 ceases, the springs return the lever-arm to 125 130

its intermediate position for the normal feed of the stock.

To the pipe 231 is united a source of oil at a pressure of, say, 250 pounds to the square inch, this being produced by any suitable pumping and storage arrangement (not herein illustrated). The low-pressure oil enters the system through a pipe 408 (Figs. 20 and 21), and since this oil tends to vary in volume as it flows back and forth between the active and inactive cylinders 224, there is joined to the admission-pipe 408 and pipes 409, which supply the ports 242, 242, a reservoir 410 mounted upon the extremity of the frame-portion 170, receiving any excess of oil due to its movements in the system and supplying and deficiency. To the top of this reservoir, air pressure of, for example, 50 pounds is admitted through a pipe 411. As leakage naturally occurs in the system and would decrease the height in the reservoir, means for maintaining this constant is provided. Within the reservoir operates a float 412, from which depends a rod 414 joined to a valve-plunger 416 movable in a casing 418 forming a portion of the pedestal upon which the reservoir is supported. As the float rises above a predetermined level, the plunger is elevated to close the port supplied by the pipe 408 for introducing the low-pressure oil, and to open an exhaust-port, from which leads a pipe 422 to the exhaust-piping (Fig. 59). If the float falls below the level fixed, the reverse action occurs, the delivery by the pipe 408 taking place and the exhaust-pipe 422 being closed.

It is preferable, as the stock is fed forward between the abutments to the bending mechanisms, to maintain its advancing portion in a horizontal plane, both supporting its weight and resisting the tendency to vertical deflection, which is liable to result in connection with the bending of material having a tapered cross-section, as does the die-stock A. For this purpose, a stock-carrier, freely movable in all directions horizontally, is preferably included in the machine. As is illustrated in Figs. 2, 4 and 37 of the drawings, there is pivoted about a vertical axis, upon a bridge-portion 430 of the frame, an arm 431. At the outer extremity of this arm is similarly pivoted an arm-section 432 carrying at its outer end a vertical spindle 433 adjustable through the arm by a lever 434, which may be fixed at different angles to secure the spindle at varying heights. Fixed to the spindle to turn with it is a carrier-arm 435, and swiveled at 436 to receive, with little friction, both upward and downward thrust is a yoke 437, upon the arms of which are swiveled stock-engaging members 438 and 439. The member 438 is provided at 440 with a vertically extending slot, so formed that the extremity of the die-stock, as it is projected from between the abutments, may

be inserted in and retained by it. This is particularly employed when the stock first emerges from the abutments and until the more effective engagement of the member 439 with the side of the stock may be had. The action of the two members in maintaining the stock against vertical displacement is, however, the same. The member 439 is recessed at 441 so that the side of the stock may be placed within it, it being secured therein by a clamping member including a cam-lever 442. After the stock has been secured in place in either of the members 438 or 439, the elements 431, 432 and 435 of the support will swing freely as the stock is advanced under the influence of the gripping jaws, maintaining it at a constant horizontal level without interfering with its feed.

Carriage for the operating mechanisms and its control

The carriage J, with the mechanisms and elements mounted thereon and the supporting and controlling means, may be seen in Figs. 1, 2, 22 to 32, inclusive, and 34. It consists of a plate-like casting having a central, enlargement 443 (Fig. 31) and various supporting bosses and brackets. Extending across the front of the main frame E and situated in vertical alinement are opposite ways 444, 444, in which the carriage slides. The hot-bending mechanism G is supported upon the left extremity of the carriage, as one views it from the operator's position, with the cold-bending mechanism H next to the right, and the cutting mechanism I at the extreme right. The carriage may be moved upon its ways to position the desired mechanism in operative relation to the outer ends of the abutments D, D by fluid-operated motor mechanism, preferably having oil as the pressure medium. Stops, against which the carriage is moved by the pressure, determine the operating positions of the respective mechanisms. These stops are later described in detail.

Opening outwardly through opposite ends of the carriage, and situated one above the other, are elongated chambers 445, 445 (Fig. 22) furnishing cylinders, into which extend tubular pistons 446, 446 fixed upon the frame, being held therein by coupling members 447. Connected to the pistons by these couplings, and communicating through them to the cylinders, are pipes 448, 448, which lead to the opposite sides of a reversing valve 449 (Figs. 23 to 26, inclusive). This valve has been already described in connection with the reversing valve 272 of the feed mechanism. Oil for the pressure-system is supplied by a pipe 450 to the valve-casing, exhaust occurring by way of a pipe 451 delivering back to the pressure-producing system. When the valve-elements have the relation illustrated in Fig. 25 of the drawings, the pressure ad-

mitted through the pipe 450 passes through the right-hand pipe 448, entering the corresponding cylinder 445 through its piston and exerting its force to move the carriage to the left, at which time either the cold-bending or cutting mechanism will be carried beneath the abutments. During this travel of the carriage, the oil in the associated cylinder 445 is passing through the left-hand pipe 448 and 10 into the exhaust-pipe 451. When the plug of the valve is rotated through 90 degrees to the position of Fig. 26, the connection of the pressure and exhaust-pipes is reversed, so that oil is admitted to the left-hand cylinder 15 445 and allowed to flow from the right-hand cylinder. At this time, the movement of the carriage brings the hot-bending mechanism beneath the forward ends of the abutments. Fixed to rotate loosely upon the outer extremity of the plug of the reversing valve is an 20 arm 453, joined by a link 454 to an arm 455 rising from a shaft 456 journaled in the lower portion of the frame and extending from front to rear thereof. Fixed upon the 25 shaft 456 is a treadle-lever 457 carrying a foot-piece at a point convenient to the operator's position. A spring 458, extending between the arm 455 and the frame, exerts its force to maintain the treadle 457 normally 30 elevated. Pivoted upon the lower extremity of the valve-arm 453 is a pawl 459 co-operating with ratchet-teeth 460, four in number and separated by angles of 90 degrees about the periphery of the valve-plug. A weight 35 461 upon the pawl, aided if necessary by a spring 462, holds the pawl for engagement with the ratchet-teeth. For each downward stroke of the treadle 457, the valve-arm 453 is swung to the left (Fig. 23), this, through 40 the pawl 459 and a tooth 460, turning the valve-plug through 90 degrees, so that it either assumes the position illustrated in Fig. 25 or that of Fig. 26. When the treadle is raised by its spring 458, the pawl slips idly 45 over the ratchet to permit the treadle and connecting elements to assume their initial positions. Consequently, each treadle-depression will, by the admission of pressure to one or the other of the carriage-cylinders 445, 50 move the carriage to different operating positions.

Journalized across the front of the lower portion of the frame, at the rear of the treadle 457, is a shaft 468, upon which is fixed a treadle 470, its foot-pad lying adjacent to that of the companion treadle. At the extremity of the shaft 468, above the treadle 457, is fixed an arm 472, this, upon depression of the treadle 470, rotating the shaft 456 in an 55 anti-clockwise direction (Fig. 23) to turn the reversing valve, as has just been described, by its contact with 457. At the opposite end of the shaft 468 from the arm 472 is secured an arm 474, to which is articulated a link 476, 60 the upper extremity of which is joined to an

arm 478 (Fig. 29) pivoted upon the frame and guiding the link in its movement. From the outer side of the link and arm is a projection furnished by a prolongation of the pivot-pin 480, this entering a slot in a link 482 pivoted at its upper end to a stop-block 484 mounted to turn about a spindle 486 carried at the top of the frame. A spring 488, connecting the link 482 and the frame, so acts upon the stop-block that, when free, it is 70 turned about its pivotal connection to the frame to swing downwardly and forwardly between the adjacent end of the carriage and said frame. When the treadle 470 is depressed, the connections from the shaft 468 raise the block 484 against the tension of the spring, so that it is removed from the path of the carriage. It will be seen that when the treadle 457 is depressed, the valve 449 is turned to reverse the travel of the carriage, but that when the treadle 470 is actuated, not only does this occur, but the stop-block is at the same time raised. The operation of the first treadle, when the block is left between the carriage and the frame, results in the bringing either the hot-bending mechanism or the cold-bending mechanism into operating position, while depression of the treadle 470, as a result of the removal of the block 484, permits the carriage to go to the cutting 80 85 90 95 position.

Carried horizontally in the stop-block is a rod 490, having at its opposite ends enlargements, one of which co-operates with the carriage and the other contacts with a screw 492 threaded horizontally through the adjacent end of the frame. This rod furnishes the actual stopping member for the carriage, it being held by a spring 494, interposed between its inner enlargement and the block, in such a 100 relation to the frame that it will clear the end of the screw 492 with certainty as the block swings in and out, yet will be carried into engagement with the screw when the spring is compressed as the carriage moves 105 into co-operation with the stopping device. This gives a definite limit of travel for said carriage, which is dependent upon the length of the rod between the outer surfaces of its enlargements. Variation in the carriage-position to properly locate the cold-bending mechanism beneath the stock is provided for by the adjustment of the screw 492. The correct alinement of the stop-rod with the stop-screw is determined by a screw 495 threaded through the block and contacting with the rear of the frame, this screw being turned to such a position that when it engages the frame the axis of the rod 490 substantially coincides with that of the screw 492. 110 115

When raised, the block 484 is temporarily held by a latch 496. This includes a rod 498 mounted to slide horizontally in the frame and having, acting upon it, a spring 500, which forces the inner end of the rod toward

a surface 502 upon the stop-block, which surface slides over the end of the latch as the block oscillates. When the block is elevated by the connections from the treadle 470, the forward end of the surface 502 is carried beyond the latching rod, which is pressed outwardly by its spring into the path of the block to hold it raised. For the next movement of the carriage in this direction, a portion contacts with a downward projection 504 from the latch, carrying the end of this out of the path of movement of the block and allowing the latter to swing downwardly against the rear of the carriage, upon which it rides until the next reciprocation of said carriage in the opposite direction permits the block to assume its stopping position between the carriage and frame.

To briefly sum up the action of the treadle mechanism K, it may be said that depression of the treadle 457, moving the valve 449 into the relation appearing in Fig. 25 of the drawings, admits the oil-pressure to the right-hand carriage-actuating cylinder to cause the travel of the carriage J to the left. The stop-block 484 will be at this time found in its active position, its latch having been tripped upon the preceding movement of the carriage in this direction, so that the arrest of the cold-bender in the operating position will result by the contact of the carriage with the rod 490, the latter being definitely positioned by the screw 492. A succeeding depression of the treadle 457 reverses the travel of the carriage by applying pressure to the other cylinder, at which time it is checked in the hot-bending position by the co-operation of its opposite extremity with a second stop-screw 492 corresponding to that which is engaged by the stop-rod 490. If, after the hot-bending position, the operator wished the cutting mechanism to become effective, he would actuate the treadle 470, instead of 457, which would not only admit pressure to the carriage-moving cylinder, but would also remove the stop-block from the path of the carriage. Contact would then occur between said carriage and the left-hand screw 492, to bring the mechanism to rest with the cutter beneath the abutments.

To reduce the shock to which the carriage and frame are subjected by the impact of the former upon its change of position, a cushioning device is so situated at each side of the carriage that it will contact with a screw 492 or with the stop-rod 490. Referring to Fig. 22, there is located at the end of each of the cylinders 445 opposite its piston a bushing 510, the opening through which connects the interior of the cylinder with a chamber 512 in the carriage beyond the extremity of such cylinder. Movable within each chamber is a plunger 514 having, extending outwardly through the end of the carriage, a reduced contact-portion 516, which is in horizontal

alignment with the corresponding stop 490 or 492. A spring 518, situated between the plunger and the bushing, holds said plunger normally outward, serving to return it quickly to its contact-position after it has been forced in by engagement with the stop. Fixed axially within each plunger is a pin 520 having a tapered inner extremity extending into proximity with the opening in the bushing and being alined with the axis thereof. In the normal position of the plunger, the pin is held by its spring and the pressure of oil within the cylinder, flowing through the opening in the bushing into the chamber 512, outwardly, as appears at the right of Fig. 22. When, in the travel of the carriage, the reduced contact-portion 516 strikes the stop, the pin is moved into the bushing-opening, the plunger driving the oil before it through such opening. As the pin advances in this direction, its tapered end reduces the area of the passage through which the oil is forced back into the cylinder by the plunger. The device thus acts as a dash-pot, exerting a gradually increasing resistance to compression, which is effective in bringing the carriage to rest without objectionable impact. The final stopping relation, in which the oil-passage is most contracted, is illustrated at the left in Fig. 22.

Clearly, injury to the machine and work might result, were the carriage J shifted during the operation of the bending mechanisms G and H or the cutting mechanism I. To prevent this, there is journaled in the frame, above the treadle mechanism K, a shaft 530 (Fig. 27), upon which shaft are fixed three arms 532, 534 and 536, projecting in a substantially horizontal direction toward the front of the machine. The arms 532 and 536 are respectively joined to portions of the hot-bending mechanism G at 538 (Figs. 2 and 34) and the cutting mechanism I at 540 (Figs. 2 and 119), which portions move upwardly when these mechanisms are brought into action. The arm 534 rests at 542 (Fig. 75) upon a nut or enlargement included in the cold-bender, which has a similar travel. Consequently, when any one of these mechanisms is in action, and therefore elevated from its normal or resting position, the shaft 530 is turned, through the connections to its arms, in a clockwise direction, as viewed in Fig. 27. Upon this rotation, an arm 544, which is fixed to the shaft 530, raises a link 546 and turns an arm 548 (Figs. 4 and 23) anti-clockwise about a shaft 550 journaled at the bottom of the frame below the treadle-shaft 456. At the opposite extremity of the shaft 550 is attached a pawl 552 engaging a vertical series of ratchet-teeth 554 upon the rear of the treadle-lever 457. A spring 556, extending between an arm 558 fast upon the shaft 550 and the arm 548, acts to turn the shaft 550 so the pawl may engage the ratchet-teeth. This is prevented, however, while none of the carriage-

supported mechanisms is in operating position, by contact of a pin 560 projecting from the side of the arm 558 with the arm 548. But when this arm 548 is raised as a result of the elevation of any one of the three operating mechanisms, it is withdrawn from the path of the pin, so that the spring turns the shaft 550 to bring the pawl into engagement with the ratchet-teeth. This locks the treadle 457 against actuation, and, because of the contact of the arm 472 with the upper side of this treadle-lever, the treadle 470 is also held against operation. The spring-connection at 556 provides for different degrees of movement of the elements which produce the oscillation of the pawl 552 and of the pawl itself.

As a further guard against movement of the carriage J when the bending mechanisms are in operation, there is provision for locking the treadle mechanism against operation when the feeler mechanism L is active. For this purpose, the air-pressure supply, when the feeler mechanism is in use for either hot or cold-bending, enters a cylinder 564 through a pipe 562 (Figs. 27 and 132). Within this cylinder is a piston 566, united by a link 568 to an arm 570 depending from the shaft 530. The piston 566 is normally maintained at the right of the cylinder (Fig. 28) by a tension-spring 572. Upon the admission of air-pressure to the cylinder as the feeler mechanism becomes effective, the piston is forced to the left, turning the shaft 530 in a clockwise direction (Fig. 27), or giving it the same movement as is imparted by the arms 532, 534 and 536. This, through the arms 548 and 558, turns the shaft 550 and brings the pawl 552 into locking engagement with the ratchet-teeth upon the treadle 457, in the same manner as has just been described, locking both treadles against actuation.

The hot-bending mechanism

It has been found a desirable practice to start the formation of the dies near a corner and upon a straight or only slightly curved side, for which side no bending action of the machine is required other than that which may be produced by the passage of the stock between the abutments D, D. Therefore, the carriage J is moved, either at or before the time of the stock is fed forward between the abutments for the attachment of the templet, to bring the hot-bending mechanism G into operative position. For illustration of the bending member 600, which directly contacts with the stock, and its supporting means, reference may be had to Figs. 2, 34 and 36, while various details of structure and control are shown in Figs. 1, 4, 35 and 37 to 66, inclusive. As appears most clearly in Fig. 37, the member 600 is of generally cylindrical contour over its contact-face, though somewhat inclined to conform to the taper of the stock upon which it is to operate. At 601

it is flattened or reduced to avoid interference with the work. It is carried eccentrically upon the top of a head or enlargement 602 formed upon the upper extremity of a sleeve 604 (Fig. 36). This sleeve is electrically insulated from a surrounding sleeve 606 by a bushing 608, these sleeves being arranged to turn together in a carrier 610, to which carrier a compound movement is imparted. The supporting body 612 of the carrier has vertical, oppositely extending tubular portions 614, 614 arranged to oscillate in brackets 616 projecting from the front of the carriage J and being also movable longitudinally therethrough. By virtue of this mounting upon the carrier-extensions 614, 614, the bending member 600 may be raised and lowered, while it may also be revolved about the axis of the extensions. At the same time, the member may independently revolve through rotation of its sleeves 604 and 606. This permits the bending member to be carried from an extreme inactive position below and at the rear of the forward ends of the abutments D, D upwardly to one side of and then against the stock, either at the right or left, to bend said stock over the opposite abutment, the oscillatory travel continuing over the space between the abutments in close proximity to their ends and along the outer, rounded wall to produce, if necessary, a bend in the stock at an acute angle. After the requisite bending action, the member 600 is returned to its normal position, or to some less remote inactive point clear of the line of emergence of the stock. In their movement-restricting effect upon the stock, while this is receiving the action of the bending member, the abutments may be considered as forming a portion of the bending mechanism.

To supply the component of movement of the bender in a vertical plane, a projection 618 from the carrier 610 enters a cam-groove in a cylindrical member 620 fast upon a vertical shaft 622 journaled in the carrier-extensions 614. This shaft is rotated through bevel-gearing 624 from a shaft 626 rotatably mounted in brackets projecting from the front of the carriage J. The shaft 626 extends outwardly through a frame-portion 628 carried at the left-hand end of the main frame E (Figs. 1 and 34), and is here covered by a guard-tube 630 fixed horizontally upon the outer side of this frame-portion. Surrounding the shaft 626 is a gear 632 (Fig. 42) fixed upon a sleeve 633 splined to the shaft so that the latter may travel through it longitudinally at the same time it is rotatable. The organization by which this gear 632 is rotated to the extent and in the direction necessary to give the proper movement of the member 600 under the control of the feeler mechanism L will presently be described. In the oscillation of the hot-bending member, two components of revolution are utilized. A

minor movement of revolution is effected through a gear 634 fixed upon the sleeve 606 and meshing with gear-teeth 636 upon the upper portion of the cylindrical member 620, so that as the shaft 622 is turned from the shaft 626, the sleeves 606 and 604 are rotated and the eccentrically mounted bender 600 is revolved through an arc of relatively small radius. A revolution through an arc of 10 greater radius is obtained by swinging the carrier 612 about the shaft 622. For this purpose, an arm 638, projecting from one side of the carrier-body, has joined to it a vertical pin 640 united by a link 642 to a bell-crank-lever 644 fulcrumed upon the carriage J. A projection 646, depending from the lower side of the arm of the bell-crank-lever opposite that engaging the pin 640, enters a cam-groove in a member 648 fast upon the shaft 626. The three movements of the member 600 result in the bending and withdrawing action previously outlined.

Because of the relative abruptness of ascent of portions of the cam-groove in the cylinder 620, which raises and lowers the hot-bender, assistance is preferably given in the elevating action which is secondary to the primary effect of the shaft 626. Secured to the carriage J is a bracket 650 (Figs. 2, 36 and 38) 25 having a depression to receive the rounded end 652 of a piston 654 operating within a cylinder 656, the upper rounded end 658 of which is received within a socket fixed to the carrier-body 612. A clip 660 is shown as 30 attached to the bracket 650, it having a portion entering an annular groove in the bottom of the piston. An arm 662 is attached to the carriage above the cylinder 656, and has in it a vertical slot to receive a pin 664 projecting from the cylinder-wall. This arm and the clip retain the piston and cylinder against displacement from the sockets by which their ends are received, yet allow lateral movement of these elevating members to compensate for 35 the oscillation of the carrier-body 612. Within the cylinder 656, received in a bore in the piston, is a spring 666, which at least partly counterbalances the weight of the elements carrying the bending member. Fluid under 40 pressure, air in the present instance, is admitted by a pipe 668 near the upper end of the cylinder. The opposite extremity of this pipe leads to a casing of a valve 670 (Figs. 34, 43 to 49, inclusive, and 132). The valve 670 45 is double, having plungers 672, 672 operating in cylindrical chambers both receiving air pressure through a pipe 674. Springs 682, 682 hold these plungers to normally join the cylinder 656 to exhaust-openings 676, 676. 50 The position of this valve to admit air to the cylinder 656 from the pipe 674 is governed by air supplied through pipes 678, 678 when the feeler mechanism L is causing, respectively, a right or left bend, and by rods 680, 680 which 55 are aligned with the valve-plungers at the ends 60

opposite those receiving pressure from the pipes 678. The rods are moved toward the valve-plungers to control the extent of their movement by cams 684, 684 fast upon the sleeve 633 of the bender-moving gear 632. These cams are of such contour that the positions of the plungers 672, 672 are synchronized with the inclined elevating portions of the cam-groove in the member 620 which is effecting the elevation of the bending member 600. That is, as one side or the other of this groove is moving the bender up into its working position, the corresponding cam 684 will so limit the movement of its plunger 672 that said plunger, urged toward it by the pressure in the pipe 678, will open communication between the pressure-pipe 674 and the pipe 668 to the elevating cylinder. At all other times than when the pressure should be thus applied, the rod 680 is inactive, and absence of air in the pipe 678 allows the spring 682 to so hold the plunger 672 that it cannot connect pressure to the elevating cylinder. The associated plunger, with its rod and cam, acts in the same way for the opposite side of the cam-groove. As a result of this, at predetermined periods when the ascent of the groove is most abrupt and least effective in its elevating action, pressure upon the cylinder 656 aids in raising the bender. 95

To rotate the gear 632 in one direction or the other and thereby impart to the member 600 its right or left bending movement in a horizontal plane, there mesh with the gear rack-teeth 700, 700, upon opposite bars 702, 702 each forming a part of like mechanisms V, V (Fig. 39). These bars are mounted to slide vertically in the frame-portion 628 and are guided by rolls 703. Since these rack-bars and the elements controlled by them are substantial duplicates, but one will generally be hereinafter described. Each bar is joined (Fig. 42) to a piston 706 operating in a cylinder 708, these cylinders being mounted in a casting 710 included in the frame-portion 628. Formed in an upper casting 711, beside each power-cylinder 708, is a valve-cylinder 712 (Figs. 39 and 40), in which is arranged to reciprocate a plunger-valve 714. This controls between its separated heads the admission through ports 717, 717 (Fig. 54) to the corresponding cylinder of oil-pressure supplied by a pipe 718, and also controls exhaust from the cylinder by way of a port 720 and pipe 722. A spring 724, situated between the upper end of each valve-plunger 714 and the adjacent extremity of its cylinder, holds such cylinder normally connected to the exhaust. From the under side of each valve-plunger is a projection 726 passing through the lower head of the cylinder, and connected to this is the rod 728 of a piston 730 movable in a vertical cylinder 732 carried on the frame-portion 710. Air-pressure, governed by the feeler mechanism L for the direction 100 105 110 115 120 125 130

of movement to which the associated motor-piston 706 is to respond, is delivered to the cylinder 732 by a pipe 734 (Figs. 35 and 132). At the same time, it flows through a contracted passage 736 to a horizontal cylinder 738 supported adjacent to the vertical cylinder. It there acts upon a piston 740 fixed upon a horizontal rod 742, which is articulated at 744 to the depending arm 746 of an equal-armed, horizontally extending rocker-lever 748 fulcrumed upon the casting 710, the lever having pivoted upon its outer extremities blocks 749 loosely surrounding the piston-rods 728. The horizontal piston-rod 742 serves for both the pistons 740, so it is moved by pressure admitted to either of the cylinders 738. Surrounding each piston-rod 728, and supported at its lower extremity on a flange 747 upon the rod, is a spring 750, the upper extremity of which contacts with the under side of a flange 751 upon its piston-rod. Extending upon opposite sides of each piston-rod, above its flange, is the forked end of an equal-armed connecting lever 752 fulcrumed on the frame above the lever 748. The upper side of the lever 752 bears against a flange 754 on the rod 728.

On the casting 710, below the arm 746 of the lever 748, is pivoted a pair of horizontally extending, double-ended pawls 756, 756. The respective ends of each pawl co-operate with contact-projections 758, 758, these projections depending below the sides of the arm 746 and preferably being arranged to slide thereon toward and from the pawls, but held normally downward by springs 760 (Fig. 41). When the lever 748 is in its horizontal position, it is maintained against oscillation in either direction by the engagement of the right-hand projection 758 (Fig. 39) with the corresponding end of the front pawl and the left-hand projection with the adjacent end of the rear pawl. The form of the contact-portions of the pawls and the associated ends of the projections 758 is such that the surfaces which are in contact in the manner just described hold the arm 746, and therefore the lever, against oscillation respectively in a clockwise and anticlockwise direction. But when the arm has been released by movement of the pawls and said pawls have again returned to normal, the engaging faces of the pawls and projections will slide over one another, the springs 760 yielding and allowing the arm 746 to regain its vertical locked position. Each pawl is normally held in the arm-retaining relation just set forth by a stop-projection 762 vertically adjustable upon a return-controlling slide 764 for the corresponding rack-bar 702. A tail from the front pawl (Fig. 39) rests upon the top of the projection rising from the right-hand slide 764, while the rear pawl is similarly held by a projection upon the left-hand slide, these elements being drawn into engagement by

springs 766, 766 joining the respective pawls to a portion of the frame. Each of the slides 764 is movable in vertical ways 768 in the frame-portion 710 (Fig. 55), being held normally raised, with its stop 762 in the pawl-retaining position, by a spring 770 joining a lateral projection 772 from this slide to an arm fixed to the casting 711. Depending from the slide is an actuating link 774 therefore, this link being divided at 776 to pass upon opposite sides of the corresponding rack-bar 702 and having, joining its outer ends, a contact-bar 778. Fixed or formed upon the side of each rack-bar, adjacent to the contact-bar 778, is a tooth or projection 780 (Fig. 42). The vertical location of this tooth upon the rack-bar is such that said tooth strikes the contact-bar when the bender has been moved in the direction determined by said rack-bar, as a result of its descent and action upon the gear 632, to an extent resulting in a travel of the bender to a point just clear of the stock at one side or the other. This is the position from which the bender is ready to move into engagement with the stock to produce its bending action. The link is held with the contact-bar resting against the side of the rack-bar in the path of the tooth, and the form of the contacting surfaces of the tooth and bar causes the former to engage and lower the latter in the continued downward or bending movement of the rack-bar, thus depressing the slide connected to this link. When the rack-bar rises, the contact-bar 778 moves with it until the initial position of the slide 764 is reached.

To arrive at an understanding of the action of the just described mechanism in causing, under the control of the feeler mechanism L, a bending movement of the member 600, with a reverse movement to its inactive position following the completion of the bend, it will be assumed that in the feed of the stock A carrying the templet B there has been a departure of said stock from the templet in a direction calling for a left-hand movement of the member 600. Under these circumstances, the feeler mechanism causes the supply of air to the right-hand vertical cylinder 732 (Fig. 39), forcing the piston 730 upwardly so that its rod raises the oil-valve 714, which is in control of the right-hand cylinder 708. Oil is therefore admitted to this cylinder 708, and the rack-bar attached to its piston is forced downwardly, rotating the gear 632 to raise and revolve, through its operating cams and gearing, the member 600 in the direction to produce the desired action upon the stock. The rotation of the gear 632 also raises the opposite rack-bar, the cylinder of which is connected to exhaust, this movement being an idle one. To prepare for the movement of the bender in the reverse direction, the air-pressure entering the vertical cylinder also passes into

the horizontal cylinder 738. This acts upon its piston to exert pressure upon the rod 742 tending, through the arm 746, to rotate the lever 748 in a clockwise direction to cause compression of the left-hand spring 750 between said lever and the flange 751. No movement of the lever 748 takes place, however, since it is at this time retained against oscillation in this direction by the contact of its right-hand projection 758 with the co-operating portion of the front pawl 756. The travel of the member 600 from its extreme position of downward and rearward withdrawal until it reaches a point adjacent to the side of the stock has no effect thereon, and since, up to the time of contact between the stock and bender, the latter will not interfere with the feed of the former, no provision need be made for the withdrawal of the bender to its initial position. But when the member 600 has reached the stock, the tooth 780 on the right-hand rack-bar arrives at the contact-bar 778, in preparation for the reverse movement of the bending member when the condition of the feeler mechanism indicates that the stock has been brought into agreement with the contour of the templet. It may be considered, then, that this has taken place and that the feeder mechanism has returned to neutral, in which case the member 600 should be carried clear of the path of the stock in preparation for its advance between the abutments. The action of the tooth 780 upon the bar 778, by lowering its slide, withdraws the right-hand stop 762 from the front pawl 756. This pawl is lowered by its spring, releasing the retaining lever 748, which rotates to compress the left-hand spring 750, exerting a clockwise rotating stress upon the connecting lever 752 through pressure of the flange 751. The right-hand end of this lever, however, is in contact with the flange 751 upon the rod 728 of the right-hand piston 730, the flange having been carried against the fork of the lever when the right-hand valve 714 was opened. When the feeler mechanism assumes its neutral relation, this results in an exhaust of the air-pressure from the right-hand cylinders 732 and 738, allowing the oil-valve 714 controlled by the cylinder 732 to close. This carries away the flange 751 from the right-hand end of the connecting lever, which turns clockwise, opening the left-hand oil-valve 714. The returning lever 748 during this action is held in its tilted position, although the pressure of the right-hand spring 750 has been released, because said lever is locked by the raised left-hand end of the front pawl which engages the left-hand projection of the lever-arm 746. The opening of the left-hand oil-valve admits pressure to the associated cylinder 708, resulting in a downward movement of the left-hand rack-bar 702, rotating the gear 632 and thus raising the right-hand rack-bar. Consequently, the right-hand slide 764 is released by the elevation of the tooth 780, and is drawn up by its spring 770. This lifts the front pawl to its initial position, unlatching the arm 746 by tilting said pawl left-handedly, and allowing the lever 748 to be rotated in an anti-clockwise direction by the left-hand spring 750. In this return movement, the yield of the right-hand projection 758 against its spring 760 permits this projection to pass over the now elevated co-operating right-hand end of the front pawl 756. The consequent lowering of the left-hand piston 730 allows the valve 714 actuated thereby to close, connecting the left-hand power-cylinder 708 to exhaust. Under the returning influence of the left-hand power-cylinder, the bending member 600 has been carried clear of the stock and there stops, without traveling to its extreme inactive position, unless the templet-control calls for an opposite bend, in which case the left-hand elements of Fig. 39 will be brought into action. If, on the other hand, after the stock has fed forward, bending in a left-hand direction is needed, the associated elements will become effective without unnecessary movement of approach of the member 600, functioning in the manner which has been outlined.

Instead of the feeler mechanism going to neutral governed by the relative movement between the stock and templet, the movement of the hot-bender may be arrested by a discontinuance of the automatic action of the machine, a device being provided for effecting this, which will hereinafter more particularly be described. In such event, the bending member 600 should assume its extreme inactive position, thus being not only clear of the path of the stock to prevent interference with the feed but also permitting movement of the carriage J, and this is provided for in the following manner: Formed in the frame-casting 711, adjacent to each of the valve-cylinders 712, is a cylinder 800 (Figs. 39, 40 and 42), in which moves a piston 802 held normally downward by air-pressure introduced by a pipe 804 whenever the feeler mechanism is in control of the member 600. Each piston 802 is connected by a bracket 806, upon which it is supported, to a rod 808 vertically movable through the frame. Fixed upon the rod, below the bracket, is a fork 810, the arms of which extend outside the forked portion of the connecting lever 752 and similarly contact with the under side of the flange 754. The air-pressure acting upon the piston 802 resists the expansive force of a spring 812 surrounding the rod 808, this spring tending to raise the fork 810 to open the oil-valve 714. The force of the spring is also resisted by a link 814 joined to the outer arm of a bell-crank-lever 816 fulcrumed upon the frame beside the gear 632.

- the corresponding rack-bar 702. The inner arm of the bell-crank carries a roll 818, which, when the bending member is at the extreme position, rests against an elevated surface 820 on said rack-bar, so that in this position of the elements the fork 810 is held against movement by the spring 812, even if pressure is withdrawn from the cylinder 800. Below the elevated surface, in vertical alignment with the roll, is a groove 822. This groove is so located that it will come opposite the roll 818 when its rack-bar has been raised by the gear 632, due to the bender-moving depression of the opposite rack-bar to a point at which the member 600 has left its extreme inactive position. The depth of the groove is such that when the roll enters it, the vertical travel of the fork 810 imparted by the release-spring 812 acts to open the oil-valve 714.
- To consider the general action of this returning mechanism upon the throwing-off of the automatic control of the feeler mechanism, the air-pressure is thereby removed from the cylinders 800. The idle rack-bar 702, which was raised during the downward stroke of the opposite bar producing the bender movement, has its groove 822 opposite the roll 818 at this side of the apparatus. Therefore, the force of the spring 812, being opposed neither by the pressure in the cylinder 800 nor by the contact of the roll with the surface 820 on the rack-bar, lifts the fork 810, raising the corresponding oil-valve 714 by contact with the flange 754 and admitting oil to its cylinder 708 to carry down the associated rack-bar. This rotates the gear 632 to move the bending member 600 rearwardly and elevates the opposite rack-bar. The travel of the bars continues until the surface 820 at the upper end of the groove of the descending idle bar arrives at the roll 818, swinging the bell-crank-lever 816, and through the link 814 lowering the fork 810 to permit the descent of the oil-valve, shutting off pressure from the cylinder and opening connection to the exhaust. Both rack-bars are now in the relation illustrated in Fig. 42 of the drawings, awaiting the control of the feeler mechanism, at which time pressure will be restored to the cylinders 800. The bending member 600 is at the extreme inactive position, so the carriage J may, if desired, be shifted without interference of the bender with the stock. When automatic control is again initiated, or if the operator desires to advance the stock under the manual control of the valve 354, the bending member will also be found clear of the stock.
- I prefer to guard positively against the feed of the stock at all other times than when the bending member is so located that it cannot interfere with the advance. To this end, the feeding action is governed by the bender returning slides 764. As has already been

explained, these slides do not start downward under the influence of the teeth 780 on the sides of the rack-bars 702 until the bender is engaging the stock. Each slide carries a yieldable pad 824 (Figs. 55 and 58) upon a bracket 826 fixed to the slide, this pad constituting the movable member of an air-valve. The body 828 of each valve is fixed to the frame-portion 710, and has an opening closed by the pad in the normal raised position of the corresponding slide. The opening in each casing 828 is joined by a pipe 830 to a leakage-valve 832, this leakage-valve being common to both the valves 828. As may be seen in Figs. 34 and 50, the leakage-valve 832 is supported across the sides of the cylinders 708, and is similar in structure to the valves 336 and 340. Air-pressure, admitted to the casing of the leakage-valve through a pipe 834 and the double-check valve 367, which has already been referred to, is conducted, under the control of the leakage-valve, by pipe 362, double-check valve 366, three-way cock 332 and pipe 328 to the under side of the piston 326 of feed-controlling valve 310 (Figs. 1, 5, 50 and 132). When both the slides 764 are raised by their springs 770, this being the relation at all times before the descent of a rack 702 has caused the bender to engage the stock at one side or the other, both valves 828 are closed by the pads 824, maintaining the leakage-valve 832 open. This provides for the delivery of air-pressure over the path just traced to the under side of the feed-controlling piston, so that the advance of the stock may take place. But when a rack-projection 780 has, by its contact with a bar 778, lowered the active slide at the time of engagement of the bender with the stock, the resultant slide-travel will open the way through the corresponding valve 828, to cause the closure of the leakage-valve 832. This, closing the passage of the feed-controlling air through pipe 362, renders impossible the opening of the feed-controlling valve 310, so that the stock cannot be carried forward until the valves 828 have both been closed by the return of the slides to normal, this condition obtaining only when the hot-bending member 600 is clear of the path of feed of the stock.

In the pipe 718, through which the oil-pressure is delivered to the hot-bender-actuating cylinders 708, 708, are two automatic valves 840 and 842. These are well illustrated in Fig. 50. The first determines, by the extent to which the passage through the valve is open, the speed at which the bending member 600 shall move, while the companion valve, by varying the quantity of oil flowing through the pipe 718, provides for different pressures of the member against the stock.

It is desired to avoid loss of time by bringing the bender as quickly as possible from its inactive position into proximity with the

stock, ready to apply the bending pressure. To avoid the shock produced by contact of the thus rapidly moving bender and the possible injury to the machine, this travel should be slowed just before the point of engagement is reached, and the movement completed at a less rate. To produce this effect, the valve 840 has a double-headed plunger 844, normally held at its upward limit of movement by a spring 846 interposed between the lower extremity of the plunger and the bottom of the valve-cylinder in which it moves. At this time, a port 848, governing the rate of flow of the oil through the valve, is opened to its maximum extent. Carried at the top of the valve-casing is a cylinder 850, in which operates a piston 852 resting upon the upper extremity of the valve-plunger 844 and being raised therewith by the spring 846. A pipe 853 leads from the top of the cylinder 850 to the casing of a leakage-valve 854 (Fig. 56), which is supported in a vertical position upon a frame 856 of generally H-form, fixed upon the lower extremity of a rod 858 depending from the frame-portion 628 (Fig. 34). To this frame-portion the rod is secured by a set-screw 859, this connection of the rod permitting the frame 856 to be vertically adjusted toward and from the lower ends of the rack-bars 702. Within the valve-casing, a plunger 860 is mounted to reciprocate, the form and action of these parts being as has already been defined in connection with the valves 336 and 340. It regulates the application of pressure to the piston 852 controlling the valve-plunger 844. Air-pressure is supplied to the leakage-valve 854 from a pipe 862, and exhaust 854 occurs through a port 864 at its top, while at the lower extremity of the valve-casing is a leakage-port 866, with which co-operates a pad or valve member 868 fixed upon a spring-arm 870 projecting across the top of the H-frame 856. Fulcrumed at 872 at the opposite horizontal extremities of the frame 856 are levers 874, 874 (Fig. 57), each of which has an arm 876 extending below the spring-arm 870 carrying the pad 868. A spring 878, joining each of the levers 874 to a depending portion of the frame 856, acts to so turn its lever upon its fulcrum that the arm 876 is held down, permitting the spring-arm 870 to maintain the pad 868 away from the leakage-opening 866. The valve 854 will thus be closed. Under these conditions, air-pressure will be cut off from the cylinder 850 and the spring 846 will hold the plunger of the valve 840 raised and the passage through the pipe 718 open to its maximum extent. At the opposite extremity of each lever 874 from its arm 876 is a forked portion having horizontally extending alined sockets 880, in which operate plungers 882 carrying opposed heads 884, these heads being held yieldably toward one another by springs 886 situated within the sockets. The space between each pair of heads, which lies in vertical alinement with the corresponding rack-bar 702, is such that the tapered end 888 of this bar may enter between the heads, forcing them apart against their springs and producing sufficient frictional engagement to cause the rack, in its descent, to tilt the lever 874 about its fulcrum. The extent of this tilting is adjustably limited by inclined stop-screws 889 threaded through depending portions of the lever contacting with the frame 856. The rack-bars are of such length and the frame 856 is so adjusted by positioning its rod 858 in the frame-portion 628 that this engagement between the rack-bar and friction-heads occurs as the bending member 600 approaches the stock. The tilting of the lever, raising its arm 876 against the spring-arm 870, elevates this to close the leakage-port 866 by the pad 868. The plunger of the valve 854 therefore moves to apply pressure from the pipe 862 to the pipe 853, forcing down the piston 852. This similarly lowers the plunger of the valve 840, decreasing the area of the port 848 to the desired extent. This contraction of the passage through the pipe 718 diminishes the rate of flow of oil therethrough, and consequently the speed at which the bending member 600 is moved by the rack-bar and other connecting elements. The amount of closure of the port in the valve 840, and thus the rate of movement of the bender, may be varied by vertical adjustment of a screw 891 threaded through the bottom of the casing of the valve 840 in alinement with its plunger, and with which said plunger contacts to limit its downward movement.

It has been explained that when the feeler mechanism assumes its neutral relation after initiating a right or left-hand bend, the bending member 600 may not return to its extreme inactive position, but stops just clear of the stock. The reverse or upward travel of the active rack-bar 702 in this return movement opens the leakage at 866 to cause the leakage-valve 854 to remove pressure from the piston 852, so that the valve 840 accelerates the movement of the bender. Were a bending action of the member 600 to occur from this point, it might be brought, in its rapid travel, against the stock before the leakage-valve had time to again act to produce the retarding effect. To avoid this and the resultant objectionable impact of the bender, there is situated upon the outer face of each rack-bar a projection 890 (Figs. 34 and 56), which is so placed that at this stopping point clear of the stock, the projection of the ascending bar contacts with the extremity of an upwardly extending arm 892 carried by an outward projection 894 from the corresponding lever 874. The outward thrust exerted by the projection 890 upon the arm 892 tilts the lever to close the leakage-port 866 and nullify the acceler-

ating action. Consequently, when the bending movement takes place, the retarding action is at once effective without waiting for the downward travel of the rack-bar. Delay in the action of the pneumatic system is thus compensated for. The projections are shown as in the form of plungers, yieldable against springs 896, this being to avoid interference as the projections pass beneath the guide-rolls 703.

The valve 842 (Fig. 50) for controlling the force exerted upon the stock by the bending member 600 is, as to its general characteristics, of a type commonly employed for maintaining a predetermined pressure. The heretofore-known structure of the valve need not be described in much detail, it including disks 900, 900 arranged to simultaneously open or close passages through the valve-body and being mounted upon a stem 902. With the lower end of this stem contacts a piston 904 operating in a cylinder 906 situated below the valve-casing, and having opening through its wall, beneath the piston, a pipe 908 communicating with the pipe 718 at the outlet side of the valve 842. A spring 910 surrounds the valve-stem, being interposed between a collar 912 threaded upon the stem and an abutment member 914, through which the stem is free to move. The tendency of the spring 910 is to hold the passages through the valve normally open. The parts of the structure are so proportioned and the tension of the spring so adjusted by movement of the collar 912 upon its threaded mounting, that the spring-pressure and the fluid-pressure transmitted through the pipe 908 balance each other, holding the valve open to a predetermined extent. If, because of any condition external to the valve, there is an increase of the pressure at the outlet side, this, acting through the pipe 908 upon the piston 904, will raise the disk 900 to reduce the area of the passage through the valve and lessen the pressure. If, on the other hand, this pressure falls, the spring becomes active to open the valve to a greater extent and thus restore the pressure to the desired amount. In the present organization, the abutment 914 is movable on vertical bars 918 upon the frame-portion 628 (Fig. 35). The abutment is connected by an intermediate frame 920 and a link 921 to an arm 922 upon a fulcrum-shaft 924 rotatable in the frame. Fixed upon the shaft are upwardly extending arms 926, 926, respectively contacting with cam-surfaces 928 upon the slides 764, which control the return of the bending member for its right and left movements. A strut-rod 930 is interposed between the mounting of the shaft 924 and the lower extremity of the cylinder 906, steadyng this and counteracting the movement which might be caused by the operation of the link 921. When the member 600 comes into contact with the stock, it is un-

der the influence of the pressure resulting from the normal balanced position of the valve 842. This is of the proper magnitude to bring the bending member into firm contact with the stock. This relation having been attained and heating current caused to flow between the bender and stock in a manner which will be explained, and this current having exercised its softening influence, it is desirable that the pressure be increased to produce the bend as quickly as possible. This saves time, avoids cooling of the stock after the application of current has been withdrawn to prevent burning the material, and overcomes the greater resistance which is encountered as the acuteness of the angle which is being bent increases. The relation of the cam-surfaces 928 to the contacting ends of the arms 926 is such that they lower the abutment 914 at a time when the stock has become softened by the heat and the bending begins. Downward movement of the cross-head increases the force which the spring 910 exerts upon the valve-stem, this overbalancing the pressure through the pipe 908 and opening the valve. As a consequence, the pressure at the outlet side of the valve 842 is increased, giving the results just outlined.

The circuit supplying current for heating the stock to facilitate bending is illustrated in Fig. 66 of the drawings. In this is included, in a diagrammatic manner, the bending member 600, various of its governing elements, which also play a part in the control of the current, together with back-pressure switches M, M, a relay-valve N, a secondary switch O, a back-pressure switch P, a primary switch Q, and switches R, R actuated by the bender-returning slides 764 to open the heating circuit.

Figs. 34, 35 and 58 show the switches M, M. Mounted side by side at the outer extremity of the frame-portion 710 are cylinders 940, 940, in each of which operates a piston 942, which is held normally at its lowest point by a spring 944. The spring is interposed between the piston and a threaded head 946 of the cylinder, the position of this head enabling the operator to determine the pressure exerted by the spring, and therefore the opposing force necessary to raise the piston. A pipe 948 opens into the lower extremity of each cylinder 940, and communicates at its opposite end with the corresponding bender-actuating cylinder 708. When movement of the bender, under the influence of pressure in a cylinder 708, is stopped by contact with the stock, the back pressure produced is exerted through the pipe 948 to raise the piston 942 of the associated cylinder. The rod 950 of this piston has, fast upon it outside the cylinder, a collar 952 containing a peripheral groove to receive the rounded end of a short arm 954 joined to a switch-lever 956, the upper end of which co-operates with contacts

958, 958 mounted within and protected by a casing 960. While the piston 942 is held in its downward relation by its spring, the switch-lever 956 is separated from the contacts 958. But when back pressure from the cylinder 708 through the pipe 948 forces the piston up against the spring, the elevation of the arm 954 swings the switch-lever down, closing the contacts.

10 The relay-valve N (Figs. 4, 59 and 60) includes a winding 962 surrounding one-leg of a core 964 carried at the rear of the frame E beside the frame-extension 170, the lower extremity of this leg of the core having, 15 pivoted upon it, an armature 966 raised and lowered by the magnetization of the opposite leg of the core and by gravity or under the influence of a spring, respectively. Upon this leg of the core, opposite the winding, 20 is clamped the casing of an air-valve 968, within which operates a valve-plunger 970. The lower extremity of the plunger extends below the casing for contact with the armature 966, it being there held normally by a 25 spring 972 situated between the upper extremity of the plunger and a bracket mounted upon the magnet-core. Air-pressure enters the cylinder by a pipe 974, and, when the plunger is raised against the force of its 30 spring by contact of the armature 966 with its lower end, passes through a pipe 976 to a cylinder 978 mounted upon the frame. In absence of this air-pressure upon the plunger, the pipe 976 is connected to an exhaust- 35 opening 980 in the valve-casing. Operating in the cylinder 978 is a piston 984, the rod 986 of which enters the upper extremity of the casing of an oil-valve 988. The plunger 990 of this valve, when forced down against a 40 spring 992, located between the bottom of the plunger and the lower head of the cylinder 988, by contact of the piston-rod 986 resulting from the supply of air to the cylinder 978, admits oil under pressure from a pipe 994 45 to a pipe 996 leading to the switches O and P. When the plunger 990 is raised by the spring in absence of pressure, the pipe 996 is joined to an exhaust-pipe 998. Since there may be in this piping system variations in 50 pressure, which, passing back into the pipes 998 and 996 might cause undesirable effects at the switch O, there is included in this pipe 998 a check-valve 999, which permits flow only in the direction of exhaust. Opening through 55 the side of the cylinder 988 is a pipe 1000, through which oil leaking by the plunger 990 may escape, thus guarding against its entrance into the air-cylinder 978. When current flows through the winding 962 of the 60 relay, its armature is lifted into contact with the plunger of the valve 968, admitting air to the cylinder 978 and forcing its piston down to lower the plunger 990 of valve 988, thus admitting oil to the switches O and P. 65 The pipe 996 of relay-valve N enters one

extremity of a cylinder 1002 of the secondary switch O, for illustration of which reference may be had to Figs. 62 to 65, inclusive. This switch O is arranged to connect and disconnect opposite sides of the secondary circuit 70 of a transformer 1004 to and from the bending member 600 and the frame, respectively. For this purpose, it has concentric, fixed inner and outer contacts 1006 and 1008 carried upon the frame below the carriage J. The 75 first-mentioned contact is united to the member 600 by a conductor 1009, and the second by a bar 1010 to the frame. The contacts 1006 and 1008 are insulated from each other at 1012 and from the frame at 1014. With them are respectively alined concentric inner and outer contacts 1016 and 1018, insulated at 1020 similarly to the fixed members and being so organized that the contact 1018 may slide within a bore in the frame, while the 80 contact 1016 is similarly movable within its companion. Attached to the frame, in axial alinement with the movable contacts, is the cylinder 1002, within which is movable a tubular piston 1024 situated opposite and connected to the movable contact 1018, and an inner piston 1026 arranged to move independently within the tubular piston and connected to the contact 1016. Insulating material 1028 is interposed between the pistons 95 and their respective contacts. Springs 1030 and 1032, the first of which is situated between a flange on the piston 1024 and the frame, while the latter is interposed between the insulation of the piston 1024 and a flange 100 upon the inner piston 1026, hold these and the connected movable contacts to the right, as viewed in Fig. 63 of the drawings, so that these contacts are normally separated from the fixed contacts. To lugs 1034, 1034, insulated from each other at 1036 and projecting from the sides of the movable contacts 1016 and 1018, conductors 1038, 1038 are connected, leading to the terminals of the secondary winding of the transformer 1004. It should 105 be noted that when the contacts are made, the flow of current will be in opposite directions through parallel paths. This will neutralize counter-electromotive forces, which would otherwise result from the passage of 110 the secondary current through an enclosing magnetic portion of the frame, and which, with a current of as low voltage as is employed in the secondary of the transformer 1004, would greatly reduce the available energy. 115

In connection with the operation of the switch O, pressure in a pipe 1040 joined to the pipe 996 is communicated to a cylinder 1042 of the back-pressure switch P (Figs. 59 125 and 61). Within the cylinder 1042 moves a piston 1044, which is normally held down by a spring 1046 situated between the upper side of the piston and an abutment 1048 surrounding the piston-rod 1050. This abutment is 130

maintained in position by a screw 1052 threaded through the top of the cylinder 1042, and which, when turned, will cause an alteration in the resistance of the spring and the force which it opposes to elevation of the piston 1044. To the top of the piston-rod 1050 is articulated a short arm 1054 of a switch-lever 1056 fulcrumed upon brackets extending upwardly from the cylinder. Under the influence of the spring 1046, this switch-lever is held separated from contacts 1058; but when pressure enters the cylinder through the pipe 1040 to raise the piston, the connection to the lever lowers it to close the contacts.

For the device Q, any suitable switch of the remote-control type may be employed, this having a magnet-winding 1060 (Fig. 66) to receive a relatively small energizing current, and acting through an armature 1062 to close contacts 1064 of a heavy-duty circuit, these contacts being normally open.

For an understanding of the switches R, R, reference may be had to Figs. 34 and 39 of the drawings. Mounted at each side of the frame-portion 628, adjacent to the slide 764, is a switch-lever 1066, normally held against a contact 1068 by a spring 1070. Secured to the fulcrum of each switch-lever to rotate therewith is an arm 1072 extending into the path of the pin 772 carried by the associated slide. When either of the slides 764 has descended to an extent which results from a substantial bending movement of the member 600, and the consequent application of heating current to the stock for a time necessary to properly soften it, one of the pins 772 contacts with the co-operating arm 1072 to carry the switch-lever away from the contact 1068, opening the circuit at this point.

In stating the general action of the heating circuit and the included mechanisms, it will be understood that current of the proper voltage is applied to the circuit from line-terminals 1074, 1074 (Fig. 66). Under the control of the feeler mechanism L, it will be supposed that the bending member has been moved against the stock by pressure in one of the cylinders 708, and, when it encounters the resistance interposed by the stock, stops in its movement. Thereupon the back pressure in the cylinder 708 is transmitted through the pipe 948 to the cylinder of the corresponding switch M, closing the contacts of this switch. This causes current to flow from the line over conductor 1076, just-closed contacts of switch M, conductor 1078, normally-closed contacts of switch R associated with the returning slide of the companion bending control mechanism, conductor 1071, closed contacts of the other switch R, conductor 1073, and the winding of relay-valve N to the opposite side of the line by way of conductor 1075. This energizes the magnet of the relay, opening the air-valve 968 and

causing oil to flow through the valve 988 to the cylinder of the secondary circuit switch O, carrying both movable contacts against the fixed contacts to complete the circuit from the secondary of the transformer 1004 through the bending member 600, the stock, with which the bender is now held in firm contact, and the frame. When proper contact between the members of the switch O has been attained, there will be back pressure through the pipe 1040 into the cylinder of the switch P, closing its contacts. We now have current from the line over the circuit just traced for relay N to the point 1077, then through conductor 1079, contacts of switch P, conductor 1081, winding of remote-control switch Q and conductor 1091 to the opposite side of the line. The switch Q thereupon attracts its armature and closes the primary circuit of the transformer, this not being effected until the secondary circuit has been properly closed and the bending member is firmly against the stock. As a result of this order of actuation, there will be no undue heating of the contacts. In the production of a bend of considerable extent in the stock, this condition will continue until the pin 772 strikes the arm of the switch R adjacent to the returning slide 764 which is moving downwardly, this determining the length of time of application of the current. The contact of the pin 772 opens the switch R, severing the initiating circuit at this point. This releases the remote-control relay Q to open the primary circuit, stopping the flow of heating current. At the same time, relay-valve N is de-energized, exhausting the air from its cylinder 978, actuating the plunger 990 to connect the oil-cylinder of the secondary switch O to exhaust and relieving the back pressure in the cylinders of switch P and switch O. The contacts in the secondary circuit are thus broken after the primary circuit. It is to be observed that before the contacts conducting the current of high volume can be separated or substantially weakened in their engaging pressure, the circuit is deprived of current at points through which only relatively small flow occurs, again preventing injurious heating. If, instead of the bend having progressed to the point just described, the action of the machine had been interrupted accidentally, manually by the operator, or there had been a return of the feeler mechanism to neutral after making a relatively small bend, this occurring before the time of opening of switch R, the initiating circuit would have been severed at the contacts of one of the switches M. This de-energizes the magnet-relay Q, which, similarly to the manner just described, opens the primary circuit prior to the secondary circuit, with the absence of the heating effect noted. However the cutting off of heating current is accomplished, the switches are carried back

to their normal positions by their springs, M, M, O opening their contacts upon the withdrawal of pressure, N shifting the air-valve to its closed position, P and Q separating their contacts, and the switches R, R being closed.

While not essentially a part of the hot-bending mechanism, there is supported with it, upon the cylinders 708, a device S (Figs. 34, 50, 51 and 52), which exercises control over both the hot and cold-bending, determining the air-connections for these operations. This device S, which I term a triple valve, may conveniently be described at this point. It has three sections 1080, 1082 and 1084, which determine the application of air-pressure for the feeding of the stock, the left-hand bending and the right-hand bending. Each section includes a cylinder formed in a body-portion 1086 common to all, and in which cylinders operate identical double-headed plungers 1088. Air, the connections for which are best illustrated in Fig. 132, is admitted to section 1080 through a centrally located pipe 1090 joined to the source of pressure, while sections 1082 and 1084 receive air through similarly positioned pipes 1092 and 1094, respectively, leading to the feeler mechanism L. These last-mentioned pipes also communicate with the pipe 376 to the feeding mechanism through the double-check valve 377. From the upper portion of the section 1080 there is a connection 1096, which supplies air-pressure to the feeler mechanism L and communicates with the feeding mechanism F, and another 1098 which supplies air to the hot-bender return-control cylinders 800, to a portion of the feeler mechanism and to the air-cylinder 968 of the relay-valve N. From the lower portion of this section 1080 a pipe 1099 passes to the cold-bending mechanism, from which connection is made to a pipe 1100 with the feeding mechanism over the same path as that from the hot-bending mechanism by the pipe 1096. From the upper portions of the sections 1082 and 1084, pipes 1102 and 1104 supply air respectively to the left and right bender-valve-actuating cylinders 732, 732 and 50 to the valve 670 of the elevating cylinder for the bending member 600, the latter by way of pipes 678, 678. At the lower portions of these sections, pipes 1106, 1108 respectively provide for left and right-hand bending action of the cold-bending mechanism.

Whether the central air-supply-pipes shall be united to the upper or lower delivery-pipes for hot or cold-bending is determined by the position of the carriage J. Each plunger has 60 connected to its lower extremity, in vertical alinement, a rod 1110 (Fig. 50), the three rods for the plungers of the three valve-portions being mounted together upon a horizontal connecting bar 1112. A spring 1114, sur-

65 rounding the central rod 1110, urges all of

the rods and their plungers to their lowest positions. Opposite the central rod 1110, which is shown as of greater diameter than its companions and guided for vertical movement by brackets 1116 and 1118 fixed to the valve-body 1086 and to the frame-portion 628, respectively, is an actuating rod 1120 for the plungers. This rod has threaded into its upper extremity a screw 1121, the head of which contacts with the opposite rod 1110, and by its position determines the normal relation of the plungers to the pipes communicating with the valve-cylinders. Mounted to slide at 1122 upon the frame-portion 628 is a bar 1124 (Figs. 1, 34 and 50), joined at its inner extremity to a stud 1126 rising from the bearing of the hot-bender actuating shaft 626, this bearing being movable with the carriage J. The upper edge of the bar 1124 slides beneath and furnishes a support for the lower end of the rod 1120, there being an extended surface 1128 upon the bar, which, when in contact with the rod, holds the valve-plungers in their intermediate positions, at which the ports to the upper and lower delivery-pipes of all the valve-portions are closed to the supply-pipes, but are opened to exhaust-ports 1130 through the upper and lower extremities of the cylinders. In the hot-bending position of the carriage, an upward projection 1132 from the surface 1128 of the bar 1124 is beneath the rod 1120, raising this and the plungers to connect the supply-pipes with the upper delivery-pipes, which furnish the connections for the hot-bending operation. In the cold-bending position of the slide, a depression 1134 is aligned with the rod 1120, permitting the valve-plungers to be lowered by the spring 1114 until they join the lower set of delivery-pipes to the supply-pipes. This provides the air for the cold-bending connections.

When the carriage J is traveling between the hot-bending and the cutting positions, it is not desired that the triple valve S shall be shifted from its neutral relation to that for cold-bending, as would be the case were the rod 1120 allowed to fall into the depression 1134 as this passed beneath it in the travel of the bar. To prevent such an effect, I have associated with the actuating mechanism for the triple valve a temporary lock for the plungers and for their rod 1120. Pivoted to the top of the stop-block 484 (Figs. 29, 30 and 34), which block, when lowered as appears in these figures, stops the carriage in the cold-bending position, and which, when raised, allows it to move to the cutting position, is a link 1136. To the upper extremity of this link is articulated by a slot-and-pin connection 1137 a retaining member 1138 (Fig. 53), swinging upon lugs 1140 depending from the under side of the bracket 1116. The hooked upper end of this member 1138 may be moved by the link beneath

a collar 1142 upon the rod 1120, there being a surface 1144 of the member upon which this collar may rest. At this time, the rod 1120 is supported with its lower end at the surface 1128 of the bar 1124. When the stop-block 484 is moved downwardly to bring the carriage to rest in the cold-bending position, the link 1136 draws the retaining member 1138 away from the rod, so that the collar 1142 is freed and the valve-plungers 5 may be carried down to establish the cold-bending connections. When, however, the stop-block is swung outwardly so that the carriage may go to the cutting position, the link permits a spring 1137 to bring the member 1138 into its locking position, in which the surface 1144 is arranged to receive the contact of the collar 1142. Consequently, when the depression 1134 now arrives below 10 the rod 1120, it finds said rod supported independently of the surface 1128, so the depression may pass beneath the rod without affecting the valve-plungers. The connection 1137 allows for differences in the extent of 15 movement of the elements joined.

The cold-bending mechanism

The cold-bending mechanism H appears in Fig. 2 in its position upon the carriage J 30 between the associated hot-bending mechanism G and the cutting mechanism I, and in Fig. 67 as separated from these. Its structural details, including its controlling valves, are made the subject of Figs. 68 to 82, inclusive. Secured to the front of the carrier is a yoke-shaped bracket 1150, pivoted to which, at 1152 within the curve of the yoke, is a generally cylindrical carrier-casing 35 1154. Between the casing and the arms of the bracket at each side is a sufficient space to permit the swinging of the former about its pivot. Fitting the cylindrical interior of the casing is an inner carrier-cylinder 1156 (Figs. 70 and 71) having a central, cylindrical depending portion 1158, the inner carrier being supported at 1160 upon the casing by means of a ball-bearing. An upper ball-bearing 1162 guides the carrier 1156, and receives its lateral thrust. Annular plates 1163, 40 1163 upon the upper end of the casing and on the carrier close the opening between these members to prevent the entrance of dirt. Movable vertically in the carrier-cylinder 1156 is a piston 1164, having at one side 45 a segmental upward extension 1166. At each side of this extension are oppositely curved guiding walls 1168. Passing loosely through an axial opening in the piston is a rod 1170 carrying at its upper end a bender-operating 50 yoke 1172, which is guided for movement in the piston by contact of one arm with the extension 1166, and engagement of the other arm with an opposite separable wall 1173 of the piston. A segmental member 1174 (Fig. 67) secured to the interior of the carrier-

cylinder compels the rotation of the piston 1164 with said carrier-cylinder. Joined to a horizontal pin 1176 extending between the arms of the yoke are body-portions 1180, 1180, each having a slot 1178 to receive the pin and provided at its upper end with a bending projection 1182. These projections are arranged to contact respectively with the stock at opposite sides, and are eccentric to the axis of the cylinder 1156. The body-portions 1180 of the benders are generally in the form of flat plates, the adjacent sides of which move over each other. Fixed in horizontal positions upon the top of the piston-extension 1166 and upon the wall 1173 are 55 opposite bars 1184 and 1186 (Fig. 80), which guide and receive the side thrust of the upper part of the bender-portions 1180. The opposite outer edges of these body-portions are oppositely curved to correspond to and move over the curved edges 1168 of the walls. The result of this engagement is that when the benders are in their highest positions in the piston, which is their normal relation when the cold-bender is inactive, they are 60 separated (Fig. 67); but when the curved walls of the piston are forced along them, they are swung together upon these walls to bring the projections 1182 into close proximity with the sides of the stock (Figs. 69 and 70). The portions 1180 of the benders are provided with overlapping walls 1188, 1188, which, in the closed position of the benders, bridge the space between them, furnishing a continuous surface on which the stock may rest as it is fed forward. This supporting surface is continued by the top of the bar 1184. In the inner faces of the projections 1182 are generally vertical depressions 1190, these giving spaces into which the stock may be bent in its formation, and thus 65 permit the projections to be nearer together during the time at which they are exercising their bending effect, which is produced by rotating the inner carrier member 1156, with which turn the rod 1170, its yoke and the bending members. The normal position of the benders is as appears in Fig. 67 of the drawings, with the upper ends of the bender-projections 1182 below the corresponding 70 end of the carrier-cylinder 1156. At this time they are entirely clear of the path of the stock to permit the movement of the carriage J without interference. If the piston is forced up by fluid pressure introduced to the interior of the cylinder 1156, the yoke and the benders united thereto are first carried with it, spaced therefrom by a spring 1192 seated in a depression in the upper face of the piston about the rod 1170 and contacting at its opposite extremity with the under side of the yoke. When the elements are 75 thus held apart, the engagement of the curved walls 1168 maintains the bending projections 1182 separated from each other, as has previ-

ously been described, ready to be raised to opposite sides of the stock. When they are elevated, the nut 542, threaded upon the bottom of a reduced portion of the rod 1170 and 5 retained in place by a lock-nut 1194, contacts with the adjacent end of the cylinder-extension 1158. The cooperating arm 534 is at this time forced to one side, as appears in Fig. 75. This stops the elevation of the benders, while 10 that of the piston may continue, compressing the spring 1192. Consequently, the walls 1168 now travel over the curved surfaces of the benders, bringing them toward each other, from points removed from the sides 15 of the stock, close to it ready for the bending action. The movement of the piston is arrested, with the benders at the working point, by engagement of its upper face with a stop-screw 1196 adjustable vertically through the 20 guide-segment 1174. The benders appear in their raised or operative relation in Figs. 69, 70 and 71 of the drawings.

Upon the lower extremity of the cylinder-extension 1158 is an external thread to receive a nut 1198, which supports a lower head 1200 for the cylinder-extension, the diameter of this head being shown as equal to that of the upper or body-portion of the cylinder. The outer, lower peripheral portion of the 25 head is threaded for engagement by a nut 1202, upon which is supported an outer cylinder 1204 by means of a ball-bearing 1206. Upon the opposite ends of the cylinder 1204 are annular heads 1208, 1208 fitting about 30 the main portion of the carrier-cylinder 1156 and its lower head 1200, they forming there-with fluid-tight joints. Projecting from the front face of the carriage J, beneath the lower head of the outer cylinder, is a bracket 1210, 35 joined at its upper face to the adjacent cylinder-head 1208 by a coupling 1212, which may be of the Oldham type, this allowing the 40 oscillation of the outer cylinder with the inner cylinder and its casing about the pivot 45 1152, while holding it against rotation. The outer cylinder may thus follow the benders in their movement, and yet serve to transmit to them the rotary effect which produces the bending action. Secured to the inner wall of 50 the cylinder 1204, lying vertically between its heads, are segmental abutments 1214, 1214 (Fig. 72), the axes of which are separated from each other by 180 degrees. Held between the main body of the inner cylinder 55 1156 and its head 1200 by nipples 1216 are segmental abutments 1217 corresponding to the cylinder-abutments 1214. These abutments 1217 are similarly separated by 180 degrees, and are, in effect, pistons, which 60 respond to pressure introduced between them and the fixed abutments to rotate the carrier-cylinder 1156 and therefore revolve the benders. Passing vertically through each of the abutments 1217 is a passage 1218 opening 65 through the nipples 1216 into the cylinder

1156 and being continued downwardly below the head 1200 by a pipe 1220. These two pipes of the movable abutments at 1222 have connection with a casing 1224 swiveled at 70 1225 to a pipe 1226 (Fig. 75), through which oil under pressure may be delivered, this flowing from the casing through the pipes 1220 and the passages 1218 to the carrier-cylinder 1156 to raise the piston 1164 for the elevation of the benders. The piston and connected elements may be returned to their normal positions by gravity. 75

To revolve the members 1182, 1182 about the axis of the cylinder 1156, which extends vertically between them, to produce their bending effect, the outer cylinder 1204 has a lateral projection or boss 1228, through which are upper and lower passages terminating at pairs of ports 1230, 1230, 1232, 1232, respectively. The ports of each pair open 80 through the cylinder-wall at opposite sides of the fixed abutments 1214. If pressure is applied through one pair of ports, the movable abutments 1217, and with them the benders, will be turned in one direction to correspondingly bend the stock; and, if it is applied through the other pair of ports, it will turn the abutments and benders in the other direction, thus oppositely deflecting the stock. 85 As the stock is so bent, assuming a new direction in its advance by the feeding mechanism, movement of the casing 1154 about its pivot 1152 allows the benders to adapt themselves to the altered relation. This leads to a maintenance of a balance of the forces exerted by the benders, which act as a pure couple, avoiding the deformation of the abutments by pressure of the stock against them through unbalanced stresses. Since the cylinder 1204 shares in the movement of self-accommodation, it in no way interferes with 90 95 this action. 100

Were pressure to be applied to the pipe 1226 to elevate the benders and the elements chanced to be so related that said benders 110 struck the stock or abutments, instead of assuming their correct positions at opposite sides of the stock, injury to the machine might result. To guard against this, the fluid from the pipe 1226 flows to the pipes 1220 115 through a cylinder 1234 (Figs. 75 and 81), which is formed within the casing 1224. The passage of the fluid through this cylinder is under the control of a valve-plunger 1236 having spaced heads and an intermediate reduced portion, one of the heads being of greater diameter than the other. The pressure through the pipe 1226, acting oppositely upon these heads, tends to force the valve-plunger to the left, as viewed in Fig. 75 of 120 125 the drawings; but this tendency is resisted by a spring 1238 situated in a casing-projection 1240 in horizontal alinement with the valve-cylinder. Movable in the plunger and forced upwardly by a spring 1243 is a latch 130

1242, which, in the open position of the valve, when flow between the pipe 1226 and the pipes 1220 is uninterrupted, is opposite a bore through a boss 1244 upon the casing. Guided in the bore is a plunger 1246, forced normally downward by a spring 1248, which is of greater strength than the spring 1243, holding the latch 1242 depressed. If, when the benders are raised and before they have reached their uppermost operating position, abnormal resistance to movement is encountered short of the operating position, as already indicated, the back pressure becomes effective in the cylinder 1234. This, acting against the head of the valve of greater diameter, moves the valve-plunger against the force of the spring 1238, shutting off the pressure from the pipe 1220, stopping the upward movement of the benders and preventing injurious contact. At this time, the upper end of the latch 1242 slides along the aligned lower surface of the plunger 1246 and the wall of the casing-portion 1240. If, however, no such interference as has been assumed occurs and the benders rise unimpeded to their working position, a collar 1249, held between the nut 1194 and a nut 1251 upon the rod 1170, contacts with the under side of a head 1250 on the plunger 1246. This lifts the plunger, freeing the opening in the boss. Under these conditions, the latch is raised into the bore in the casing-boss by its spring 1243, retaining the valve-plunger against movement. Therefore, communication between the pipe 1226 and the pipes 1220 remains open, and the normal application of pressure may be continued to further elevate the piston 1164 and close the bending members 1182 into proximity with the sides of the stock.

To control the reciprocatory and rotary movements of the cold-bender, a manually operable valve T and an automatic valve U are included in the mechanism H (Figs. 2 and 67). These valves may have their bodies furnished by a single casting 1252 carried upon the boss 1228 of the cold-bender rotating cylinder 1204. The manual valve T alone determines the vertical or active and inactive positions of the bending members, and with the assistance of the automatic valve may govern the bending rotation. The valve U co-operates with the manual valve, as just indicated, and also acts similarly with the feeler mechanism L.

Considering the valve T, there is formed in the body 1252 a cylinder 1254 (Fig. 77), which may be internally bushed. In the wall of this cylinder is a central delivery-port 1256 connected by the pipe 1226 and its swivel connection 1225 to the pipes 1220, 1220 leading to the elevating cylinder 1156 of the cold-bender. Above the delivery-port is a supply-port 1258 connected by a passage through the body 1252 to a pipe 1260 (Fig. 76), which communicates with the upper cylinder 445 in the carriage J (Fig. 22), in which there exists fluid pressure whenever the carriage is in the cold-bending or cutting positions. Below the delivery-port is an exhaust-port 1262, from which a pipe 1263 leads to the base of the machine. Operating within the cylinder 1254 is a double-headed valve-plunger 1264, upon the upwardly extending stem 1266 of which is fixed a handle-lever 1268 projecting horizontally toward the operator's position. Fixed in an outer movable section of this handle is a latch-rod 1270, held by a spring 1272, interposed between the inner section of the handle and a shoulder upon the rod, into one or another of lower and upper horizontal arcuate grooves 1274 situated in the inner surface of an upward extension 1275 from the head of the cylinder 1254. By drawing out the section of the handle carrying the rod 1270, its inner end may be released from the lower groove, which it normally occupies, or in which it rests when the cold-benders are lowered, and the valve 1264 thus freed elevated until the latch-rod is aligned with the upper groove, release of the rod by the operator, and its consequent engagement with the upper groove, locking the valve in this position. With the valve latched in its lower position, the delivery-port 1256 is joined to the exhaust-port 1262, so that the piston 1164, which controls the elevation of the cold-benders, is free to fall by gravity, establishing their inactive relation. With the latch-rod in the upper groove, the delivery-port is joined to the supply-port 1258, so fluid pressure passes through the pipe 1226 and pipes 1220 into the cylinder 1156 to raise the cold-benders and bring them together into co-operation with the sides of the stock. Resistance is offered to the rotation of the handle 1268 by engagement of the end of the latch-rod within the grooves with series of depressions, shown as formed in arcuate bars 1277 secured at the bottoms of the grooves. These cause the handle and valve-stem to remain in the position to which it may be set by the operator. In both its vertical movement and that of rotation, the valve 1264 acts upon the automatic valve U through connections which will be described after a statement of the general structure of said valve U has been given.

Besides the cylinder 1254 in the body 1252 is a cylinder 1276 (Fig. 78), which may, as in the companion cylinder, be provided with an internal bushing. The cylinder 1276 has a central supply-port 1278, joined to the pipe 1260 from the source of fluid pressure at the carriage J. At opposite sides of the port 1278 are delivery-ports 1280, 1281, communicating respectively through the boss 1228 with the ports 1230 and 1232 in the cold-bender revolving cylinder 1204. Above and below these delivery-ports are exhaust-ports 1282, 1282, which open into a pipe 1284 con-

ected to the lower cylinder 445 in the carriage J. This last-mentioned cylinder is, at the time the slide is in the cold-bending position, connected to exhaust. The cylinder 1276 contains a valve-plunger 1286, having four circumferential flanges or enlargements 1288. These are so spaced from one another, that when the valve is in its central position all the ports are closed. If the valve is lowered, the upper delivery-port 1280 is in communication with the supply-port 1278, while the lower delivery-port 1281 is connected to exhaust at 1282. This provides for revolution of the cold-benders in one direction by pressure applied to the movable abutments 1217, while upon raising the valve, the pressure is introduced into the cylinder 1204 to cause revolution in the opposite direction. Fixed upon the top of the cylinder 1276 is a cylinder 1290, in which is situated a piston 1292, and above and below air-pressure may be introduced by the pipes 1106 and 1108 (Figs. 1 and 132) leading respectively from the left and right bending sections of the triple valve S, which govern the application of air from the feeler mechanism. Below the cylinder 1276 is a casing 1294 surrounding a double piston member 1296. The valve 1286, the piston 1292 and the piston 1296 are connected to move together vertically by a rod 1298. This rod passes through axial bores in the two members first mentioned, and is threaded at its lower end into the piston 1296, while its upper end is conical, being received by a corresponding surface surrounding the bore in a portion of the piston 1292. There is some slight lateral play permitted, whereby, when the rod is turned down to hold the members together, they may aline themselves within their cylinders to travel therethrough without undue resistance. At the same time, they are clamped against relative movement longitudinally by the rod. In this clamping relation, the rod is locked against rotation by an arm 1300 extending from its outer extremity and being forked to lie upon opposite sides of a pin 1302 rising from a collar 1304 threaded about a portion of the upper head of the cylinder 1290. The collar 1304 is preferably split, so it may be held against rotation by a screw 1306 threaded through the opposite sides of its divided portion. The vertical movement of the valve member 1286 is limited to establish the proper relation between the ports when it is raised or lowered, by collars 1308, 1308 threaded about the outer ends of the pistons 1292 and 1296. These collars may be adjusted and fixed at the desired points similarly to the collar 1304, and strike respectively against the adjacent heads of the cylinder 1290 and casing 1294 in exercising their valve-limiting effect.

To raise and lower the valve-plunger 1286 under the influence of the manual valve T, the plunger 1264 of the latter has, attached to its stem, a downward extension 1310, to which is splined at 1311 for longitudinal movement the supporting body 1312 of an actuating segment 1314. The upper and lower edges of this segment lie between the adjacent flanged ends of cylinders 1316, 1316, which surround upper and lower portions of the piston member 1296. These cylinders are forced by springs 1318, 1318, which contact with their adjacent flanges and with split stop-collars 1320, 1320 threaded about oppositely projecting portions of the casing 1294, against a circumferential flange 1322, the width of this flange being substantially equal to that of the segment 1314. The effect of the springs is to normally maintain the valve-plunger 1286 and its connected pistons in their central position, with the valve-ports closed. Movement of the segment, either up or down, will compress the spring at that side, carrying the end of its cylinder 1316 away from the flange 1322. This leaves the opposite spring free to expand and thus move the valve in the same direction as the segment 1314 is traveling to open delivery and exhaust-ports and produce the desired revolution of the cold-benders. Projecting from one side of the mounting of the segment 1314 is a roll 1323 entering a cam-groove 1324 in a cylindrical member 1326 surrounding the extension 1310 of the manual valve-spindle and within a portion of the segment-body 1312. The form of this groove is best shown in Fig. 82 of the drawings, it having a central inclined portion terminating in portions approximating a horizontal direction. As the spindle-portion 1310 is turned by the handle 1268 to the right or the left, the roll 1323 rides up or down the groove 1324 to raise or lower the segment 1314 bodily and similarly actuate the valve 1286, to rotate the cold-benders in a right or left-handed direction. Formed upon the lower extremity of the cylindrical member 1326 is a laterally projecting arm 1328, joined by a link 1330 (Figs. 67 and 70) to one of the pipes 1220 which supply the cold-bender elevating cylinder, and which turn with the inner carrier member 1156. Near the upper end of the member 1326 are opposite cam-walls 1332, between which lies a projection 1334 from the arm of a lever 1336 fulcrumed at 1338 on the valve-body 1252. The opposite arm of the lever has articulated to it a vertically extending link 1340, which is pivoted at its lower end to the flange 1322 of the piston member 1296. It will now be understood that the rotation of the segment 1314 by the handle 1268 will raise or lower the valve member 1286 to produce a revolution of the cold-benders in the same direction as that in which the handle is moved. As the cold-benders thus turn, the pipe 1220, to which the link 1330 is connected, communicates its movement of revolution to the cylindrical member 1326. This brings the cam-groove 1324 into engagement with the roll 1323.

1323 to lower or raise it and the segment. Consequently, the piston member 1296 and the valve 1286 are shifted in the opposite direction to the movement imparted under the influence of the handle 1268, closing the previously opened delivery-port to stop the rotation of the cold-benders whenever the operator ceases turning said handle. If there is an excessive movement of the cold-benders, either manually or automatically effected, one of the walls 1332 will engage the projection 1334 before the rotary abutments 1217 can contact with the fixed abutments 1214. The lever 1336 is thereby shifted to raise or lower the piston 1296 and close the valve 1286, thus stopping the rotation of the carrier-cylinder 1156 and preventing injury to the machine.

To prepare the valve U for purely automatic control of the cold-bender, there is associated with the manual valve T a valve 1342, within the casing of which is a reciprocatory plunger 1344 having spaced double heads. This valve governs the application of air-pressure from the pipe 1099, receiving said pressure from the controlling section 1080 of the triple valve S when the latter is in its cold-bending position, to a flexible pipe-section 1346 leading to a bore 1348 formed in the piston-portion 1296 movable with the valve 1286. The flexibility of this pipe-section allows for the movement of the valve and associated pistons without interference. Rising from the plunger 1344 is a stem 1350 entering an elongated chamber 1352 in the lower extremity of the extension 1310 of the manual valve. The space between the opposite heads of this chamber 1352 is such that when the handle 1268 of the manual valve is raised and in its latched position, the valve-plunger 1344 is so elevated by the contact of a head upon its stem with the lower end of the chamber that the pipe 1099 communicates with the pipe-section 1346, admitting pressure to the bore 1348 in the piston-portion 1296. Upon lowering the handle to its opposite extreme or latched position, the pipe 1099 is closed by the plunger, and the piston-chamber is united to an exhaust-opening 1354 through the casing of valve 1342. In these extreme positions, the plunger 1344 is retained during the movement of the manual valve to the opposite extreme by a spring-pressed latch 1356, the pointed end of which may enter one or the other of two circumferential grooves 1358, 1358 about said plunger. One of the grooves having been brought into alignment with the plunger by the movement of the manual valve to one end of its travel, it will there remain during the opposite travel of the valve, until the contact of the corresponding end of the chamber 1352 with the head of the stem 1350. At this time, the pointed end of the latch is forced back by the wall of the

groove in which it has rested, and the plunger is shifted in the final movement of the manual valve until the opposite groove reaches it. This it will enter and again retain the plunger, awaiting reverse travel of the valve. When pressure is applied to the chamber 1348 in the manner just stated, it is communicated through inclined passages 1360 to the interior of both cylinders 1316 about the piston-portion 1296. Thereupon the cylinders are simultaneously forced away from the flange 1322 against their springs 1318 until their outer ends contact with stop-surfaces 1362, 1362 upon projections from opposite heads of the casing 1294 and corresponding surfaces upon sleeve-portions 1363 movable with the piston 1296. The inner, flanged extremities of these cylinders, which have been in engagement with the flange 1322 ready for movement under the influence of the segment 1314, are now so removed from the actuating edges of this segment that, in its opposite extremes of movement under the influence of the cam-groove 1324, it cannot shift the valve 1286. Therefore, the cold-bender is freed from manual control. The valve with its pistons is yieldably held by a balanced air-pressure in its normal closed position, and with the piston 1292 midway between the openings of the pipes 1106, 1108 ready to respond to the control of the feeler to cause movement of the cold-bender in either direction.

From what has been stated, it will be obvious that, with the plunger 1264 of the manual valve fully raised and latched, the valve U normally is prepared for automatic and not manual control. Consequently, if the operator wishes to turn the cold-benders by manipulating the handle 1268, the effect of the automatic control should first be nullified. This may be accomplished by shutting off the air from the automatic system in a manner which will be developed later; or the relation between the valve-plunger 1264 and its ports, the extremes of elevation and depression of the handle 1268, and the time of opening and closing of the valve 1342 may be such that when the handle is raised to something less than its latched position, the cold-benders will have been elevated to their active relation, while the valve 1342 still holds the air shut off from the bore 1348. At this time, then, if the handle be turned, the automatic valve will still be under the influence of the segment 1314 to revolve the cold-benders to an extent corresponding to the angular relation of the handle.

To allow the rate at which the cold-benders are elevated to be adjusted and to permit their free return to normal, there is included in the pipe 1226 delivering the fluid pressure to the elevating cylinder 1156 a check-valve 1370 (Fig. 67) arranged to open upwardly, but to obstruct flow from the supply-port 1258

to the cylinder, and leading into the pipe 1226 at opposite sides of this check-valve is a by-pass 1372, in which is a gate-valve 1374. When pressure is being applied to the pipe 1226 to raise the cold-benders, the closure of the check-valve 1370 diverts the flow through the valve 1374, which may be opened to the desired extent, to give a rate of flow which will result in the proper speed of elevation 5 of the benders. When pressure is released and the benders fall, the check-valve opens so that this movement is not interfered with. I prefer to provide for a plurality of speeds of revolution of the cold-benders, in the present instance two. For relatively small departures of the stock from the templet, as determined by the feeler mechanism, it is found best to turn the benders slowly, so that in establishing coincidence there will be less 10 tendency to overbend. If the difference between the stock and templet is relatively great, at the initiation of the bend a greater speed of revolution of the benders is desirable to bring the stock promptly to the field or 15 zone of slower movement, and through this into agreement with the templet. This result I accomplish by a valve 1376 (Figs. 67 and 68), which is arranged to alter the area of the opening through which flows the exhaust 20 from the ports 1282, 1282 of the valve U. A throttling of the exhaust, rather than supply to effect the regulation is utilized in this machine, because the pipe 1260, through which the rotating pressure is applied to the cylinder 25 1204 of the cold-benders, also conveys pressure to the cutting mechanism I. The exhaust-pipe 1284, however, is individual to the cold-bender, and changes in flow through it do not influence the action of other mechanisms. The casing of this valve 1376 contains 30 a double plunger 1378, between the heads of which leads the opposite runs of the pipe 1284. The plunger-head at the right, as seen in Fig. 68 of the drawings, presents a larger area to the pressure supplied through the pipe 1284 than does the companion head. As 35 a result of this, the plunger is normally maintained against the tapered, inner extremity of a screw 1380, threaded through the top of the valve-casing and having a hand-wheel by 40 which its position may be altered. This adjustment provides for the maximum opening through the pipe 1284 to give the greatest speed of revolution of the cold-benders. 45 Leading into the extremity of the valve-casing, beyond the plunger-head of greatest area, is a pipe 1382, which communicates with the pipe 378 (Fig. 132), the latter being subjected to pressure through valve 340 of the 50 feeler mechanism, and this valve being open only when said mechanism is acting in the zone in which there is a lesser separation between the stock and templet. When the pipe 1382 supplies the pressure to the valve plunger 1378, it carries the opposite extremity of 55

this plunger against the inclined circumferential surface of a screw 1384, passing transversely through the valve-casing at the end opposite the screw 1380, and capable of adjustment by a hand-wheel to present different portions of the incline for contact with the adjacent end of the plunger. When the plunger is stopped by engagement with the screw, the passage through the valve-casing between the runs of the pipe 1284 is partly closed, the extent depending upon the adjustment of the screw, thus choking the flow and correspondingly diminishing the speed of rotation of the cold-benders. 70

Remembering that the cylinders 445 of the carriage J each alternately receive pressure and are connected to exhaust, in the opposite movements of the carriage, it should be noted that the flow in the cold-bender supply-pipe 1260 and the cold-bender exhaust-pipe 1284 is through check-valves 1386 and 1388, respectively. The direction of opening of these valves in the cold-bending and cutting positions of the carriage permits the fluid to pass through the pipe 1260 to the valves T and U 80 and on to the cutting mechanism I, and to exhaust from said valves by way of the pipe 1284, but prevents movement in the opposite direction when the carriage is in the hot-bending position and the pressure of its cylinders is reversed. Between the pipes 1260 and 1284, opening on the inlet sides of both the check-valves 1386, 1388, is a by-pass 1390, in which is a check-valve 1392 opening in the direction of the pipe 1260. At the time of 85 hot-bending, when pressure exists in the lower cylinder 445, which carries the exhaust for cold-bending, there may be some leakage by the check-valve 1388, which would be prevented from passing on to the upper carriage-cylinder by the check-valve 1386. An accumulation of this pressure in the cold-bending system might produce false movements 90 of the benders; but this will be relieved through the by-pass 1390 and its check-valve without affecting the cold-bending mechanism. 95

The automatic controlling or feeler mechanism

The relation of the feeler mechanism to the other elements of the machine may be seen in Figs. 4, 37 and 119. Its structural details appear in Figs. 83 to 95, inclusive, while diagrams of the main valve-positions and corresponding feeler-positions are furnished by Figs. 96 to 118, inclusive, with the air-connections as in the diagram of Fig. 132. As in the earlier machine previously referred to, I prefer to employ both a templet-feeler 1400 and a stock-feeler 1402 (Fig. 37) to compensate for the effect produced by the lateral play of the templet and stock together, and to cause the controlling action upon the bending mechanisms G and H only when the stock 120 125 130 135 140 145 150 155 160 165 170 175 180 185 190 195 200 205 210 215 5 departs from the contour of the templet. Both feelers are supported upon a carrier-frame 1404 (Figs. 83 and 119) pivoted or trunnioned at 1406 and 1408 to swing laterally upon an arm 1410 extending horizontally from the front of the bridge member 430 of the frame. Projecting to the right of the carrier-frame as one faces the machine in the operator's position is a horizontal arm 1412 secured upon the lower end of a rod 1413 arranged to rotate under some frictional resistance in the carrier-frame. The arm 1412 has attached at its outer extremity, in a V-shaped depression, a block 1415 having vertical slots through which screws 1417 pass into the arm. 10 Depending from the block is the vertical stem 1414 of the stock-feeler 1402. The block 1415 is insulated from the arm at 1416 to prevent the flow of current through it, as this might be transmitted from the bender in contact with the stock, seeking the grounded side of the circuit. The clamping of the stock-feeler by its block upon the arm by the screws 1417 permits it to be adjusted vertically to bring it into correct relation with the stock. 15 The feeler may also be turned about the axis of the rod 1413 during the operation, to avoid interference by contact of said feeler with the templet. The contact-end of the 20 feeler is curved upon an arc centered in the axis of the rod, so that this movement of the feeler upon the axis 1413 may occur without changing the relation of the contact-surface to the other elements of the feeler mechanism 25 or varying the normal spacing between such surface and the templet-feeler. To hold the end of the feeler 1402 yieldably against the stock to permit it to move laterally with said stock in its advance, a spring 1418 is connected between the carrier-frame and the 30 arm 1410, this exerting its tension to swing the carrier-frame about its trunnions 1406, 1408 to hold the end of the feeler against the stock. The pivotal mounting of the frame 35 also enables the feelers to be swung to one side, the right and upward as seen from the front of the machine, to carry the feelers clear of the ends of the abutments. In this raised position it may be secured temporarily 40 by a latch 1420 (Fig. 4) arranged to slide upon the arm 1410 and movable into engagement with a projection from the frame. 45

50 Turning with a vertical spindle 1422 pivoted in the main carrier 1404 is a secondary carrier in the form of a sleeve 1424, which has within it the horizontal stem 1426 of the templet-feeler 1400. At the forward extremity of this stem is a feeler-holder 1428 clamped at 1430 so that its angle with respect 55 to the horizontal may be varied. The feeler may also be adjusted vertically in the holder, which is split and in which the feeler is retained wherever it may be moved, by the clamping effect of a screw 1432. From the 60 holder the templet-feeler is insulated by a

bushing 1434 for the same reasons as already given in connection with the stock-feeler 1402. The feeler 1400, in horizontal section, is preferably of rhomboidal form, or at least having its sides at the forward extremity 70 making an acute angle with each other. The side engaging the templet is determined by the angular adjustment of the feeler in the holder. This is facilitated by a knurled upward extension 1436, by which it may be 75 turned when the clamping screw 1432 has been loosened. The relation of the sides of the rhomboid to the templet is well illustrated in Figs. 106 to 118, inclusive, of the drawings, and a statement will later be given of 80 the utility of this particular feeler-contour. A spring 1438 (Figs. 4 and 95), joining the secondary carrier 1424 to some such element as the main carrier-frame, holds the feeler 1400 yieldably in contact with the edge of the 85 templet independently of its yield with the feeler 1402 as provided for by the spring 1418. It will thus be seen that the feelers can swing together about the trunnions of the main carrier-frame, and that they also may 90 separate by virtue of the movement of the secondary carrier about the pivot 1422, the latter taking place only when the stock and templet are not in coincidence at the points of 95 contact of the feelers. The controlling action of the feeler mechanism is exerted as a result of this separation of the feelers, so hereafter, in explaining this, only the templet-feeler will be referred to as being moved.

The templet-feeler, in the exercise of its 100 normal control, should lie just back of the imaginary vertical axis about which the bending occurs, since here it is best able to detect the separation between the stock and templet which the bending action is to eliminate, 105 without producing a false bend, which might result were it to be at a point of wider separation. On account of the form of the bending members and their relation to the ends of the abutments, the position of this bending axis is 110 different for hot and cold-bending, generally being farther to the rear for the former than for the latter. For this reason, the machine includes means for correctly locating the feelers—rearward for hot-bending and forward for cold-bending. Axially aligned with the trunnion 1408 at the rear of the carrier-frame 1404 is a cylinder 1440 supported upon the frame-arm 1410 and having within it a piston 1442, the rod of which is connected 115 to the trunnion 1408. Pipes 1444 and 1446 deliver air-pressure to the cylinder at opposite sides of the piston. The pipe 1444 opens from the pipe 1098 (Fig. 132) leading from the hot-bending end of the triple-valve-section 120 1080, while the pipe 1446 joins, through pipe 378, the pipes 1099 and 1100 from the cold-bending end of the same valve-section. Whenever the machine is employed for hot-bending, air-pressure exists in the pipes 1444, 125 130

forcing the piston 1442 to the right (Fig. 83), and, through its connection to the carrier-frame-trunnion, shifting this rearwardly until a portion contacts with the head of an 5 adjustable stop-screw 1448 threaded into the frame-arm 1410. For cold-bending, pressure is applied to the cylinder through the pipe 1446 to move the piston in the opposite direction and bring the carrier-frame to its forward 10 position, in which it is variably stopped by a screw 1450 turning in a member mounted on the frame-arm in alinement with the outer extremity of the carrier-frame-trunnion 1406. This last-mentioned screw is readily 15 accessible to the operator, and provides for a further positioning of the feelers during cold-bending than that furnished by the action of the piston 1442. As there must always be at least some clearance between the stock 20 and the adjacent walls of the abutments, and since these walls may wear considerably at their forward ends in the use of the machine, it will be obvious that when a curve of relatively large radius, or one approximating 25 the unformed stock in its contour, is being bent, this curved stock will extend farther back between the abutments than when the curvature is of less radius, or bent more abruptly. To locate the feelers in their correct 30 relation just to the rear of the bending axis, they must be farther back for the flatter curve. This requirement may be met by turning the screw 1450, the trunnion of the carrier-frame being forced against it, if desired, 35 by the air-pressure in the outer portion of the cylinder 1440. Turning the screw 1450 in a clockwise direction, as seen from the operator's position, carries the frame 1404 and the feelers farther back from the ends of 40 the abutments for most advantageous co-operation with the stock curved upon the larger radii, while opposite rotation of the screw permits the carrier-frame and feelers to come forward, under the pressure of the air, to the 45 point at which the feelers best act for curves of less radii.

Returning to the oscillation of the templet-feeler 1400 about the axis 1422 whenever the stock does not conform to the templet, this 50 movement is communicated to a segment 1452 controlling the ports of a main feeler-valve 1454. Variation in these ports, to produce which there is joined with the oscillation of the segment a vertical movement of reciprocation, as will later be described in detail, determines the air-supply to the cylinders 732, 732 (Fig. 40) to cause movement of the hot-bender to the right or left, to the cylinder 1290 (Fig. 78) to similarly affect the cold-bender, to the upper portion of the cylinder of valve 370 (Fig. 5) to stop the feed of stock during such bending, and to the cylinder 400 to slow the feed of stock during the formation of acute angles in hot-bending. The valve 55 segment 1452 also governs the application

of air within the feeler mechanism to cause its own movement. The connection between the feeler 1400 and the valve-segment includes an arm 1456 (Fig. 85) fixed upon the upper extremity of the spindle 1422 and having at its outer end a vertical pin 1458 engaging a lever 1460. This lever is fulcrumed upon a block 1462 arranged to slide in the carrier-frame 1404 and being fixed in its adjusted position by a screw 1464 (Fig. 84). The co-operating arm 1456 and lever 1460 furnish a portion of a movement-multiplying connection between the feeler and valve-segment, and by altering the position of the fulcrum of the lever by the means just described, the extent of this multiplication may be controlled. Secured upon the lever, so that it bears upon the pin 1458 at its outer side, or that removed from the contacting lever-wall, is a leaf-spring 1466. This permits a yield 75 in the connections for movement in one direction, and also takes up lost motion at this point. Rising from the opposite extremity of the lever 1460 from its fulcrum is a pin 1468 contacting with the side of an arm 1470 fastened near the lower end of the spindle 1472 of the valve-segment. With the arm 1470 and the pin co-operates a spring-wall 1474, serving the same purpose as the spring 1466 80 of the lever. 85

The segment 1452 is by these connections carried over an arcuate surface 1476 formed within a valve-casing 1478, from which casing depends a cylindrical boss 1480 arranged to turn in the carrier-frame 1404. 100 The stem 1472 of the valve-segment is rotatable in a bore in this boss, and the body of the segment is normally held in contact with an upward projection from the bottom of the casing by its weight and by a spring 1482 interposed between the upper end of the segment-stem and a cap 1484 threaded upon a projection from the casing. In the surface 1476 are formed valve-ports 1486, 1488, 1490 and 1492 (Figs. 90 and 96 to 105). The edges of the segment adjacent to these ports are so formed that in its various movements it may either wholly close one or more to prevent the passage of air, or at least partly open them to permit a leak 110 of air. The condition at each port governs corresponding leakage-valves 1494, 1496, 1498 and 1500 mounted together in a common casing 1502 attached to the rear of the valve-casing 1478. These leakage-valves 115 may be precisely the same as those already described, being in the present instance held normally closed by leakage through the ports of the main feeler-valve, and caused to open when the leakage is cut off to permit the 125 passage of the air-pressure through the pipes which they control. This air-pressure is delivered to the casing 1502 by a pipe 1504 leading from the pipe 562 (Fig. 132), which receives air through the double-check valve 130

367 (Fig. 50) whenever it is being supplied by the triple valve S for either hot or cold-bending. This pipe 1504 communicates with a central chamber 1506 in the valve-casing, which opens into the cylinders of all the four leakage-valves surrounding it. From the cylinders of these leakage-valves 1494, 1496, 1498 and 1500 lead, respectively, the pipe 1094 conducting the feeler-controlled air for right-hand bending to the section 1084 of the triple valve, the pipe 1092, which similarly conducts the feeler-air for left-hand bending to section 1082 of the triple valve, the pipe 406 terminating in the cylinder 400 for throttling the actuating oil to the feeding mechanism to slow the feed, and a pipe 1508 going to an air-cylinder 1510 (Fig. 83) forming a part of the feeler mechanism. At this point, it may be well to again explain that whenever right or left-bending air-pressure is thus applied by the feeler mechanism to the pipes 1092 and 1094, the normal feed-preventing pressure for the valve 370 enters the pipe 376 through the double-check valve 377. The normal relation of the feeler-ports to the co-operating segment-edges circumferentially of the casing 1478 may be adjusted by means of opposite screws 1512, 1512 (Fig. 119) threaded through lugs carried at the top of the frame 1404 and bearing at their adjacent ends against an arm 1514 projecting from the front of said casing. By loosening one of these screws and correspondingly advancing the other, the casing may be turned upon the boss 1480 to alter the position of the ports beneath the valve-segment 1452. In cold-bending by the mechanism G and hot-bending by the mechanism H involving relatively gradual changes in form, oscillatory movement only of the segment 1452 is used for causing the right and left bending through variation in the opening of the ports 1486 and 1488, the other two ports being at all times sufficiently open to maintain their leakage-valves closed. In hot-bending, however, when an angular portion is to be formed, the valve-segment is reciprocated vertically in combination with the oscillatory movement to affect all the leakage-valves, and I provide for this reciprocatory movement in four ways, three of which are utilized in connection with external angles produced by the hot-bender in traveling to the left, and the fourth, which is a variation of a procedure of the first group, is employed in making internal or re-entrant angles with the hot-bender moving to the right. Taking these reciprocatory controls up in the order in which they act, there projects from the left of the carrier-frame 1404 (Fig. 92) a bracket 1516, to the under side of which is attached a vertical bearing-sleeve 1518. Carried in this sleeve for vertical reciproca-

tion is a stem 1520 having fixed at its lower end a contact-foot 1522, which is forced normally downward by a spring 1524 lying between the foot 1522 and a collar 1526 fast upon the lower end of the bearing-sleeve. The yield of the foot, provided by this spring, allows it to ride upon the top of the templet, and then, as this passes from beneath it, to be lowered to exercise a valve-controlling effect, which is the initial step in preparing for the execution of angular bends by the mechanism G. The relation of this foot to the templet is well shown in Figs. 106 to 118, inclusive, of the drawings. It is insulated from the supporting stem and spring by a bushing 1527, to prevent the passage of current from the hot-bender and stock to the frame. Secured upon the upper portion of the stem 1520 is a head 1528 having an arm 1530 movable vertically in a slot in a member 1532 fixed to the side of the carrier-frame. Engagement of the head-arm with the slot holds the stem and foot against rotation, while allowing it to rise and fall under the influence of the templet and spring. A portion of the head 1528 extends over and contacts with a rounded boss upon a generally horizontal lever 1534 fulcrumed upon the member 1532 (Fig. 93). The rounded, upper face of the opposite arm of the lever contacts with the under side of a short arm 1536 projecting from the segment-stem 1472 opposite the arm 1470. The end of the forward arm of the lever 1534, beyond its point of engagement with the head 1528, moves between an adjustable stop-screw 1535, threaded vertically through a portion of the bracket 1516, and an opposite upper stop-screw 1537 similarly mounted. By these may be adjusted the extent to which the lever is lowered under the influence of the foot 1522 and the normal raised position of this end of said lever. The former movement, transmitted through the head 1528, determines the extent to which the lever shall raise the stem 1472 and its segment. When the port 1492 is closed, the leakage-valve 1500 admits air to the cylinder 1510, in which operates a piston 1538 (Fig. 83). The rod of this piston, at its top, contacts with a horizontal arm of a bell-crank-lever 1540 fulcrumed at 1542 upon an arm 1544 (Fig. 95) fixed to the spindle 1422 of the carrier-sleeve of the templet-feeler with the arm 1456 and lying substantially at right angles to said arm. Air-pressure in the cylinder 1510 forces up the piston 1538 so that it contacts with the bell-crank-lever, which, in turn, is pressed against the bottom of the segment-stem 1472, lifting this. A stop 1545, lying above the end of the piston 1538 limits the upward movement of this piston when it is without other restraining influence. A vertical arm of the bell-crank-lever 1540 has a laterally projecting pin 1546 extending between contact-screws 1548, 1550 oppositely

threaded through a central yoke 1551 upon an arm 1552. This arm is secured upon the rear extremity of the stem 1426 of the templet-feeler 1400, the upper end of the arm lying within a slot 1554 formed at the bottom of the arm 1544. This co-operation of the arm 1552 with the slot allows the feeler-stem to move back and forth in its carrier-sleeve without rotation or lateral displacement of the feeler upon the edge of the templet. The feeler is normally held back with its holder in contact with a nut 1556, adjustable upon the carrier-sleeve and retained against accidental displacement by a lock-nut, through the agency of a spring 1558 surrounding the stem of the feeler within the carrier-sleeve. The oscillation of the bell-crank-lever by the piston presses the pin 1546 against the screw 1548 to cause the arm 1552 and stem 1426 to move forward, carrying the feeler 1400 against the templet. The simultaneous elevation of the stem 1472 by the lever-arm 1540 brings the elevation of the valve-segment to such a point as to initiate the bending action as the templet moves forward to the bending point of external angles.

Whenever air enters the pipe 1092 as a result of the opening of the leakage-valve 1496 to cause a left-hand bend, this following the action of the segment-elevating device just described, it also passes through a pipe 1560 (Fig. 132) to a cylinder 1562 (Fig. 84), one end of which is threaded through the side of the valve-casing 1478. Within the cylinder 1562 is a piston 1564, held out from the valve-casing by a spring 1566. A stop-rod 1568, movable with the piston, has, outside the cylinder, a nut and lock-nut 1570 furnishing means for varying the inward position of the piston, and therefore of the inner end of the piston-rod which lies within the valve-casing. This inner portion of the piston-rod is tapered at 1572 for contact with an inclined, annular surface 1574 formed upon a collar 45 or enlargement encircling the body of the valve-segment. Upon the admission of air-pressure to the cylinder 1562, the piston is forced toward the valve-casing, causing the tapered end of the rod to pass beneath the inclined surface 1574 and bear against it to raise it and the segment vertically, thereby establishing a new relation of the controlling edges of the segment to the valve-ports. This gives the final step in the vertical movement of the segment for the bending of external angles.

During the bending of re-entrant angles, the advancing templet-edge engages the feeler 1400 (Fig. 113), drawing this forward against the resistance of the spring 1558. At this time, the screw 1550 contacts with the pin 1546, oscillating the bell-crank-lever 1540 and, by the engagement of the horizontal arm of this lever with the valve-stem 1472, raising the valve-segment to control

the co-operating ports. Between the ends of the screws 1548 and 1550 there is a space, greater than the diameter of the pin 1546, providing for lost motion during the relative movements of the vertical arm of the bell-crank-lever and of the arm 1552 of the templet-feeler. Because the screw 1548 is effective in the valve-movement during the bending of external angles, and the screw 1550 while internal angles are being formed, change in the position of these screws permits the extent of movement of the valve-segment for each operation to be adjusted independently. These adjustments determine in each instance the location of the bending axis.

Since the control of the bending action is through interposed elements in which there is resistance to movement, as is introduced, for example, by the friction of the leakage-valves, the controlling effect may lag behind the valve-movement which produces it, and this may in some instances, as when the bending takes place during the advance of the stock in cold-bending, be objectionable in delaying the stopping of such bending. To counteract this, I have included in the feeler mechanism means for anticipating the reverse movement of the valve-segment 1452 when the feeler 1400 is returned from the active to a neutral position. Supported upon a bracket at the upper, forward extremity of the carrier-frame 1404, above the bracket 1516, is a cylinder 1576 (Figs. 92 and 94), into which enters a pipe 1577 (Figs. 119 and 132) connected to the pipe 376 which delivers air to the valve 370 to prevent the feed of stock when the feeler mechanism is controlling bending. The cylinder has within it a piston 1578, the rod of which rests upon a plunger 1580 mounted to reciprocate vertically in a screw 1582 threaded into an axial bore in the upper end of the stop-screw 1537. With the upper surface of the head of the screw 1582, a head upon the plunger contacts to limit its downward movement. This plunger has a depending extension 1584 passing through an axial opening in the screw 1537, and being acted upon by a spring 1586 to normally hold the plunger-extension above this stop-surface of the screw. Upon the depression of the plunger against its spring by contact of the piston-rod with it, following the admission of air to the cylinder 1576, the extension 1584 strikes the forward end of the lever 1534. This, by upward movement of the opposite end of the lever, raises the valve-segment a portion of the distance which it must travel to become effective, anticipating its action under the control of the feeler 1400. This influence is exerted whether the bend be right or left and regardless of which bending mechanism is employed. This will be clearer if reference is had to Fig. 96 of the drawings and it is re-

membered that in cold-bending, for example, one of the normally open ports 1486, 1488 of the main feeler-valve is closed by the adjacent inclined edge of the segment in its oscillation to produce the bending effect. After this closure, it will be apparent that by raising the segment in the manner just described, the inclined edges will approach more closely to the ports, hastening the reverse action of the mechanism when the feeler swings the valve-segment in the opposite direction. By adjusting this anticipating movement of the segment through alteration of the extent of movement of the plunger 1580 by the stop-screw 1582, the effect of lag may be completely overcome to cause the valve to act at exactly the same point for the travel of the feeler in both directions.

20 In the section dealing with the feeding mechanism, it has already been explained that the pressure applied to the valve 370, through the feeler mechanism by way of pipe 378, acts to nullify the normal feed-preventing action of said mechanism when it is governing the benders for their movement in either direction. This nullifying air-pressure is under the control of the leakage-valve 342, the structure of which has been outlined as an example of this type of valve. As to the action of the valve 342 in connection with the cold-bending mechanism, it has been explained in general terms that the bending members move at different speeds in different zones of action, and it will now be well to define clearly the nature of these zones. There is first a certain limited field in which the templet and stock may depart from exact agreement in either direction, without altering the normal control which the feeler mechanism exerts over the feeding and bending mechanisms, this producing advance of the stock and withholding the benders from action. This may be termed the neutral zone. For hot-bending, when the feeler leaves this neutral zone by shifting either to the right or left, it enters an outer zone, in which feed is stopped and bending in the indicated direction occurs. In cold-bending, I introduce a field of influence at each side of the neutral zone, which fields fall within the inner areas of the just described outer zones. These I designate as intermediate zones, and when in them the feeler mechanism causes feed of the stock with action of the cold-benders by relatively slow movement. Beyond these there are the outer zones for cold-bending, in which feed ceases similarly to hot-bending, and the benders move more rapidly than in the intermediate zones. In these last-mentioned zones, the valve 342 operates to supply air to the upper portion of the valve 370 to cut off the feed-preventing pressure through pipe 376 and so allow feed

to continue while the feeler mechanism is governing the movement of the cold-benders. Mounted upon the side of the valve-casing 340 is a cylindrical casing 1590 (Figs. 84 and 86), containing at the side next to the casing 340, and communicating with its interior, the leakage-port 350 controlling said valve. Journaled in the bottom of the casing 1590 is a vertical spindle 1592, having fast upon its lower extremity an arm 1594 slotted to receive the end of the pin 1458, which is included in the lever-system interposed between the feeler 1400 and the valve-segment 1452. Fixed upon the upper end of the spindle 1592 is a valve-finger 1596, formed at its outer end to move in close proximity to the wall of the casing 1590 and in the horizontal plane of the leakage-port 350. The area of this end of the finger is greater than the opening of the port with which it co-operates, so that, from a position of axial agreement, it may be carried in one direction or the other by the oscillation of the pin 1458 without uncovering the port. When the feeler 1400 is in the center of the neutral zone, the valve-finger 1596 is in axial alinement with the port 350, just mentioned. When the feeler moves outside of this neutral zone to stop the feed of the stock and begin the bending action in one direction or the other, the port still remains covered by the end of the finger for a certain range of movement of the feeler, this giving the intermediate zone. During the closure of the port 350, the valve-plunger 342 is so held as to open communication through the pipe 378, overcoming the force of the spring of valve 370 and closing the connection between the pipes 330 and 376 to cut off the pressure to the cylinder 324, which, if permitted, would close the feed-valve 310 and stop the advance of the stock. With the feeler in the neutral zone, there will be no pressure furnished by the feeler mechanism to the pipe 376, so in any event, the stock is fed. But when the feeler leaves the neutral zone and air is admitted to the pipe 376, the maintenance of the closure of port 350 by the finger 1596 in the intermediate zone gives the continued pressure in the pipe 378, which, through the shutting of the valve 370, bars the feed-preventing air from the cylinder 324. Further movement of the feeler and finger out of this intermediate zone causes the latter to open the leakage-port 350, resulting in the closing of the valve 342. The nullifying pressure being thus removed from the pipe 378, the valve 370 is opened by its spring, restoring the usual control of the feeler mechanism, and the feed stops. From what has been stated of the action of the elements 1596, 350 and 342, it will be seen that these may be considered as furnishing a secondary valve modifying the action of the primary feeler-valve, which includes the segment 1452.

Air connections and operation of the feeder mechanism in control of the feeding and bending mechanisms

The structural details of the feeding and bending mechanisms and the way in which the elements act within the respective mechanisms being understood, their manner of co-operation may be stated, particularly with reference to the effect of the main feeler-valve, while the paths of the controlling air will at the same time be reviewed. Certain auxiliary devices not yet discussed will also be taken up.

Air is supplied under pressure from a source not illustrated, through a pipe 1600 (Fig. 132). From this two branches 328 and 862 receive pressure. The first acts through the three-way cock 332 upon the cylinder 324 of the valve 310 to cause continuous feed of the stock when communication through the three-way cock is opened. Pressure from the pipe 328 is also delivered through pipe 334 to the normally closed leakage-valve 336, opened by a leak governed at the hand-valve 354 joined to the valve 336 by the pipe 338. This leakage-valve allows manual control of the feed. The second branch 862 from the main supply-pipe furnishes air to the normally closed leakage-valve 854, opened at predetermined points in the movement of the hot-bender to supply pressure through the pipe 853 to the cylinder 850, and thus shift the oil-valve 840 to slow the hot-bender in its travel into contact with the stock. From the branch 862, air is also received through branch 674, applying pressure to the auxiliary hot-bender elevating cylinder 656 under the control of the valve 670 by way of the pipe 668. The main supply-pipe 1600 terminates in a leakage-valve 1602 (Fig. 34), normally open and connected to section 1080 of the triple valve S by pipe 1090. The valve 1602 may be closed in two ways to completely cut off the supply of air which causes the automatic operation of the apparatus. One of these controls is exercised through a pipe 1603 terminating in a leak-opening 1604, normally closed by a pad carried upon a lever 1606 of valve 1608 (Fig. 130). This valve I prefer to locate on the rail 352 of the machine adjacent to the feed-controlling valve 354. The opening of the leak 1604 and the consequent closure of the leakage-valve 1602 may be maintained against the tension of a spring 1609 by a sleeve 1610 arranged to slide upon the rail, and having a projection 1612 which may be carried over the end of the lever 1606. The closure of the leakage-valve 1602, under the control of the valve 1608, prepares the machine for automatic operation by opening the main air-supply pipe 1600. There is also a leak from the valve 1602 by way of a pipe 1614, the end of which is normally closed by a pad upon the

under side of a head 1616 (Figs. 29 and 33). This head is fixed upon the top of a rod 1618, having at its lower extremity a float 1620 situated within the chamber in the base of the machine, receiving a portion of the exhaust-oil. The rod 1618 is shown as guided by a tube 1622 upon which the leakage-end of the pipe 1614 is clamped, this tube being supported in brackets projecting rearwardly from the main frame. If, because of failure of other means for removing it, the waste oil rises to such a height in the base that it might overflow, the float lifts the pad upon the head 1616 to uncover the leakage-opening thus closing the valve 1602 and notifying the operator of the condition by the stopping of the machine.

Proceeding from the section 1080 of valve S, it will be assumed that this valve has been brought to its hot-bending position by the projection 1132 upon the bar 1124 movable by the carriage J, this positioning of the valve occurring when the hot-bending mechanism is in operative position below the ends of the abutments D, D. Air, under these circumstances, continues from the pipe 1090 through the pipes 1096 and 1098. From the latter the branch 804 furnishes pressure to the cylinders 800, 800, the withdrawal of pressure from which permits the hot-bender returning mechanism to functionate after, say, the valve 1602 has been closed to cut off air from the automatic system. The branch 974 from pipe 1098 communicates with valve 968 of the relay-valve N, which governs the application of fluid pressure to the secondary switch O of the electric heating circuit for the hot-bender. Still another branch or continuation 1444 of the pipe 1098 opens into the cylinder 1440, which carries the templet-feeler 1400 to its rearward position appropriate for the hot-bending operation. From the pipe 1096 air-pressure through the double-check valve 367 to pipe 1624 is applied to the pipe 1504, giving the air-supply for the group of feeler leakage-valves 1494, 1496, 1498 and 1500 contained in the casing 1502. From the same source, air is received by pipe 562 for locking the treadle mechanism K through the agency of the cylinder 564. The valves of the feeler mechanism thus have upon them the pressure which they are to control. It is also transmitted by pipe 1624 to the leakage-valve 832, which is held open by the closure of its leak-passages at 828, 828 terminating pipes 830, 830, whenever the hot-bender is clear of the path of the stock, so that feed may take place. From the valve 832, pipe 362 supplies pressure through the double-check valve 366, three-way cock 332 and pipe 328 to the cylinder 324 for opening oil valve 310 to cause feed. The sections 1082 and 1084 of the triple valve, receiving air-pressure through the left and right-bending pipes 1092 and 1094, respectively, from the

feeler mechanism applies it, under feeler control, to the actuating cylinders 732, 732 of the hot-bender by way of pipes 1102, 1104 and 734 corresponding pressure being made effective at the valve 670 which governs the elevating cylinder 656.

The manner in which the hot-bending, feeding and feeler mechanisms are provided with air to control their operation having been explained, it will be assumed that the stock is in such relation to the templet that the feeler 1400 lies in the neutral zone, that feed forward of said stock with the attached templet is taking place automatically, and that there is approaching the feeler an external angle of the templet sufficiently acute to call for the action of the hot-bender G. This may be considered as already positioned by the carriage J beneath the abutments D, D. The controlling elements might appear as illustrated in Fig. 106 of the drawings, with the valve-elevating foot 1522 resting upon the templet. At this time, the valve-segment 1452 is as illustrated in Fig. 96, each of the ports 1486, 1488, 1490 and 1492 being sufficiently open to cause leaks holding the corresponding valves 1494, 1496, 1498 and 1500 closed. As the stock and templet advance and the latter reaches the point illustrated in Fig. 107, the foot 1522 slips off the rear edge of the templet, and through the already described connections lifts the valve-segment, as illustrated in Fig. 97. This produces an alteration in the condition of the ports which is preparatory to a further movement of the valve-segment. When the feed has brought the templet to the position of Fig. 108, the spring 1438 has forced the feeler back of the advancing templet and out of its neutral zone. A corresponding oscillation of the valve-segment, as appears in Fig. 98, closes the ports 1490 and 1492, the bending ports 1486 and 1488 remaining open. Consequently, the leakage-valves 1498 and 1500 are opened, and by the admission of air to the cylinder 400 controlled by the valve 1498, the feed of the advancing stock is reduced to give more time for the controlling operations, while at the same time pressure is applied to the feeler-cylinder 1510, governed by the valve 1500. The response of the piston in cylinder 1510 turns the bell-crank-lever 1540 upon its fulcrum to press the feeler 1400 forward behind the advancing templet, and at the same time to lift the valve-segment, this assuming the position shown in Fig. 99 at the time in the advance of the feeler that the templet has reached the bending point (Fig. 109). The ports 1490 and 1492 remain covered, the port 1486 uncovered, but port 1488, which controls the movement of the hot-bender to the left, is closed, admitting through its leakage-valve 1496 air to the left-hand bending cylinder 732 and starting the bending action in the direction of the arrow

in Fig. 110 and stopping the feed. When air is admitted to the cylinder 732, pressure is also applied to the cylinder 1562, so that the tapered end of its piston-rod lifts the valve-segment, as appears in Fig. 100. The port 1492 is opened, releasing the feeler from the pressure of the bell-crank-lever 1540 and allowing it to be carried back by its spring to the point shown in Fig. 110, in which it is out of the way of the templet during the first portion of the bending. The port 1488 is still closed to provide for the completion of the bender-movement, and this keeps pressure upon the cylinder 1562, so that the valve-segment is held up. At the termination of the bend, illustrated in Fig. 111, the advancing edge of the templet strikes the feeler and carries it into its neutral zone. In passing beneath the inclined rear face of the foot 1522, this is brought to its original elevation upon the upper surface of the templet. The lateral movement of the feeler, under the influence of the templet, turns the valve-segment so that it assumes the relation to the ports appearing in Fig. 101. This opens all the ports, and upon the admission of air to the port 1488 the movement of the bender stops, and the piston-rod of cylinder 1562, which has been supporting the valve-segment, is withdrawn by its spring, so said segment drops to the initial point (Fig. 96), restoring the feeler mechanism to its normal condition. The returning mechanism carries the bender out of the path of the stock, which is then fed forward with the templet, as may be seen in Fig. 112.

Had the approaching angle of the templet been re-entrant, as appears in Fig. 113, calling for a right-hand action of the hot-bender, the operation would have proceeded as follows, the segment-controlling foot 1522 not now being considered, since during the entire operation it rests idly upon the top of the templet: When the advancing templet reaches the position illustrated in Fig. 114, the contact of the approaching edge with the rear of the feeler 1400 draws this forward against the tension of its spring 1558, and by the contact of the screw 1550 with the pin 1546 swinging the bell-crank-lever 1540 about its fulcrum to raise the valve-segment, as is shown in Fig. 102 of the drawings. This produces closure only of the port 1490, slowing the feed of the stock, as has already been described in connection with the bending of the external angle. Under the influence of the slower feed, the templet is brought to the location of Fig. 115, which is the bending position, elevating, by the continued pull upon the feeler, the valve-segment to the point shown in Fig. 103. The feed-controlling port is maintained closed, the ports 1488 and 1492 open, they thus remaining throughout the operation, while the right bending port 1486 has become closed, stopping the

feed and starting the hot-bender in movement in the direction of the arrow in Fig. 116 through admission of air to the right-bending cylinder 732. This, as is made evident in Fig. 116, allows the feeler to be drawn back by its spring 1558, tending to close the port 1486 by the depression of the valve-segment; but at the same time the anti-clockwise rotation of the forward edge of the templet 10 carries the feeler to the right, maintaining the port-closure so that the bending action is not interrupted. This places the valve-segment in the relation illustrated in Fig. 104. As the bending of the stock continues, as is shown in Fig. 117, the feeler is drawn back to its initial position by its spring, permitting the valve-segment to descend to its normal level, as appears in Fig. 105, the right-bending port 1486 remaining closed. By the 20 bender, the stock is finally brought to that relation, shown in Fig. 118, in which the templet allows the feeler to enter the neutral zone, stopping the movement of the bender by turning the valve-segment to the position of Fig. 96. All the valve-ports now being uncovered, the condition of no bender-movement with feed of the stock is reestablished, the latter occurring after the returning mechanism has carried the bender clear of the 30 stock.

The form of the feeler plays a part in the bending operation by determining the location of the bending axis in accordance with the degree of the angle being bent. This 35 may be understood by reference to Fig. 109, in which the feeler 1400 has been carried forward into contact with the advancing templet to start the feeding action. With the angle of 60 degrees illustrated, a forward side of the rhomboid meets the edge of the templet at the time of the closure of the left-bending port 1488. Suppose, instead, the angle of the templet were 90 degrees, then an apex of the rhomboid would strike the templet-edge, this 40 contact occurring when the templet had advanced a less distance than with the more acute angle. Consequently, the bending would begin farther forward. With material tapered in cross-section, as is the clicking-die 45 stock, the reduced upper edge is stretched in the bending, this effect increasing with the acuteness of the angle. The stretching tends to produce a separation between the corner of the stock and the corresponding angle of the templet, and if the feed were stopped to 50 locate the bending axis regardless of the degree of the angle, the separation would be greater as such angle becomes more acute. The present form of feeler, so contacting with the templet that an edge thereof extends laterally of the feeler apex, corrects this defect by starting the bend farther back as the acuteness of the angle increases. Consequently, 55 there is substantial agreement between the stock and templet for all angles, in spite of

the varying distortion. It will be obvious that were the feeler of another form, as round in cross-section, or square, with its side, instead of a corner, in the direction of advance of the stock, such a result could not be arrived at. 70

When the carriage J places the cold-bending mechanism H in the operating position, the depression 1134 in the bar 1124 allows the plungers of the triple valve S to be lowered. 75 Again considering particularly Fig. 132, the connections of the air-supply pipe 1600 and the leakage-valve 1602 are as in hot-bending. At the triple valve, the lower ports are now open while the upper are closed, and at section 1080 air passes from pipe 1090 to pipe 1099 and valve 1342 actuated by the plunger 1264 of the manual valve T of the cold-bender, and opened only when this is raised for the bending operation. Then air flows 80 to the valve-cylinders 1816 of the automatic valve U through pipe 1846 and by way of pipes 1100 and 834 and double check 367 to pipe 1624 and leakage-valve 832, which is open when the hot-bender is inoperative. 85 Just as in hot-bending, pipe 1504 furnishes the air-supply for the feeler leakage-valves in the casing 1502 and pipe 562 for the treadle-locking cylinder 564, while pipe 362 from the leakage-valve 832 provides for the 90 feed of the stock by action in the cylinder 324. Continuing from the junction of the pipes 1100 and 834, pipe 378 includes the casing 340 of the intermediate-zone valve, which applies pressure above the piston of cylinder 370 to cause the continuation of feed of the stock during the bending action in this zone. Branches 1446 and 1382 from pipe 378 respectively introduce air to the cylinder 1440 to hold the feeler 1400 in its forward cold-bending relation, and to the valve 1376 to produce the relatively slow oscillation of the cold-benders in the intermediate zone, the latter device being under the influence of the 95 intermediate-zone valve. 100

By the sections 1082 and 1084 of the triple valve, the left and right-bending feeler air-pipes 1092 and 1094 are respectively joined by pipes 1106 and 1108 to opposite sides of the piston in the cylinder 1290, positioning the valve-plunger 1286 for controlling the left and right revolution of the cold-benders. The governing of the air through the pipes 1106 and 1108 by the feeler-valves 1494 and 1496, under the influence of the valve-ports 115 1486 and 1488, involves only the oscillation of the valve-segment 1452 by the rotation of its spindle 1472, this spindle not being moved vertically for cold-bending, save by the anticipating mechanism under the influence 120 of pressure in the cylinder 1576. The ports 1490 and 1492, controlled by the segment, are inactive, remaining uncovered at all times 125 during this operation. Starting with the feeler 1400 in the neutral zone, a departure 130

of the stock from the templet, either to the right or left, will produce a corresponding oscillation of the segment through the interposed lever-system, completely closing the port which will give the proper bending movement, and keeping the companion bending port open. In this departure of the feeler from the neutral zone in either direction, the connection of the lever-system to the finger 1596 of the intermediate-zone valve at first maintains the port 350 covered after the bending action has started. Therefore, the valve-plunger 342 is so positioned that the passage between the sections of the pipe 378 through the casing 340 remains uninterrupted, and pressure in the cylinder 370 holds the feed-preventing pipe 330 closed, so feed continues. There being at this time pressure applied through the pipe 1382 to the valve 1376, the exhaust from the rotating-cylinder 1204 of the cold-benders is throttled to slow their oscillation. If the divergence between the stock and templet is greater, the finger 1596 is carried to a point at which it uncovers the port 350, so the plunger 342 is shifted to shut off pressure from above the piston in cylinder 370, and the feed is stopped by air applied to the cylinder 324 through pipes 376 and 330 under the control of the feeler-valve. Simultaneously, pressure is removed from the cylinder 1376, so the cold-benders exercise their bending action at their maximum rate and with successive periods of formation and feed. After the stock has been brought by the benders to a point at which the feeler 1400 has returned to the intermediate zone, the slower bending effect with simultaneous feed is restored by governing actions the reverse of those just outlined. Finally, when conformity with the templet is established, the feeler 1400 is returned to the neutral zone, opening the port 1486 or 1488 which has been closed, and causing the cold-bender valve 1286 to go to normal, stopping bender movement. There is now a resumption of the feed of the stock if an outer zone had been reached, or its continuance if the displacement of the feeler were not beyond the intermediate zone. If it is for any reason desirable, as in producing curves of relatively small radii, the hot-bending mechanism may be employed in the same general manner as is the cold-bender in the outer zone, to form by successive operations with intermediate periods of feed. In this case, the foot 1522 remains upon the stock, and there is no engagement of the feeler by the templet to draw the former forward. Therefore, the valve-segment 1452 is not raised, and right or left-bending with alternate advance of the stock is effected by oscillation of the segment, as just described.

The cutting mechanism

Upon the front face and at the left of the carriage J is a horizontal way to receive a

tongue or projection 1630 (Fig. 119) formed upon the rear face of a mounting-plate 1632 for supporting the cutting mechanism I. This plate may be adjustably attached to the carriage, to allow the position of the cutting mechanism to be varied transversely of the ends of the abutments D, D by screws 1634 threaded into the carriage and passing through horizontal slots in the plate. Projecting from the front of the plate 1632 (Figs. 120 and 121) are upper and lower forwardly extending arms 1636, 1636. In vertically alined openings in these arms are upper and lower pivot-pins 1638 and 1640, respectively, upon which turn lugs projecting from the rear of a carrier-casing 1642. The lower pin 1640 is tapered at its upper extremity to enter a correspondingly tapered opening in an abutment member 1644 (Fig. 122), which may be adjusted through a limited angle about the pin. To clamp the abutment member in place by forcing its tapered opening upon the pin, a screw 1646 is threaded into the top of the pin and has a flange bearing upon a horizontal surface of the member 1644. In the head of this screw is a socket, accessible through an axial opening in the pin 1638. To release the abutment member from the position in which it is clamped by the screw, so that it may be turned to another angle, the member 1644 has a portion 1648 overhanging the head of the screw, so that when this is backed off, said head contacts with the under surface of the overhanging portion, lifting the member 1644 from the pin. Resting against the abutment member, at opposite sides of its central mounting, is a pair of rods 1650, 1650 movable horizontally through the casing 1642, the outer extremities of these rods passing through tubular screws 1652 threaded through the front of the casing, said screws being held in place by lock-nuts 1654. Between an annular flange 1656 upon each rod within the casing and the inner extremity of the corresponding screw 1652 is a spring 1658, which forces the flange of its rod against a boss upon the casing and the rear extremity of the rod in proximity to the abutment. The two springs, through the thrust of the rods, yieldably hold the casing in a predetermined relation to the space between the abutments D, D and the stock issuing therefrom, the position being fixed by the angle at which the abutment member 1644 is set. Yet, said casing may swing in either direction to enable the cutting mechanism to adjust itself to the angular position of the stock at the time of its operation. A variation in the position of the screws 1652 will change the force exerted by the springs 1658.

The oscillatory carrier-casing 1642 has, arranged to slide within it, a vertically reciprocating bearing-casing 1660 (Figs. 123, 124 and 125). Between upwardly extending lugs at the top of this inner casing passes a

pivot-pin 1662, upon which are fulcrumed oscillatory holders 1664, 1664 for cutting blades 1666, 1666. These blades are removable to allow them to be sharpened or replaced, but the holders, especially for the purpose of definition in the claims, may be considered as part of them. The holders swing upon their fulcrum-pin so that their adjacent sides are in close contact to bring the blades into the proper cutting relation, and at their outer sides and ends, the latter being arcuate, they move in close proximity to the walls of the casing 1660 to prevent the introduction of dirt, 10 which would tend to clog the holders and the actuating elements in their movement. The casing 1660, which may be considered as a secondary carrier for the cutters as compared with the main casing 1642, has separated 20 downward extensions 1668, 1668, between which are extensions 1670, 1670 from the cutter-holders. In each of these holder-extensions is a longitudinal slot 1672, the upper portion of which extends in a generally vertical direction when the cutters are separated, while the lower portion is curved in the direction in which the cutting blade of its holder moves upon closing, this movement being considered as rotation about the pivot- 25 pin. When the cutters are open, as best appears in Fig. 124 of the drawings, the upper portions of the slots are parallel, while the curved ends are alined, these ends at this time receiving rolls 1674, 1674 (Fig. 126) rotatable about a spindle 1676 fixed between the upper ends of the spaced arms of a yoke 1678. Outside the rolls 1674 about the spindle are rolls 1680, 1680, which run in ways in the adjacent walls of the bearing-casing 1660. 30 The yoke 1678 is carried at the top of a tubular rod 1682 extending from the upper side of a piston 1684 movable within a cylinder 1686 depending from the bottom of the outer casing 1642. Rising from the lower head of the cylinder is a pipe 1688, the upper extremity of which is closed, save for opposite elongated openings 1690, 1690 in its side walls. When the piston is at the lower portion of the cylinder, where it is normally held by gravity, the rolls 1674 lie within the lower curved 45 portions of the slots 1672, maintaining the bearing-casing 1660 in its lowest position (Fig. 124), with the cutting blades below the plane of the stock A (Fig. 119), and the holders 1664 turned to such a position as to separate said blades. Upon the application of pressure to the cylinder through the pipe 1688, the openings 1690 and the space between the pipe and the tubular rod 1682, this forces 50 up the piston. The rolls 1674, in their upward travel, communicate their movement to the blade-holders, similarly moving them and the bearing-casing 1660. At this time, rolls 1692, 1692, mounted to turn upon an inward 55 flange 1694, formed upon the outer casing

1642, contact with the straight outer edges of the holder-extensions, preventing these from separating and maintaining the blades in their open position. As soon as the lower extremities of the extensions pass the rolls 1692, they are allowed to separate under the influence of the pressure of the rolls 1674 on the outer edges of the slots 1672. When this point is reached, the elevation of the blade-holders and their bearing-casing has been 60 completed, vertical points at opposite sides of the stock, such as are illustrated in Fig. 123, having been attained. Movement in this direction is stopped by the contact of a surface upon a projection 1693 from each casing-extension 1668 with the under side of the flange 1694. The action of the rolls 1674, still rising under the influence of the piston 1684 through the straight portions of the slots 1672, is now directed wholly to camming the holder-extensions apart, rotating these holders upon the pin 1662 to bring the blades into contact with and through the stock. As the piston approaches its upward limit of movement, the surfaces of opposite, vertically extended 65 projections 1695 upon the lower portion of the interior of the tubular piston-rod come into co-operation with the elongated openings 1690, and as they move along them, gradually cut off the flow therethrough. 70 This correspondingly reduces the speed at which the piston is rising, and minimizes the shock which would be produced by contact of the piston at the termination of the upward travel of the cutting blades. By the elevation and closure of the blades, the relation shown in Figs. 123 and 125 is attained, the stock being severed. Here a limit of movement is established by engagement of a surface 1697 upon the piston-rod 1682 with the lower end of the casing-extensions 1668, which are held against upward movement by the flange 1694. During the holder-oscillating 75 travel of the piston, it compresses a spring 1696 located between the upper face of the piston and a flange 1698 within the casing 1642. The expansion of this spring, after release of pressure from the cylinder, is utilized to draw the piston down until the rolls 1674 have reached the curved portions of the slots 1672, restoring the casing-extensions to their parallel relation and bringing their edges within the rolls 1692 (Fig. 124). Thereafter, the greatest resistance having been overcome, the movable elements may be brought to the normal 80 position of Fig. 124 by gravity.

Connected with the pipe 1260, which receives pressure from the upper cylinder 445 of the carriage J in its cold bending and cutting positions, is a pipe 1700 (Figs. 67 and 123), which includes a coil 1701 (Fig. 2) of considerable length and of such area in transverse section that the rate of flow through it will be relatively high, and which delivers to the supply-port of the casing of a valve

1702 (Figs. 123 and 128) fixed upon a bracket 1704 at the front of the cutter-casing 1642. A lower delivery-port in the valve-casing is joined by a pipe 1708 to the pipe 1688 within the cylinder 1686. The delivery-pipe 1708 is connected by a by-pass-pipe 1710, which leads through a check-valve 1712, to the cylinder 1686 at one side of the pipe 1688. The check-valve opens, as is indicated by the arrow in Fig. 128, in a direction from the cylinder, preventing flow through the by-pass from the pipe 1708 toward the cylinder. At the bottom of the casing of valve 1702 is an exhaust-port, from which a pipe 1714 goes to the base of the machine. Within the valve-casing is a double-headed plunger 1716, to which is pivoted a hand-lever 1718 fulcrumed upon the said casing. When the hand-lever is raised, lowering the valve-plunger, communication is established between the supply-pipe 1700 and the delivery-pipe 1708 to provide for the elevation of the piston 1684 and the operation of the cutting blades. In this cutting movement, the coil 1701 in the pipe 1700 plays a part, by providing a body of the actuating fluid of considerable weight and moving at such a high velocity that its momentum will be effective in carrying the blades through the stock, there being required, therefore, less pressure to accomplish the severance. The heads of the valve-plunger 1716 are of different diameter, the upper head being larger. This gives an unbalanced effect of the pressure through the pipe 1700, so that when the operator releases the hand-lever, the excess of pressure upon the larger head raises the plunger to shut off pressure from the pipe 1708 and connect the latter to the exhaust-pipe to provide for the lowering of the piston. When this occurs, the outflow of oil from the cylinder is not limited to the contracted openings 1690, but may take place freely through the by-pass 1710 and the now open check-valve 1712, thus removing resistance to the piston-movement.

General procedure in forming a die

For the purpose of briefly outlining the manner in which my improved machine is used in the formation of a clicking die, let it be supposed that a vamp-die corresponding to the templet B (Fig. 133) is to be made. In connection with the outline of action of the feeding mechanism F, hot-bending mechanism G, cold-bending mechanism H and feeler or controlling mechanism L, particular attention should be given to the air-diagram of Fig. 132, and there borne in mind the relations of the main feeler-valve illustrated in Figs. 96 to 105, inclusive, and of the feeler and templet appearing in Figs. 106 to 118, inclusive. From the previous operation, the stock A has been left protruding between the abutments D, D, and selecting a point *a* upon the templet a short dis-

tance from a corner *b*, the stock may be bent with a hand-tool in accordance with the contour of the templet between this point and the corner. To this formed portion, the templet is then secured by one or more clips C, the corner *b* coming just within the points of the abutments. If, from the formation of a previous die, the carriage J (Figs. 22 and 34) has been left in the cutting position, a depression of the treadle 457 (Figs. 4 and 27) by the operator so moves the carriage by the admission of oil to the upper cylinder 445 that the hot-bending mechanism G is brought into operative relation below the abutments. In this location of the carriage, the projection 1132 (Figs. 34 and 50) upon the carriage-bar 1124 is beneath the actuating rod 1120 of the triple valve S, producing through this valve the necessary air-connections for the hot-bending operation. The feelers 1400 and 1402 (Fig. 36) of the mechanism L being in contact with the templet and stock, respectively, automatic operation may be initiated by the opening of the rail-valve 1608 and thus supplying air to the various pneumatic controlling mechanisms by way of the leakage-valve 1602. The templet-feeler has been placed by pressure in the air-cylinder 1440 (Fig. 83) in its rearward position peculiar to hot-bending. This bending operation involves, at first, feed of the stock, as a result of the application of air-pressure below the piston of the cylinder 324 (Fig. 5), opening the valve 310 to admit oil to the cylinders 224, 224 (Figs. 10 and 11) of the feeding mechanism F under the alternate control of the valve-plungers 226, 226. The advance of the stock by the feeding mechanism produces a travel of the templet past the feeler 1400 until this is allowed to spring behind the corner *b* out of the neutral zone, the foot 1522 (Fig. 92) falling off the templet upon which it has been resting. These and succeeding feeler-movements, combined with the admission of air to the feeler-cylinders 1510 (Fig. 83) and 1562 (Fig. 84) governed by the segment 1452 of the main feeler-valve (Figs. 83, 85, 87, 88, 89 and 90) cause the reciprocation and oscillation of said segment, first to reduce the rate of feed of the stock, under the influence of the cylinder 400 upon the valve 312 (Figs. 5 to 8, inclusive) and then stop the feed by the action of the valves 370 and 310, the former acting upon the latter through the cylinder 324. Coincidentally with the discontinuance of feed, there is application of pressure to the left-bending-control cylinder 732 (Figs. 34, 39, 40 and 41), resulting in the supply of oil under pressure to the corresponding cylinder 708 under the influence of its valve-plunger 714. This oil-pressure first brings the hot-bending member 600 (Fig. 36), with its normal rapid travel, into proximity with the stock, this movement being slowed prior

to contact of the bender with the stock, to prevent shock, by the bender-moving rack-bar 702 acting upon the air-valve 854 (Fig. 56) and controlling the valve 840 (Fig. 50) to throttle the flow of oil. When the bending member 600 is in firm contact with the stock, the back-pressure switch M, relay-valve N, secondary-circuit switch O and remote-control switch Q (Figs. 58 to 66, inclusive) act in succession to apply current to the stock through the bender and frame after contact has been made, to so soften said stock without burning as to facilitate the bending. At the time the bender reaches the stock, the valve 828 (Fig. 55) associated with the left-bending-control mechanism is opened as a result of the travel of the corresponding returning slide 764, and the leakage-valve 832 (Fig. 50) closes. This bars the way to cylinder 324 of the valve 310, so feed of the stock cannot take place during bending. While the heating is going on, the operator may attach to the protruding portion of the stock the engaging member 439 of the supporting arm 431 (Fig. 2). With the stock thus heated, the bending pressure is increased by the effect of the cam-surface 928 (Fig. 50), carried by the left-bending returning-slide 764, upon the valve 842, the opening through which is increased beyond that initially existing. When the angle produced in the bending operation has progressed to the point at which the pin 772 upon the slide 764 opens the switch R (Figs. 34 and 39), the devices N, O, P and Q are released and sever the heating circuit, while the member 600 is still in firm contact with the stock. In this way, burning is again avoided. When, as a result of the action of the bender, the templet arrives at a point at which the feeler 1400 is allowed to return to the neutral zone, air is shut off the left-bending cylinder 732, and when the slide 764 has reached the height, in effecting the return of the bender, at which the latter is out of the path of the stock, both feed-preventing valves 828 are closed, and the leakage device 832 is opened to permit air in the cylinder 324 to cause the resumption of feed of the stock.

The curve *c* is now to be formed by the use of the cold-bending mechanism H, the extent to which the bend is to go not being sufficient to demand the application of heat, and to give room for the association of the cold-bending members 1182, 1182 (Figs. 67, 69, 70 and 71) with the stock, the portion of the curve adjacent to the corner *b* is preferably formed with a hand-tool while the stock is still heated. For this purpose, the automatic control of the machine is discontinued by operating the rail-valve 1608 (Fig. 130), closing the leakage-valve 1602 (Fig. 34), which governs the main air-supply. If this manual control had for any reason been exerted during the operation of the bending

member 600, this would have been carried to its rearward position by the removal of air-pressure from the appropriate cylinder 800 (Fig. 39) and the consequent operation of the oil-valve 714. The feed of the stock during this period of manual bending is effected by closure of the rail-valve 354 (Fig. 129), this acting upon the leakage-valve 336 (Fig. 5) to supply air to the feed-controlling cylinder 324. The treadle 457 is again depressed by the operator, and the carriage J goes to the cold-bending position, as a result of the introduction of oil-pressure to the lower cylinder 445, it being stopped by the block 484 (Fig. 29). The depression 1134 in the bar 1124 is now aligned with the rod of the triple valve S, the connections of which are such as to properly exercise control of the cold-bending mechanism. Raising the hand-lever 1268 of the manual valve T (Fig. 77) brings the bending members 1182 into co-operation with the opposite sides of the stock by the admission of oil to the cylinder 1156 (Fig. 70), and at the valve 1342 places the control of their revolution under the influence of the automatic valve U (Fig. 78) governed by the feeler mechanism. If the angle at which the benders stood when lowered was not such as to correctly present them to the stock in their elevation, their angle may be changed by turning the lever 1268 and transmitting this movement mechanically to the valve U, the automatic action simultaneously being nullified by the opening of the rail-valve 1608. When the valve 1608 is released to restore automatic action, the bending of the stock begins, and, under the effect of the valve 340 (Fig. 84) in closing the valve 370, allows the feed to continue when the templet-feeler 1400 is in the intermediate zone, or that in which the differences in contour between the stock and templet are not great. The feeler is now in control of the valve-segment 1452, oscillated without vertical movement, by the departures of the stock from the templet. An exception to this absence of vertical displacement of the segment is found in the anticipating mechanism actuated by the piston 1578 (Fig. 94), which insures prompt response of the bender to feeler-control. The angular relation of the segment determines the admission of air, either above or below the piston of cylinder 1290 of the valve U, to cause such introduction of oil under pressure to the cylinder 1204 (Fig. 70) as to move the bending members 1182 either to the right or to the left. In this intermediate zone of action, to prevent over-correction, the oscillation of the benders is slowed by feeler-air applied to the valve 1376 (Fig. 67), which throttles the exhaust-oil from the bender-turning cylinder 1204. If the curve *c* carries the feeler 1400 outside the intermediate zone, then the valve 340 becomes ineffective, feed stops because the opening of the valve 370 is

now permitted, and the cold-benders act upon the stock at the normal higher rate of speed on account of the removal of air-pressure from the valve 1376. As the formation of the stock about the templet thus proceeds, these 5 may be attached to each other at properly separated points by the application of additional clips C.

Toward the end of the curve *c*, a re-entrant 10 angle *d* of the templet approaches the end of the abutments, and when this is in proximity to them, the automatic control is again thrown off by the rail-valve 1608, the cold-bender lowered manually and the machine treadled to return the hot-bending mechanism G to operative position. Generally, the 15 action of the apparatus upon the angle *d* is as for the angle *b*, though here the pull of the templet upon the feeler 1400, acting through the bell-crank lever 1540 (Fig. 83), is substituted for the effect of the foot 1522 and the feeler-governed devices for elevating the 20 segment 1452.

For the portion *e* of the templet, which approximates in contour the curvature of the 25 stock as it emerges from the abutments, automatic action would be unnecessary, the feed taking place under the control of the manual rail-valve 354, while the angle *f*, the curve *g* 30 and the angle *h* involve nothing which has not already been outlined. After the hot-bending at *h*, the cold-bending mechanism is brought into play to complete the long curved 35 portions *i*, *j*, *k*. Its operation here will be as for the curves *c* and *g*, save at the forward portion *j*. The curve of small radius may call 40 for an adjustment of the screw 1450 (Fig. 83) to bring the bending axis, as determined by the feeler 1400, farther forward, it being restored to its more rearward position when the 45 curve *j* has passed.

Upon reaching some such point as *l* upon the templet, actuation of the rail valve 1608 causes the machine to stop, and the bending 50 members 1182 are lowered by the depression of the handle 1268. Actuation of the treadle 457 shifts the carriage J idly to the hot-bending position, and then, by treadle 470, the carriage is moved oppositely to bring the 55 cutting mechanism I beneath the stock projecting from the abutments, the block 484 being elevated clear of the path of the carriage to give its full travel to the left. During the treadling of the machine, the operator 60 may feed forward the stock by closing the rail-valve 354 until a point *m* arrives over the cutting blades 1666 (Fig. 123). By lifting the hand-lever 1718, the operator admits oil through the valve 1702 to the cutter-cylinder 65 1686, whereupon the blades are raised and brought together to sever the stock, the velocity of approach being slowed, toward the termination of their travel, by the action of the projections 1695 upon the oil-conducting 70 openings 1690. Release of the handle by the

operator allows the valve 1702 to close and the cutting blades to descend to their initial position. The formed stock and the attached templet are now separated from the main body of the stock, and the machine is ready 75 for another operation. The die requires only the welding of the ends together to complete its forming to the templet.

Having described my invention, what I claim as new and desire to secure by Letters 75 Patent of the United States is:

1. In a machine for forming material, means for restricting the movement of the material, and a plurality of mechanisms each including a bending member for contact with the material to be formed and actuating means for such bending member, said mechanisms being arranged to be brought into initial co-operation with the restricting means in an operating position common to all. 80

2. In a machine for forming material, means for restricting the movement of the material, means for heating the material, forming mechanism arranged to operate upon the heated material, forming mechanism arranged to operate upon the material when cold, and means for bringing either of the forming mechanisms into co-operation with the restricting means. 90

3. In a die-bending machine, hot-bending 95 mechanism including heating means for the material to be bent, cold bending mechanism, and means for bringing either of said mechanisms into operative relation to the die-stock.

4. In a machine for forming material, 100 means for restricting the movement of the material, a plurality of bending mechanisms, a cutting mechanism, and a support common to said mechanisms and movable to bring any one into co-operation with the restricting 105 means.

5. In a machine for forming material, means for restricting the movement of the material, forming mechanism arranged to operate upon heated material, forming mechanism arranged to operate upon the material when cold, cutting mechanism, and means for bringing the mechanisms one at a time into co-operation with the restricting means for exclusive operation upon the material. 110

6. In a die-bending machine, hot-bending mechanism, cold-bending mechanism, mechanism for severing the completed die from the die-stock, and means for bringing any one of said mechanisms into operative relation to said stock and for simultaneously withdrawing a mechanism previously associated therewith. 115

7. In a machine for forming material, means for restricting the movement of the material, a carriage mounted to slide adjacent to the restricting means, a plurality of forming mechanisms mounted upon the carriage, each mechanism including operating and controlling elements, and means for mov- 120 125 130

ing the carriage to associate any one of the forming mechanisms with the restricting means.

8. In a die-bending machine, a reciprocatory carriage, hot-bending mechanism and cold-bending mechanism mounted upon the carriage, means associated with the hot-bending mechanism for heating the work, and mechanism for reciprocating the carriage to associate either of the bending mechanisms with the die-stock.

9. In a die-bending machine, a reciprocatory carriage, a plurality of bending mechanisms and a cutting mechanism mounted upon the carriage, and mechanism for reciprocating the carriage to associate any one of the mechanisms with the die-stock.

10. In a machine for forming material, separated abutments between which the material projects for its formation, a carriage movable in proximity to the abutments, a plurality of forming mechanisms mounted upon the carriage, and means for moving the carriage to bring any one of the forming mechanisms into co-operation with the abutments.

11. In a machine for bending material, separated abutments, means for feeding material between the abutments, a carriage movable beneath the abutments, a plurality of bending mechanisms and a cutting mechanism mounted upon the carriage, and means for reciprocating the carriage to bring any one of the mechanisms into co-operation with the abutments.

12. In a machine for forming material, means for restricting the movement of the material, a carriage mounted to move adjacent to the restricting means, a plurality of forming mechanisms movable upon the carriage, means for moving the carriage to bring any one of the forming mechanisms into co-operation with the restricting means, and means for moving the forming means upon the carriage into position to operate upon the material.

13. In a machine for forming material, separated abutments between which the material projects for its formation, a carriage movable in proximity to the abutments, a plurality of forming mechanisms movable upon the carriage, means for moving the carriage to bring any one of the forming mechanisms into co-operation with the abutments, and means for moving the forming mechanisms upon the carriage into and out of operative relation to the material.

14. In a machine for forming material, separated abutments between which the material projects for its formation, a carriage movable in proximity to the abutments, a plurality of forming mechanisms movable upon the carriage, means for moving the carriage to bring any one of the forming mechanisms into co-operation with the abutments, and means for moving the forming mechanisms upon the

carriage into and out of operative relation to the material and for thereafter actuating the mechanisms to form said material.

15. In a machine for bending material, separated abutments, means for feeding material between the abutments, a carriage mounted to reciprocate beneath the abutments, a plurality of bending mechanisms and a cutting mechanism movable upon the carriage, mechanism for reciprocating the carriage to bring any one of the mechanisms into co-operation with the abutments, and mechanism for elevating the bending and cutting mechanisms into position to operate upon the material.

16. In a machine for forming material, means for presenting the material for the forming operations, a carriage mounted to move adjacent to the presenting means, a plurality of forming mechanisms mounted upon the carriage, and means for applying fluid pressure to the carriage to associate any one of the forming mechanisms with the presenting means.

17. In a machine for forming material, means for presenting the material for the forming operations, a carriage mounted to move adjacent to the presenting means, a plurality of forming mechanisms mounted upon the carriage, stops located in the path of the carriage to determine the association of one or another of the forming mechanisms with the presenting means, and means for forcing the carriage into contact with the stops.

18. In a machine for forming material, means for presenting the material for the forming operations, a carriage mounted to slide adjacent to the presenting means, a plurality of forming mechanisms mounted upon the carriage for co-operation with the presenting means, stops located in the path of and adjustable toward and from the carriage, and fluid-pressure mechanism for forcing the carriage into contact with the stops.

19. In a machine for forming material, abutments between which material projects for its formation, a carriage mounted to slide adjacent to the abutments and having cylinders opening through its opposite ends, means for introducing fluid pressure to the cylinders, and a plurality of forming mechanisms mounted upon the carriage to be differently associated with the abutments upon the application of fluid pressure to the cylinders.

20. In a machine for forming material, abutments between which material projects for its formation, a carriage mounted to slide adjacent to the abutments and having cylinders opening through its opposite ends, means for introducing fluid pressure to the cylinders, a plurality of forming mechanisms mounted upon the carriage, and stops arranged for contact with the carriage to determine the association of one or another of the forming mechanisms with the abutments.

21. In a machine for forming material,

- abutments between which material projects for its formation, a carriage mounted to slide adjacent to the abutments and having cylinders opening through its opposite ends, tubular pistons fixed in position and extending into the cylinders, means for introducing fluid pressure to the cylinders through the pistons, and a plurality of forming mechanisms mounted upon the carriage to be differently associated with the abutments by the action of the fluid pressure.
22. In a machine of the class described, a movable carriage, a plurality of mechanisms mounted thereon and each constructed and arranged to perform an operation upon the work, and a stop movable into and out of the path of the carriage to receive contact of said carriage in its travel and determine the position of an operating mechanism.
23. In a machine of the class described, a movable carriage, a plurality of operating mechanisms mounted thereon, stops fixed in the path of the carriage to determine the co-operation of either of two mechanisms with the material to be formed, and a stop movable into and out of the path of the carriage to determine the co-operation of another of the operating mechanisms with the material.
24. In a machine of the class described, a movable carriage, a plurality of operating mechanisms mounted thereon, a stop movable into and out of the path of the carriage to determine the position of an operating mechanism, a latch arranged to hold the stop out of the path of the carriage, and automatic means for releasing the latch.
25. In a machine of the class described, a movable carriage, a plurality of operating mechanisms mounted thereon, a stop movable into and out of the path of the carriage to determine the position of an operating mechanism, a latch arranged to hold the stop out of the path of the carriage, and means acting in the movement of the carriage to release the latch and permit the stop to assume its active position.
26. In a machine of the class described, a movable carriage, a plurality of operating mechanisms mounted thereon, a stop movable into and out of the path of the carriage to determine the position of an operating mechanism, means arranged to hold the stop out of the path of the carriage, and means acting in the movement of the carriage to permit the stop to assume its active position, the stop after being thus freed contacting idly with the carriage during a portion of the movement thereof.
27. In a machine of the class described, a movable carriage, a plurality of operating mechanisms mounted thereon, a stop movable into and out of the path of the carriage to determine the position of an operating mechanism, and a latch arranged to hold the stop out of the path of the carriage, said carriage and latch being arranged for contact in the travel of the former to release said latch.
28. In a machine of the class described, a movable carriage, a plurality of operating mechanisms mounted thereon, a stop movable into and out of the path of the carriage to determine the position of an operating mechanism, and operator-controlled means for moving the stop.
29. In a machine of the class described, a movable carriage, a plurality of operating mechanisms mounted thereon, a stop movable into and out of the path of the carriage to determine the position of an operating mechanism, a latch arranged to hold the stop out of the path of the carriage, automatic means for releasing the latch, and operator-controlled means for moving the stop into engagement with the latch.
30. In a machine of the class described, a movable carriage, a plurality of operating mechanisms mounted thereon, a stop movable into and out of the path of the carriage to determine the position of an operating mechanism, a latch arranged to hold the stop out of the path of the carriage, means acting in the movement of the carriage to release the latch and permit the stop to assume its active position, and a treadle connected to the stop to restore it to its latched position.
31. In a machine for forming material, a reciprocatory carriage, a plurality of forming mechanisms mounted thereon, stops for the carriage situated at opposite ends of its path, and a block pivoted to swing from an inactive position to a point between the carriage and one of the stops.
32. In a machine for forming material, a reciprocatory carriage, a plurality of forming mechanisms mounted thereon, stops for the carriage situated at opposite ends of its path, a block pivoted to swing from an inactive position to a point between the carriage and one of the stops, and a latch arranged to engage the block in its inactive position.
33. In a machine for forming material, a reciprocatory carriage, a plurality of forming mechanisms mounted thereon, stops for the carriage situated at opposite ends of its path, a block pivoted to swing from an inactive position to a point between the carriage and one of the stops, a treadle, and connections between the treadle and block.
34. In a machine for forming material, a reciprocatory carriage, a plurality of forming mechanisms mounted thereon, stops for the carriage situated at opposite ends of its path, a block pivoted to swing from an inactive position to a point between the carriage and one of the stops, a latch arranged to engage the block in its inactive position, said latch having a portion arranged for contact

- with the carriage to release the block, a treadle, and connections between the treadle and block.
35. In a machine for forming material, means for presenting the material for the forming operations, a carriage mounted to move adjacent to the presenting means, a plurality of forming mechanisms mounted upon the carriage, means for applying fluid pressure to the carriage to associate one or another of the forming mechanisms with the presenting means, and means for alternately reversing the application of fluid pressure to the carriage.
36. In a machine for forming material, means for presenting the material for the forming operations, a carriage mounted to move adjacent to the presenting means, a plurality of forming mechanisms mounted upon the carriage, connections for applying fluid pressure to opposite ends of the carriage to effect its movement, and a valve in the connections, said valve being organized to reverse the flow therethrough.
37. In a machine for forming material, means for presenting the material for the forming operations, a carriage mounted to move adjacent to the presenting means, a plurality of forming mechanisms mounted upon the carriage, connections for applying fluid pressure to opposite ends of the carriage to effect its movement, a valve in the connections, a treadle, and connections between the treadle and valve organized to rotate said valve in successive steps in one direction.
38. In a machine for forming material, abutments between which material projects for its formation, a carriage mounted to slide adjacent to the abutments and having actuating cylinders opening through its opposite ends, a valve, conduits connecting the cylinders and valve, and fluid-pressure-supply and exhaust-conduits joined to the valve.
39. In a machine for forming material, abutments between which material projects for its formation, a carriage mounted to slide adjacent to the abutments and having actuating cylinders opening through its opposite ends, a valve, conduits connecting the cylinders and valve, fluid-pressure-supply and exhaust-conduits joined to the valve, a treadle, and ratchet-connections between the treadle and valve.
40. In a machine of the class described, a movable carriage, a plurality of operating mechanisms mounted thereon, mechanism for moving the carriage, and means both controlling the moving mechanism and acting upon the carriage to cause any one of the operating mechanisms to assume its active position.
41. In a machine of the class described, a movable carriage, a plurality of operating mechanisms mounted thereon, mechanism for moving the carriage, a plurality of treadles, and connections to the treadles organized to cause the moving mechanism to bring one or another of the forming mechanisms into its active position.
42. In a machine of the class described, a movable carriage, a plurality of operating mechanisms mounted thereon, fluid-pressure actuating mechanism for the carriage, means for governing said mechanism, a movable stop for the carriage, and operator-controlled means for actuating the governing means and stop.
43. In a machine for forming material, a movable carriage, a plurality of forming mechanisms mounted thereon, fluid-pressure actuating mechanism for the carriage, means for governing said mechanism, a movable stop for the carriage, and means for simultaneously actuating the governing means and stop.
44. In a machine for forming material, a movable carriage, a plurality of forming mechanisms mounted thereon, fluid-pressure actuating mechanism for the carriage, means for governing said mechanism, a movable stop for the carriage, means for simultaneously actuating the governing means and stop, and means for separately actuating the governing means.
45. In a machine for forming material, a movable carriage, a plurality of forming mechanisms mounted thereon, fluid-pressure actuating mechanism for the carriage, means for governing said mechanism, a movable stop for the carriage, means for simultaneously actuating the governing means and for rendering the stop ineffective, and means for separately actuating the governing means and stop.
46. In a machine for forming material, a movable carriage, a plurality of forming mechanisms mounted thereon, fluid-pressure actuating mechanism for the carriage, a valve governing the fluid pressure, a movable stop for the carriage, and a treadle movable to affect both the valve and stop.
47. In a machine for forming material, a movable carriage, a plurality of forming mechanisms mounted thereon, fluid-pressure actuating mechanism for the carriage, a valve governing the fluid pressure, a movable stop for the carriage, a treadle movable to affect both the valve and stop, and a treadle connected to the valve.
48. In a machine for forming material, a movable carriage, a plurality of forming mechanisms mounted thereon, fluid-pressure actuating mechanism for the carriage, a valve governing the fluid pressure, a movable stop for the carriage, a treadle connected to the stop, a treadle connected to the valve, and a member movable with the stop-treadle and acting upon the valve-treadle.
49. In a machine of the class described, movable operating mechanism, operator-con-

trolled means for governing the movement of the operating mechanism, and means acting in the operation of the machine for locking said governing means against actuation by the operator.

5. 50. In a machine of the class described, operating mechanism movable in successive steps into operating position, operator-controlled means for governing such movement, and means acting under the influence of the movement of the operating mechanism in one of its steps for preventing its movement in another of the steps.

15. 51. In a machine of the class described, a movable operating mechanism, automatic means for controlling the operation of the machine, means for rendering the controlling means active or inactive, operator-controlled means for governing the movement of the 20 operating mechanism, and means acting when the controlling means is active for locking the governing means against actuation by the operator.

25. 52. In a machine for forming material, means for restricting the movement of the material, a carriage mounted to move adjacent to the restricting means, a plurality of forming mechanisms mounted upon the carriage, means for determining the association 30 of one or another of the forming mechanisms with the restricting means, operator-controlled means for governing the movement of the carriage, and means for locking said governing means against actuation by the operator.

40. 53. In a machine for forming material, means for restricting the movement of the material, a carriage mounted to move adjacent to the restricting means, a plurality of forming mechanisms movable upon the carriage, means for determining the association of any one of the forming mechanisms with the restricted means, operator-controlled means for governing the movement of the carriage, a member for locking said governing means against actuation by the operator, and actuating connections between the locking member and a forming mechanism.

50. 54. In a machine for forming material, means for restricting the movement of the material, a carriage mounted to move adjacent to the restricting means, a plurality of forming mechanisms movable upon the carriage, means for determining the association of any one of the forming mechanisms with the restricting means, operator-controlled means for governing the movement of the carriage, a member for locking said governing means against actuation by the operator, and actuating connections between the locking member and each of the forming mechanisms.

55. 55. In a machine for forming material, means for restricting the movement of the material, a carriage mounted to move adja-

cent to the restricting means, a plurality of forming mechanisms mounted upon the carriage, means for controlling a forming mechanism in its operation, means for rendering the controlling means active or inactive, operator-controlled means for governing the movement of the carriage, a member for locking said governing means against actuation by the operator, and means acting when the controlling means is active for applying 75 the locking member.

70. 56. In a machine for forming material, abutments between which the material projects for its formation, a carriage mounted to slide adjacent to the abutments, a plurality 80 of forming mechanisms movable upon the carriage into and out of co-operation with the material, fluid-pressure connections including a valve for moving the carriage to associate different forming mechanisms with the abutments, connections for shifting the valve to cause the movement of the carriage, a locking member co-operating with the connections to prevent their operation, and actuating connections between the locking member 85 and the forming mechanisms.

57. 57. In a machine for forming material, abutments between which the material projects for its formation, a carriage mounted to slide adjacent to the abutments, a plurality 90 of forming mechanisms mounted upon the carriage, fluid-pressure mechanism for controlling the operation of the forming mechanisms, fluid-pressure connections including a valve for moving the carriage to associated 95 different forming mechanisms with the abutments, connections for shifting the valve to cause the movement of the carriage, a locking member co-operating with the connections to prevent their operation, and actuating connections between the locking member 100 and the fluid-pressure mechanism.

58. 58. In a machine for forming material, abutments between which the material projects for its formation, a carriage mounted to slide adjacent to the abutments, a plurality 110 of forming mechanisms movable upon the carriage into and out of co-operation with the material, fluid-pressure mechanisms for controlling the operation of the forming mechanisms, fluid-pressure connections including a valve for moving the carriage to associate different forming mechanisms with the abutments, connections for shifting the valve to cause the movement of the carriage, a locking member co-operating with the connections to prevent their operation, and actuating connections between the locking member 115 and the forming mechanisms and fluid-pressure mechanism.

120. 59. In a machine for forming material, forming mechanism movable from an inactive position toward its operating position, members for limiting such movement, one of said members being yieldable, and means 125

- acting in the yield of said member for varying its resistance to movement.
60. In a machine for forming material, means for presenting the material for the forming operations, a carriage movable adjacent to the presenting means, a plurality of forming mechanisms mounted upon the carriage to be brought by its movement into co-operation with the presenting means, contact members mounted upon the carriage and upon a relatively fixed element, one of said members being yieldable, and means acting in the yield of said member for producing therein a gradually increasing resistance.
61. In a machine for forming material, forming mechanism movable from an inactive position toward its operating position for the forming operation, means for applying fluid pressure to produce the movement, contact members for limiting such movement, one of said members being yieldable against the pressure of the fluid, and means for gradually increasing the resistance of the fluid to the yield of the member.
62. In a machine for forming material, means for presenting the material for the forming operations, a carriage movable adjacent to the presenting means and provided with a cylinder, connections for admitting fluid under pressure to the carriage-cylinder to produce its movement, a plurality of forming mechanisms mounted upon the carriage to be brought by its movement into co-operation with the presenting means, a stop for the carriage, a member for contact with the stop, said member being movable in a chamber joined to the cylinder, and means acting in the movement of the contact member for controlling the connections between the chamber and cylinder.
63. In a machine for forming material, means for presenting the material for the forming operations, a carriage movable adjacent to the presenting means and being provided with a cylinder, connections for admitting fluid under pressure to the carriage-cylinder to produce its movement, a plurality of forming mechanisms mounted upon the carriage to be brought by its movement into co-operation with the presenting means, a stop for the carriage, a member for contact with the stop, said member being movable in a chamber joined to the cylinder by a contracted passage, and a projection from the contact member acting in the movement of said contact member to control the area of the passage.
64. In a machine for bending material, a bending member, and means for imparting to the member a compound movement in intersecting planes for transferring it from one side of the material to be bent to the other side thereof.
65. In a machine for bending material, a bending member, means for imparting to the member a vertical movement elevating and depressing said member into and out of the plane of the material to be bent, and means for simultaneously imparting to the member a horizontal movement to transfer it from one side of the material to the other side thereof.
66. In a machine for bending material in accordance with a pattern, means for presenting material in a generally horizontal direction for the bending operation, a bending member, and means under the control of the pattern for moving the bending member vertically into and out of bending position and horizontally into contact with the material.
67. In a machine for bending material in accordance with a pattern, a bending member, means under the control of the pattern for elevating and depressing the bending member, and means for revolving said member about an axis outside itself.
68. In a machine for bending material, a bending member, means for elevating and depressing the bending member, and means for revolving said member about a plurality of axes each of which is outside the member.
69. In a forming machine, an oscillatory carrier, a forming member mounted upon the carrier at one side of the axis of oscillation, means for moving the carrier longitudinally of the axis, and means for imparting bodily movement to the carrier.
70. In a forming machine, an oscillatory carrier, a forming member revolvable upon the carrier, means for oscillating the carrier, means for revolving the forming member, and driving means common to both the oscillating and revolving means.
71. In a forming machine, an oscillatory carrier, a sleeve movable in the carrier, a forming member projecting eccentrically from the sleeve, a shaft about which the carrier is mounted to oscillate and move longitudinally, gearing connecting the shaft and sleeve, and cam mechanism connecting the shaft and carrier.
72. In a machine for forming material, a movable forming member, primary means for moving the member into co-operation with the material, secondary means acting upon the member in the same direction as the primary means and assisting in such movement by a force applied independently of the force exerted by the primary means, and still other means for imparting to the member its forming movement.
73. In a machine for forming material, a movable forming member, primary means for moving the member into co-operation with the material, secondary means for moving the member, and means for bringing the secondary means into action at predetermined periods in the operation of the primary means.
74. In a machine for forming material, a

movable forming member, primary means for moving the member into co-operation with the material, secondary means for moving the member, and means controlled by the 5 primary means for determining the time of operation of the secondary means.

75. In a machine for forming material, a movable forming member, primary means for moving the member into co-operation with 10 the material, secondary means for assisting in such movement, and means for controlling the operation of the primary means and for initiating the operation of the secondary means.

76. In a machine for forming material, a 15 movable forming member, primary means for moving the member into co-operation with the material, secondary means for assisting in such movement, and means for controlling the operation of the primary means and for 20 initiating the operation of the secondary means, the operation of the secondary means being modified by the primary means.

77. In a machine for forming material, a 25 movable forming member, means for elevating and depressing the member, means for oscillating the member, and auxiliary means for exerting an additional elevating force upon the member.

78. In a machine for bending material, 30 abutments between which the material projects for bending, a movable bending member, means for moving the bending member into co-operation with the abutments, means for imparting to the member a bending movement, and auxiliary means to assist one of 35 such movements.

79. In a machine for bending material, a 40 movable bending member, gearing and cam mechanism for imparting to the bending member different movements, and means for assisting the cam mechanism in moving the member and imparting such movement independently of said cam mechanism.

80. In a machine for bending material, a 45 movable bending member, gearing and cam mechanism for imparting to the bending member different movements, and fluid-pressure mechanism co-operating with the cam mechanism to move the bending member.

81. In a bending machine, a movable bending member, a driving shaft, actuating connections between the shaft and member, power mechanism connected to the bending member independently of the shaft, and controlling means for the power mechanism 50 operable by the shaft.

82. In a bending machine, a movable bending member, a driving shaft, actuating connections between the shaft and member, 55 power mechanism connected to the bending member, means for controlling the movement of the shaft, and connections to the controlling means for governing the power mechanism.

83. In a bending machine, a movable bend-

ing member, a driving shaft, actuating connections between the shaft and member, power mechanism connected to the bending member, means for controlling the movement of the shaft, connections to the controlling means for governing the power mechanism, and controlling means for the power mechanism operable by the shaft. 70

84. In a bending machine, a movable bending member, a driving shaft, cam mechanism connected to the shaft for elevating and depressing the bending member, a fluid-pressure cylinder associated with the bending member to assist in its elevation, a valve controlling the pressure to the cylinder, and a cam carried by the shaft and acting upon the valve.

85. In a die-bending machine, a movable bending member, a driving shaft, cam mechanism connected to the shaft for elevating and depressing the bending member, a fluid-pressure cylinder associated with the bending member to assist in its elevation, a valve controlling the pressure to the cylinder, fluid-pressure mechanism controlling the movement of the shaft, and connections to said fluid-pressure mechanism to actuate the valve.

86. In a die-bending machine, a movable bending member, a driving shaft, cam mechanism connected to the shaft for elevating and depressing the bending member, a fluid-pressure cylinder associated with the bending member to assist in its elevation, a valve controlling the pressure to the cylinder, fluid-pressure mechanism controlling the movement of the shaft, connections to said fluid-pressure mechanism to actuate the valve, and a cam carried by the shaft and acting upon the valve. 100

87. In a machine for bending material, a bending member movable from one side of the material to the other and then into contact therewith, and a fluid-pressure system arranged to cause such opposite movements of the bending member. 105

88. In a machine for bending material, a bending member movable into contact with opposite sides of the material, a shaft, mechanism for rotating the shaft in opposite directions, and connections between the shaft and bending member arranged to effect the transfer of said member laterally from one side of the material to the other. 115

89. In a machine for bending material, a bending member movable into contact with opposite sides of the material, a driving member, fluid-pressure mechanisms acting oppositely upon the driving member according to the direction in which the bending movement is to occur, and connections between the driving member and bending member. 120

90. In a machine for bending material, a bending member movable into contact with the material, hydraulic mechanisms arranged to move the bending member, and pneumatic 125

- mechanism for selectively controlling the hydraulic mechanisms.
91. In a machine for forming material, a forming member movable into contact with the material, a shaft, a pinion for rotating the shaft, opposite racks meshing with the pinion, and fluid-pressure means for actuating the racks. 70
92. In a machine for forming material, a forming member movable into contact with the material, a shaft, a pinion for rotating the shaft, opposite racks meshing with the pinion, pistons joined to the racks, cylinders in which the pistons operate, valves controlling the supply to the cylinders, and pneumatic mechanism for actuating the valves. 75
93. In a machine for forming material, a forming member movable against opposite sides of the material, mechanism for moving the forming member from a point removed from the material toward and into contact with one side of said material, and associated mechanism made effective in the operation of said moving mechanism for moving the forming member out of contact with said side of the material, such associated mechanism including means for carrying said forming member against the opposite side of the material. 80
94. In a machine for forming material, a movable forming member, and mechanisms for moving the forming member in opposite directions toward the material, each of said mechanisms controlling the associated mechanism to move the member from the material. 85
95. In a machine for forming material, a movable forming member, mechanisms for moving the forming member in opposite directions, and connections between the mechanisms acting upon the movement of one of said mechanisms to prepare the other for movement. 90
96. In a forming machine, a movable forming member, a plurality of mechanisms for moving the member, each including a valve, and connections between the mechanisms for shifting the valves. 95
97. In a machine of the class described, a movable operating member, and a plurality of mechanisms for moving the member, each including a valve and a fluid-pressure device for shifting the valve, said device acting upon an associated mechanism to prepare for the shifting of the valve of said mechanism. 100
98. In a machine of the class described, a movable operating member, and a plurality of mechanisms for moving the member, each including a valve, a fluid-pressure device and a spring for shifting the valve, said device acting upon the spring of an associated mechanism to prepare for the shifting of the valve of said mechanism. 110
99. In a machine of the class described, a movable operating member, a plurality of mechanisms for moving the member, each in- 115
- cluding a valve, a fluid-pressure device and a spring, connections between each fluid-pressure device and the spring of an associated mechanism to compress said spring, and connections between the mechanisms to control the expansion of the spring. 120
100. In a forming machine, a movable forming member, a plurality of mechanisms for moving the member, each including a valve, a fluid-pressure device and a spring, connections between each fluid-pressure device and the spring of an associated mechanism to compress said spring, and a latch for the spring, said latch being actuated in the operation of the mechanisms. 125
101. In a bending machine, a bending member movable in opposite directions to bend material, an hydraulic device for producing each movement, a valve for controlling the pressure in each hydraulic device, a pneumatic device having a piston acting upon each valve, levers connecting the pistons, springs co-operating with the levers and pistons, and connections between the pneumatic devices and one of the levers. 130
102. In a bending machine, a bending member movable in opposite directions to bend material, an hydraulic device for producing each movement, a valve for controlling the pressure in each hydraulic device, a pneumatic device having a piston acting upon each valve, levers connecting the pistons, springs co-operating with the levers and pistons, connections between the pneumatic devices and one of the levers, and a latch for said lever controlled in the movement of the bending member. 135
103. In a machine of the class described, a movable operating member, and a plurality of mechanisms for moving the operating member, each mechanism including a member set in motion after a predetermined extent of operation of a mechanism and controlling the operation of the mechanisms. 140
104. In a machine of the class described, a movable operating member, and a plurality of mechanisms for moving the operating member, each mechanism including a member set in motion after a predetermined extent of operation of a mechanism and acting to reverse the movement of the operating member. 145
105. In a machine of the class described, a movable operating member, a driving shaft for the member, two reciprocating actuating members arranged to oppositely rotate the shaft, fluid-pressure mechanism arranged to reciprocate each actuating member and including a valve, and a slide movable by each actuating member after a predetermined extent of travel, each slide in its movement controlling the valve of the fluid-pressure mechanism. 150
106. In a machine of the class described, a movable operating member, a driving shaft 155
- 65

for the member, two reciprocating actuating members arranged to oppositely rotate the shaft, fluid-pressure mechanism arranged to reciprocate each actuating member and including a valve, a lever connecting the mechanisms and controlling the valve, latches for the lever, and a slide movable by each actuating member after a predetermined extent of travel, the slides in their movement acting upon the latches.

107. In a machine of the class described, a movable operating member, a driving shaft for the member, two reciprocating actuating members arranged to oppositely rotate the shaft, fluid-pressure mechanism arranged to reciprocate each actuating member and including a valve and a spring for shifting the valve, a lever connecting the mechanisms and co-operating with the springs, latches for the lever, and a slide movable by each actuating member after a predetermined extent of travel, the slides in their movement acting upon the latches.

108. In a machine for forming material, a movable forming member, mechanism for moving the forming member toward the material, mechanism made effective in the operation of said moving mechanism for moving the forming member from the material, and means for stopping the movement of the member from the material at a predetermined point.

109. In a machine for forming material, a movable forming member, mechanism for moving the forming member toward the material, mechanism made effective in the operation of said moving mechanism for moving the forming member from the material, and means for stopping the movement of the member from the material at a point determined by an element of the moving mechanism.

110. In a machine for bending material, means for restricting the movement of the material, a bending member co-operating with the restricting means and movable from an extreme inactive position into contact with the material, means for moving the bending member toward the material to produce the bending effect and then moving it from said material, and means for stopping the movement of the member from the material at a point short of its extreme inactive position.

111. In a machine for bending material, means for restricting the movement of the material, means for advancing the material from the restricting means for the bending operation, a bending member co-operating with the restricting means and movable from an extreme inactive position into contact with the material and in the path of advance of the material, means for moving the bending member toward the material to produce the bending effect and then moving it from said material, and means for stopping the move-

ment of the member from the material at a point short of its extreme inactive position but out of the path of the material.

112. In a machine for bending material, means for restricting the movement of the material, a bending member cooperating with the restricting means and movable from an extreme inactive position in opposite directions into contact with the material, means for moving the bending member toward the material to produce the bending effect and then moving it from said material, and means actuated by an element of the moving means for stopping the movement of the member from the material at a point short of its extreme inactive position.

113. In a forming machine, a movable forming member, a plurality of mechanisms for moving the member, each including a controlling member, connections between the mechanisms for shifting the controlling members, and means for causing the operation of the controlling member at a predetermined point in the movement of the forming member.

114. In a machine of the class described, a movable operating member, and a plurality of mechanisms for moving the operating member, each mechanism including a member set in motion after a predetermined extent of operation of a mechanism and acting to stop the movement of the operating member.

115. In a machine of the class described, a movable operating member, a driving shaft for the member, two reciprocating actuating members arranged to oppositely rotate the shaft, fluid-pressure mechanism arranged to reciprocate each actuating member and including a valve, a slide movable by each actuating member after a predetermined extent of travel, and means for returning the slides to their initial positions, each slide in its return movement acting to close the valve of the fluid-pressure mechanism.

116. In a machine for forming material, a movable forming member, mechanism for moving the forming member from an inactive position in opposite directions, and means for stopping the member in an extreme inactive position.

117. In a machine for forming material, a movable forming member, mechanism for moving the forming member from an inactive position in opposite directions, means for stopping the member in an extreme inactive position, and means for stopping the member in a position short of such extreme position.

118. In a machine for forming material, a movable forming member, mechanism for moving the forming member from different inactive positions toward the material, mechanism for controlling the extent and direction of such movement, which mechanism may be effective or ineffective for control, and

- means for stopping the movement of the member in its extreme position when the controlling mechanism is ineffective.
119. In a machine for forming material, a movable forming member, mechanism for moving the forming member from different inactive positions toward the material, mechanism for controlling the extent and direction of such movement, which mechanism 5 may be effective or ineffective for control, means for stopping the movement of the member in its extreme position when the controlling mechanism is ineffective, and means for stopping the movement of the member 10 short of its extreme position when said controlling mechanism is effective.
120. In a machine of the class described, a movable operating member, fluid-pressure mechanism for moving the member including 20 a valve, mechanism effective to control the operation of the valve, and auxiliary means for shifting the valve, the controlling mechanism while effective preventing the operation of the auxiliary means.
121. In a machine of the class described, 25 a movable operating member, fluid-pressure mechanism for moving the member including a valve, fluid-pressure mechanism effective to control the operation of the valve, auxiliary 30 means for shifting the valve, and means for applying the fluid pressure to the auxiliary means for preventing its operation when the controlling mechanism is effective.
122. In a machine of the class described, 35 a movable operating member, fluid-pressure mechanism for moving the member including a valve, mechanism effective to control the operation of the valve, a spring acting upon the valve to cause the movement of the member, and connections to the controlling mechanism to prevent the action of the spring.
123. In a machine of the class described, 40 a movable operating member, a fluid-pressure mechanism for moving the member including a valve, mechanism effective to control the operation of the valve, a spring acting upon the valve to cause the movement of the member, and connections to the controlling mechanism permitting the spring to act only when 45 said controlling mechanism is ineffective.
124. In a machine for forming material, a movable forming member, mechanism for moving the forming member from an intermediate position in opposite directions toward and from the material, and means for stopping the movement of the member from the material, the stopping point being determined by the extent of travel of an element of the moving mechanism.
125. In a machine for forming material, a 50 movable forming member, mechanism for moving the forming member toward and from the material, mechanism for controlling the moving mechanism, and means governed by the moving mechanism and controlling mechanism for stopping the movement of the member.
126. In a machine for forming material, a movable forming member, fluid-pressure mechanism for moving the forming member toward and from the material, said mechanism including a valve and a reciprocatory member, fluid-pressure mechanism for controlling the valve, a spring acting upon the valve, and means connected to the controlling mechanism and co-operating with the reciprocatory member of the moving mechanism for preventing the action of the spring. 70
127. In a machine for forming material, a movable forming member, fluid-pressure mechanism for moving the forming member toward and from the material, said mechanism including a valve and a reciprocatory member, fluid-pressure mechanism for controlling the valve, a spring acting to open the valve, and a lever resisting the action of the spring and controlled by the fluid pressure and by the reciprocatory member. 80
128. In a machine for forming material, means for advancing the material to be 85 formed, a forming member movable toward and from the material, a controlling member actuated in the movement of the forming member, and means governed by the controlling member for changing the action of the advancing means. 90
129. In a machine for forming material, means for advancing the material to be 95 formed, a forming member movable into the path of the material, and means for preventing the advance of the material when the forming member is in its path. 100
130. In a machine for forming material, means for advancing the material to be 105 formed, a forming member movable toward and from the material, mechanism for causing the movement of the forming member, a controlling member actuated in the operation of the moving mechanism only after the forming member has reached a predetermined point, and means governed by the controlling member for stopping the advancing means. 110
131. In a machine for forming material, means for advancing the material to be 115 formed, a forming member movable toward and from the material, mechanism for causing the movement of the forming member, a controlling member actuated in the operation of the moving mechanism only after the forming member has reached a predetermined point, a valve governed by the controlling member, and fluid-pressure connections between the valve and advancing means. 120
132. In a machine for bending material, separated abutments, mechanism for feeding material between the abutments, a bending member movable into the path of the material, mechanism for producing the bending movement, a controlling member movable 125
- 130

after a predetermined movement of the bending member, and connections between the controlling member and feeding mechanism.

133. In a machine for bending material, separated abutments, mechanism for feeding material between the abutments, a bending member movable into the path of the material, a plurality of mechanisms for producing the bending movement, a controlling member movable by each of these mechanisms when the bending member reaches the path of the material, and connections between the controlling members and the feeding mechanism acting upon the movement of a controlling member to prevent the operation of the feeding mechanism.

134. In a machine for bending material, separated abutments, mechanism for feeding material between the abutments, a bending member movable into the path of the material, mechanism for producing the bending movement, a controlling member movable after a predetermined movement of the bending member, a valve governed by the controlling member, and fluid-pressure connections between the valve and feeding mechanism.

135. In a machine for forming material, means for advancing the material to be formed, a forming member movable toward and from the material, a pneumatic system containing a leak governed in the movement of the forming member, a leakage device under the influence of said leak, and means governed by the leakage device for changing the action of the advancing means.

136. In a machine for bending material, separated abutments, mechanism for feeding material between the abutments, a bending member movable into the path of the material, mechanism for producing the bending movement, a controlling member movable after a predetermined movement of the bending member has been produced, a pneumatic system containing a leak governed by the controlling member, a leakage-valve in the pneumatic system, and means controlled by the leakage-valve to prevent the operation of the feeding mechanism.

137. In a machine for forming material, a movable forming member, means for moving the member, and independent controlling means for varying the rate of movement of the member and the force which it exerts, both of said controlling means being simultaneously effective.

138. In a machine for bending material, a movable bending member, means for moving the member, means depending upon the position of the member for varying its rate of movement, and means acting after the contact of the member with the material for varying the force which it exerts.

139. In a machine for bending material, a movable bending member, fluid-pressure

mechanism for moving the member at different rates, and fluid-pressure means for changing the rate of fluid-flow to vary the rate of movement of the bending member.

140. In a machine for bending material, a movable bending member, fluid-pressure connections for moving the member, a valve in the connections, and automatic means dependent in its operation upon the relation between the bending member and the material before said bending member reaches said material for actuating the valve.

141. In a machine for bending material, a movable bending member, means for moving the member, and means under the influence of an element of the moving means for changing the rate of travel of the bending member as it approaches the material.

142. In a machine for bending material, a movable bending member, means for moving the member, and means dependent upon the position of the member for varying its rate of movement while permitting its advance for bending to continue.

143. In a machine for bending material, a movable bending member, means for moving the member from a position separated from the material into contact therewith, and means for slowing the member as it approaches the material, the member prior to such approach being free from the effect of the slowing means.

144. In a machine for bending material, a movable bending member, mechanism for moving the member into contact with the material, and means controlled by an element of the moving mechanism for varying the rate of movement of the member prior to its contact with the material.

145. In a machine for bending material, a movable bending member, fluid-pressure mechanism for moving the member into contact with the material, and means controlled by an element of the moving mechanism for varying the rate of flow of the fluid to said mechanism while permitting such flow to continue.

146. In a machine for forming material, a movable forming member, fluid-pressure mechanism for moving the member into contact with the material, a conduit for supplying fluid to said mechanism, a valve in the conduit, and fluid pressure connections controlled by the movement of an element of the moving mechanism for shifting the valve.

147. In a machine of the class described, a movable operating member, fluid-pressure mechanism for moving the member, a conduit for supplying fluid to said mechanism, a valve arranged to throttle the flow through the conduit, a piston connected to the valve, and a pneumatic system acting upon the piston and controlled by an element of the moving mechanism.

148. In a machine of the class described, a

movable operating member, mechanism for moving the member, and a pneumatic system for controlling the moving mechanism including a leak and a leakage-valve governed by said leak, an element of the moving mechanism acting to control the leak.

149. In a machine for bending material, a movable bending member, a plurality of mechanisms for moving the member in opposite directions and each including a reciprocating element, and a pneumatic system for controlling the moving mechanism including a leak and a leakage-valve governed by said leak, elements of both moving mechanisms acting in their reciprocation to control the leak.

150. In a machine for bending material, a movable bending member, fluid-pressure mechanism for moving the member into contact with the material, a conduit for supplying fluid to said mechanism, a valve in the conduit, connections controlled by the movement of an element of the moving mechanism for shifting the valve, and means arranged to vary the time of action of such element of the connections.

151. In a machine for bending material, a movable bending member, mechanism for moving the member including a reciprocating element, a pneumatic system for controlling the moving mechanism including a leak and a leakage-valve governed by said leak, the element of the moving mechanism acting in its reciprocation to close the leak, and means arranged to vary the time in the movement of the element at which the leak is closed.

152. In a machine for forming material, an oscillatory forming member, a driving shaft for the member, a pinion and a rack-bar for rotating the shaft, mechanism for reciprocating the rack-bar, and means actuated by the rack-bar for controlling the reciprocating mechanism.

153. In a machine for forming material, an oscillatory forming member, a driving shaft for the member, a pinion and a rack-bar for rotating the shaft, hydraulic mechanism for reciprocating the rack-bar, and pneumatic mechanism for controlling the hydraulic mechanism and including a leak-opening governed in the movement of the rack-bar.

154. In a machine for bending material, an oscillatory bending member, a driving shaft for the member, a pinion and a rack-bar for rotating the shaft, hydraulic mechanism for reciprocating the rack-bar, pneumatic mechanism for controlling the hydraulic mechanism and including a leak-opening, a closure governing the leak-opening, and friction connections between the rack-bar and closure.

155. In a machine for bending material, an oscillatory bending member, a driving

shaft for the member, a pinion and a rack-bar for rotating the shaft, hydraulic mechanism for reciprocating the rack-bar, pneumatic mechanism for controlling the hydraulic mechanism and including a leak-opening, a closure governing the leak-opening under the influence of the rack-bar, and means arranged to vary the normal relation between the rack-bar and closure.

156. In a machine of the class described, a movable operating member, means for moving the member, means for varying the rate of movement of the member, and means for nullifying the effective action of the rate-varying means.

157. In a machine for forming material, a movable forming member, means for moving the member from a position separated from the material into contact therewith, means for varying the rate of movement of the member by slowing it as it approaches the material and accelerating it as it retreats therefrom, and means for nullifying the accelerating action.

158. In a machine for bending material, a movable bending member, mechanism for moving the member into contact with the material, means controlled by an element of the moving mechanism for varying the rate of movement of the member, and means also controlled by said element for modifying the action of the rate-varying means.

159. In a machine for bending material, a movable bending member, fluid-pressure mechanism for moving the member into contact with the material, a conduit for supplying fluid to said mechanism, a valve in the conduit, a piston connected to the valve, a pneumatic system acting upon the piston and controlled by an element of the moving mechanism, and means for compensating for delay in the effective action of the pneumatic system.

160. In a machine for bending material, a movable bending member, mechanism for moving the member including a reciprocating element, and a pneumatic system for controlling the moving mechanism including a leak and a leakage-valve governed by said leak, the element of the moving mechanism acting in its reciprocation to both close and open the leak and being provided with auxiliary means to modify one of such actions.

161. In a machine for bending material, a movable bending member, mechanism for moving the member including a reciprocating element, and a pneumatic system for controlling the moving mechanism including a leak and a leakage-valve governed by said leak, the element of the moving mechanism acting in its reciprocation to both close and open the leak and being provided with auxiliary means to anticipate the closing of the leak.

162. In a machine for forming material,

a movable forming member, means arranged to move the forming member normally at a certain rate, automatic means for changing the rate, and means arranged to determine such rate.

163. In a machine for bending material, a movable bending member, fluid-pressure connections for moving the member, a valve in the connections, automatic means for actuating the valve, and an adjustable stop limiting the movement of the valve.

164. In a machine for bending material, a movable bending member, means for moving the member, means dependent upon the position of the member for varying its rate of movement, and means adjustable to determine the degree of variation.

165. In a machine for bending material, a movable bending member, fluid-pressure means for moving the member, a valve for controlling the flow of fluid to vary the rate of movement, automatic means for actuating the valve, and means adjustable to vary the extent of movement of the valve.

166. In a machine for bending material, a movable bending member, fluid-pressure means for moving the member, a valve for controlling the flow of fluid to vary the rate of movement, a pneumatic system for moving the valve, and an adjustable stop against which the valve is moved by the pneumatic system.

167. In a machine of the class described, a movable member for operating upon material, fluid-pressure means for moving the member into contact with the material, and means acting after contact of the operating member with the material for varying the degree of fluid pressure applied by the moving means.

168. In a machine of the class described, a movable member for operating upon material, fluid-pressure means for moving the member into contact with the material, means under control of the fluid pressure for heating the material, and means acting after the application of heat to the material for varying the force exerted by the moving means.

169. In a machine for forming material, a movable member for operating upon the material, fluid-pressure means for moving the member into contact with the material, means under the control of the fluid pressure for heating the material, and means acting after the contact of the member with the material and after the application of heat to the material for varying the degree of fluid pressure applied to the operating member.

170. In a machine for bending material, a movable bending member, hydraulic mechanism for moving the member into bending contact with the material, and means operative only after the bending of the material has begun for increasing the flow of liquid

to augment the bending pressure of the member.

171. In a machine for bending material, a movable bending member, hydraulic mechanism for moving the member into bending contact with the material, means for applying heat to the material under the influence of back pressure in the hydraulic system, and means for increasing the pressure of the bending member upon the material after such application.

172. In a machine for operating on material, an operating member movable in contact with the material, a fluid-pressure system for moving the member including a balanced valve through which flows the fluid producing the pressure, and means for affecting the balance of the valve to vary the pressure exerted by the member.

173. In a machine for operating on material, an operating member movable in contact with the material, a fluid-pressure system for moving the member including a valve movable by the fluid pressure, a spring acting upon the valve to balance the fluid pressure, and means acting in the operation of the machine for altering the force of the spring to vary the pressure exerted by the member.

174. In a machine for operating on material, an operating member movable in contact with the material, a fluid-pressure system for moving the member including a valve movable by the fluid pressure, a spring acting upon the valve to balance the fluid pressure, means for altering the force of the spring to vary the pressure exerted by the member, and means arranged to adjust the force of the spring.

175. In a machine for bending material, a bending member, fluid-pressure mechanism for moving the bending member including a valve for determining the bending pressure, said valve being positioned by the fluid-pressure upon it, an element traveling as the material bends, and means operated by said element for controlling the valve.

176. In a machine for bending material, a bending member, fluid-pressure mechanism for moving the bending member including a valve for determining the bending pressure, and means controlled by an element of the moving mechanism to open the valve and increase the bending pressure.

177. In a machine for bending material, a bending member, fluid-pressure mechanism for moving the bending member including a valve for determining the bending pressure, and a spring acting against the fluid pressure to normally balance the valve, an element of the moving mechanism cooperating in its travel with the valve to change the force of the spring.

178. In a machine of the class described, a plurality of operating mechanisms, means for positioning said mechanisms selectively

for operation, means for controlling the operating mechanisms, and means depending upon the particular mechanism thus positioned for connecting the controlling means to cooperate with it.

179. In a machine for forming material, a movable carriage, a plurality of forming mechanisms mounted upon the carriage and arranged to be positioned selectively for operation, means for controlling the operating mechanisms, and means governed in the movement of the carriage for adapting the controlling means to co-operate with the positioned operating mechanism.

180. In a machine for forming material, a movable carriage, a plurality of forming mechanisms mounted upon the carriage and arranged to be positioned selectively for operation, mechanism including fluid-pressure connections for controlling the operating mechanisms, and a valve governed in the movement of the carriage to alter the connections.

181. In a machine for bending material, a hot-bending mechanism, cold-bending mechanism, means for relatively moving the mechanisms and material so that either of said mechanisms may operate upon the material, a controlling system for the bending mechanisms having different groups of devices, and means for differently associating the groups of devices with the particular bending mechanism which is in operating position.

182. In a machine for bending material, a hot-bending mechanism, cold-bending mechanism, a carriage upon which the bending mechanisms are mounted, said carriage being movable to bring either of the bending mechanisms into co-operation with the material, a fluid-pressure system organized for different connection to respectively control the bending mechanisms, a valve for governing such connections, and means for shifting the valve in the movement of the carriage.

183. In a machine for bending material, a hot-bending mechanism, cold-bending mechanism, a carriage upon which the bending mechanisms are mounted, mechanism for moving the carriage to bring either of the bending mechanisms into cooperation with the material, a fluid-pressure system organized for different connection to respectively control the bending mechanisms, a valve for governing such connections, and a member movable by the carriage and having differently arranged contact-portions for governing the valve.

184. In a machine of the class described, a plurality of operating mechanisms, means for positioning said mechanisms selectively for operation, means for controlling the operating mechanisms, means depending upon the particular mechanism thus positioned for connecting the controlling means to co-op-

erate with it, and means for rendering the connecting means ineffective when one of the operating mechanisms is in operating position.

185. In a machine for forming material, a movable carriage, a plurality of forming mechanisms mounted upon the carriage and arranged to be positioned selectively for operation, mechanism including fluid-pressure connections for controlling the operating mechanisms, a valve governed in the movement of the carriage to alter the connections, and means for preventing the movement of the carriage from affecting the valve.

186. In a machine for bending material, a hot-bending mechanism, cold-bending mechanism, cutting mechanism, means for relatively moving the mechanisms and material so that any one of said mechanisms may operate upon the material, a controlling system for the bending mechanisms having different groups of devices, means for differently associating the groups of devices with the particular bending mechanism which is in operating position, and means for nullifying the effect of the associating means when the cutting mechanism is brought into operating position.

187. In a machine for bending material, a hot-bending mechanism, cold-bending mechanism, a carriage upon which the bending mechanisms are mounted, mechanism for moving the carriage to bring either of the bending mechanisms into co-operation with the material, a fluid-pressure system organized for different connection to respectively control the bending mechanisms, a valve for governing such connections, means for shifting the valve in the movement of the carriage, and a lock for the valve effective during a portion of the movement of the carriage.

188. In a machine for forming material, a reciprocatory carriage, a plurality of forming mechanisms mounted upon the carriage, means for reciprocating the carriage to its extremes of movement to bring either of two forming mechanisms into operating position, means for stopping the carriage in an intermediate position to provide for the operation of another mechanism, means for controlling the operation of the mechanisms, means variable in position to connect the controlling means to one or another of two forming mechanisms, and connections to the stopping means for preventing the action of the connecting means.

189. In a machine for forming material, a reciprocatory carriage, a plurality of forming mechanisms mounted upon the carriage, motor mechanism for reciprocating the carriage to its extremes of movement to bring either of two forming mechanisms into operating position, a stop movable into the

- path of the carriage, controlling mechanism for the operating mechanisms, variable connections between the controlling mechanism and two forming mechanisms to render them selectively effective, and a lock for the connections actuated in the movement of the stop.
190. In a die-forming machine, a reciprocating carriage provided with actuating surfaces, hot-bending mechanism, cold-bending mechanism and cutting mechanism mounted upon the carriage, fluid-pressure mechanism for reciprocating the carriage to its extremes of movement to bring either a bending mechanism or the cutting mechanism into operative position, a stop movable into the path of the carriage to operatively position the other bending mechanism, controlling mechanism for the two bending mechanisms, a valve for connecting the controlling mechanism to either of the bending mechanisms, said valve being under the influence of the actuating surfaces upon the carriage during its movement, and a member connected to be moved by the stop to prevent the operation of the valve when said stop is in its ineffective position.
191. In a bending machine, a movable bending member, power mechanism for moving the member, operator-controlled means for governing the application of power to the bending member, and automatic means for governing such application of power both as initiated by the operator-controlled means and through initiation independently thereof.
192. In a bending machine, a movable bending member normally out of position to operate upon the material, power mechanism for moving the member, operator-controlled means for governing the application of power to move the bending member into operating position, and automatic means for governing the application of power to impart the bending movement to the member.
193. In a bending machine, a movable bending member normally out of position to operate upon the material, power mechanism for moving the member, operator-controlled means for governing the application of power to both move the bending member into operating position and to effect the bending operation, and automatic means for governing the application of power to impart the bending movement to the member.
194. In a bending machine, a movable bending member normally out of position to operate upon the material, power mechanism for moving the member, operator-controlled means for governing the application of power to move the bending member into operating position, automatic means for governing the application of power to impart the bending

movement to the member, and operating connections between the operator-controlled and automatic means.

195. In a machine for bending material, movement-restricting means, a bending member movable from below the restricting means into co-operation therewith, power mechanism, means for governing the application of power to elevate the bending member, and means for governing the application of power to the bending member to effect a bending of the material.

196. In a machine for bending material, movement-restricting means, a bending member movable from below the restricting means into co-operation therewith, power mechanism, operator-controlled means for governing the application of power to elevate the bending member, and automatic means for governing the application of power to the bending member to effect a bending of the material.

197. In a machine for forming material, a reciprocating and oscillatory forming member, a source of power, connections to the power source for reciprocating the forming member, connections to the power source for oscillating the member, and means for governing independently the reciprocating and oscillating connections.

198. In a machine for forming material, a reciprocating and oscillatory forming member, means for reciprocating the forming member, means for oscillating the member, operator-controlled means for governing the reciprocating and oscillating means, and automatic means for governing the oscillating means.

199. In a machine for bending material, a movable carrier, a bending member movable upon the carrier, fluid-pressure mechanism for moving independently the carrier and member, and valves associated with the mechanism for separately governing the movements.

22. In a machine for bending material, a movable carrier, a bending member movable upon the carrier, a fluid-pressure mechanism for moving the carrier and member, an operator-controlled valve arranged to apply fluid pressure to the carrier, and an automatically operated valve arranged to apply fluid pressure to the bending member.

201. In a machine for bending material, a movable carrier, a bending member movable upon the carrier, fluid-pressure mechanism for moving the carrier and member, an operator-controlled valve arranged to apply fluid pressure to the carrier, an automatically operated valve arranged to apply fluid pressure to the bending member, and connections whereby the operator-controlled valve may govern the automatic valve.

202. In a machine of the class described, a movable carriage, operating mechanisms mounted upon the carriage, fluid-pressure connections for effecting the movement of the carriage, and connections upon the carriage for supplying the fluid pressure delivered thereto to the operating mechanisms. 70
203. In a machine of the class described, a movable carriage, operating mechanisms mounted upon the carriage, fluid-pressure connections for effecting the movement of the carriage, connections upon the carriage for supplying the fluid pressure delivered thereto to the operating mechanisms, and a valve movable upon the carriage for controlling the effect of the fluid pressure upon an operating mechanism. 75
204. In a machine for forming material, a movable forming member, fluid-pressure mechanism for moving the member, a valve arranged for movement in a plurality of directions to govern the pressure and thus the movement of the forming member, and retaining means arranged to hold the valve at the point to which it is moved in each direction. 80
205. In a machine for forming material, a movable forming member normally occupying an inoperative position, fluid-pressure mechanism for moving the member, and a valve for governing the pressure and having a plunger movable longitudinally to cause the movement of the forming member into and out of operating position and rotatable to cause the forming movement. 85
206. In a machine for forming material, a movable forming member normally occupying an inoperative position, fluid-pressure mechanism for moving the member, a valve for governing the pressure and having a plunger movable longitudinally to cause the movement of the forming member into and out of operating position and rotatable to cause the forming movement, and a latch movable with the plunger, there being an arcuate groove for engagement with the latch at each extreme of movement of the plunger. 90
207. In a machine for forming material, a movable forming member normally occupying an inoperative position, fluid-pressure mechanism for moving the member, a valve for governing the pressure and having a plunger movable longitudinally to cause the movement of the forming member into and out of operating position and rotatable to cause the forming movement, and a latch movable with the plunger, there being an arcuate groove for engagement with the latch at each extreme of movement of the plunger, each groove containing a series of depressions engaging the latch in the rotation of the plunger. 95
208. In a forming machine, a movable forming member normally occupying an inoperative position, fluid-pressure mecha- 100
- nism for moving the member, and a valve for governing the pressure and oppositely movable to cause the travel of the forming member into and out of operating position. 105
209. In a forming machine, a movable forming member normally occupying an inoperative position, fluid-pressure mechanism for moving the member, and a valve having ports for applying the fluid pressure to the moving mechanism and a plunger movable to govern the flow through the ports and consequently the movement of the forming member into and out of operating position. 110
210. In a machine for bending material, movement-restricting means, a bending member movable from below the restricting means into co-operation therewith, fluid-pressure mechanism for moving the member, and a valve having ports for applying the fluid pressure to the moving mechanism and a plunger vertically movable to govern the flow through the ports, said plunger being arranged when raised to cause the elevation of the forming member to the operating position. 115
211. In a machine for bending material, a movable bending member, power mechanism for moving the member, a rotatable controlling member, and means for connecting the power mechanism to the bending member to move said bending member to an extent corresponding to the angle through which the controlling member is rotated. 120
212. In a machine for bending material, a movable bending member, power mechanism for moving the member, a rotatable controlling member, means for connecting the power mechanism to the bending member to move said bending member to an extent corresponding to the angle through which the controlling member is rotated, and means operated in the movement of the bending member for disconnecting the power mechanism and bending member. 125
213. In a machine for bending material, an oscillatory bending member, fluid-pressure mechanism for oscillating the member, a rotatable controlling member, a valve opened by said controlling member to apply fluid pressure to the member, and means operating independently of the controlling member for closing the valve. 130
214. In a machine for bending material, a movable bending member, power mechanism for moving the member, a rotatable controlling member, means for connecting the power mechanism to the bending member to move said bending member to an extent corresponding to the angle through which the controlling member is rotated, and means movable in the movement of the bending member for closing the valve. 135
215. In a machine of the class described, an oscillatory operating member, fluid-pressure mechanism for oscillating the member, 140

a valve for controlling the application of fluid pressure to the operating member, a rotatable handle, an actuating member movable by the handle and connected to the valve to move it, and automatic means for moving the actuating member in a direction opposite to that produced by the handle.

216. In a machine of the class described, an oscillatory operating member, fluid-pressure mechanism for oscillating the member, a valve for controlling the application of fluid pressure to the operating member, a rotatable handle, an actuating member movable by the handle and connected to the valve to move it, and connections for moving the actuating member from the operating member.

217. In a machine for bending material, a movable bending member, fluid-pressure mechanism for moving the member, a reciprocatory valve for governing the application of pressure to the member, a handle, a segment rotatable by the handle and acting upon the valve, and mechanism acting on the segment to shift it bodily in its rotation and thereby reciprocate the valve.

218. In a machine for bending material, a movable bending member, power mechanism for moving the member, means arranged to be set for connecting the power mechanism to move the bending member, and automatic means for disconnecting the power mechanism after movement of the bending member determined in extent by the setting of the connecting means.

219. In a machine for bending material, a movable bending member, power mechanism for moving the member, means arranged to be set for connecting the power mechanism to move the bending member, and connections between the bending member and connecting means for actuating said connecting means at a time determined by its setting.

220. In a machine for bending material, a movable bending member, fluid-pressure mechanism for moving the member, a valve for governing the application of power to the member, and connections between the bending member and valve effective at all points in the advance of said bending member to move said valve.

221. In a machine for bending material, a movable bending member, power mechanism for moving the member, a rotatable controlling member, means for connecting the power mechanism to the bending member to move said bending member during the rotation of the controlling member, and means for disconnecting the power mechanism from the bending member when the rotation of the controlling member ceases.

222. In a machine for bending material, a movable bending member, fluid-pressure mechanism for moving the member, a recip-

rocatory valve for governing the application of pressure to the member, a handle, a segment movable by the handle and acting upon the valve, and cam mechanism acting on the segment to shift it bodily in its rotation and thereby reciprocate the valve. 70

223. In a machine for forming material, a movable forming member, fluid-pressure mechanism for moving the member, a valve operable to govern the application of pressure to the forming member and fluid-pressure means dependent upon the form to be imparted to the material for operating the valve. 75

224. In a machine for forming material, a movable forming member, fluid-pressure mechanism for moving the member, a valve operable to govern the application of pressure to the forming member, and a plurality of fluid-pressure means for operating the valve each of said means acting to move the valve in opposite directions. 80

225. In a machine for forming material, a movable forming member, fluid-pressure mechanism for moving the member, a valve operable to govern the application of pressure to the forming member, operator-controlled means for operating the valve, and automatic means dependent upon the form to be imparted to the material for operating 95 said valve.

226. In a machine for bending material, a movable bending member, fluid-pressure mechanism for moving the member, a valve having a reciprocatory plunger for governing the application of pressure to the member, a piston connected to the plunger, and means dependent upon the form to be imparted to the material for applying fluid pressure to the piston. 100

227. In a machine for bending material, a movable bending member, fluid-pressure mechanism for moving the member, a valve having a reciprocatory plunger for governing the application of pressure to the member, a piston connected to the plunger, means for applying fluid pressure to the piston, and connections to the valve for actuation by the operator. 105

228. In a machine for bending material, a movable bending member, fluid-pressure mechanism for moving the member, a valve having a reciprocatory plunger for governing the application of pressure to the member, pistons connected to opposite ends of the plunger, and means for applying fluid pressure to the pistons, said means being arranged for action upon one piston to maintain the plunger in normal position and upon the other piston to impart to said plunger 110 movement to vary the pressure of the bending member. 120

229. In a machine for forming material, a movable forming member, fluid-pressure mechanism for moving the member, a valve 125

operable to govern the application of pressure to the forming member, fluid-pressure means for operating the valve, and fluid-pressure means for holding the valve normally in a position to disconnect the fluid-pressure mechanism from the forming member.

230. In a machine for bending material, a movable bending member, fluid-pressure mechanism for moving the member, a valve having a reciprocatory plunger and an enclosing casing for governing the application of pressure to the member, a cylinder alined with the valve-casing, a piston operating in the cylinder to govern the movement of the valve, and means for uniting the plunger and piston to move together while permitting between them a lateral movement of alinement.

231. In a machine for bending material, a movable bending member, fluid-pressure mechanism for moving the member, a valve having a reciprocatory plunger and an enclosing casing for governing the application of pressure to the member, cylinders alined with opposite extremities of the valve-casing, pistons operating in the cylinders to govern the movement of the valve, and a rod uniting the plunger and pistons, there being permitted a lateral play between the rod and a portion of the elements united.

232. In a machine for bending material, a movable bending member, fluid-pressure mechanism for moving the member, a valve having a reciprocatory plunger and an enclosing casing for governing the application of pressure to the member, a cylinder alined with the valve-casing, a piston operating in the cylinder to govern the movement of the valve, and adjusting means for varying the travel imparted to the valve by the piston.

233. In a machine of the class described, a movable operating member, fluid-pressure mechanism for moving the member, a valve for governing the movement of the member, a plurality of mechanisms for operating the valve, and means for rendering one of said mechanisms ineffective.

234. In a machine of the class described, a movable operating member, fluid-pressure mechanism for moving the member, a plurality of valves each capable of independently governing the movement of the member, and means operable at one valve for modifying the operation of another valve.

235. In a machine of the class described, a movable operating member, fluid-pressure mechanism for moving the member, a plurality of valves for governing the movement of the member, and fluid-pressure means operable at one valve for rendering another valve ineffective.

236. In a machine for forming material, a movable forming member, fluid-pressure mechanism for moving the member, a valve having a movable portion for governing the

application of pressure to the member, said valve-portion being provided with a contact-portion by which it may be moved, an actuating member for engagement with the contact-portion, and means for moving the contact-portion away from the actuating member to render the latter ineffective.

237. In a machine for forming material, a movable forming member, fluid-pressure mechanism for moving the member, a valve having a movable plunger for governing the application of pressure to the member, said plunger being provided with a contact-portion by which it may be moved, an actuating member for engagement with the contact-portion, and a fluid-pressure device for moving the contact-portion away from the actuating member to render the latter ineffective.

238. In a machine for forming material, a movable forming member, fluid-pressure mechanism for moving the member, an automatic valve having a movable portion for governing the application of pressure to the member, said valve-portion being provided with a contact-portion by which it may be moved, an actuating member for engagement with the contact-portion, an operator-controlled valve for governing the forming member, and connections to the operator controlled valve for separating the contact-portion and actuating member.

239. In a machine for forming material, a movable forming member, fluid-pressure mechanism for moving the member, an automatic valve having a movable plunger for governing the application of pressure to the member, said plunger being provided with a contact-portion by which it may be moved, an actuating member for engagement with the contact-portion, an operator-controlled valve for governing the forming member, an auxiliary valve actuated by the operator-controlled valve, and fluid-pressure connections governed by the auxiliary valve for moving the contact-portion of the automatic valve out of operative relation to the actuating member.

240. In a machine of the class described, a movable operating member, fluid-pressure mechanism for moving the member, a plurality of valves for governing the movement of the member, and means operable by one valve at predetermined points only in its movement for modifying the operation of the other.

241. In a machine for bending material, a movable bending member, fluid-pressure mechanism for moving the member, a valve having a reciprocatory plunger and an enclosing casing, pistons projecting from the plunger and each having a contact-portion, means for moving the pistons, opposite cylinders surrounding the pistons, springs arranged to urge the cylinders toward the contact-portion of the pistons, and a valve for

- admitting fluid pressure to the cylinders to separate them from said contact-portions.
242. In a machine for bending material, a movable bending member, fluid-pressure mechanism for moving the member, a valve having a reciprocatory plunger and an enclosing casing, pistons projecting from the plunger and each having a contact-portion, an operator-controlled valve, connections to said valve for moving the pistons, opposite cylinders surrounding the pistons, springs arranged to urge the cylinders toward the contact-portion of the pistons, and a valve for admitting fluid pressure to the cylinders to separate them from said contact-portions. 10
243. In a machine for bending material, a movable bending member, a mounting for the member, and power mechanism for moving the bending member in its mounting, said mounting being free to move in opposite directions during the bending movement of the member. 15
244. In a machine for bending material, a supporting member, a casing movable thereon transversely of the material, a bending member movable in the casing and arranged to act upon opposite sides of the material, and mechanism for thus moving the bending member. 20
245. In a machine for bending material, a supporting member, a casing free to move thereon, and a plurality of separated bending members mounted to oscillate in the casing, said casing being movable independently of the oscillation of the bending members. 25
246. In a machine for bending material, a frame, a yoke projecting from the frame, a casing within and pivoted to the outer portion of the yoke, a cylinder rotatable within the casing, and separated bending members supported in the cylinder. 30
247. In a machine for bending material, a frame, a yoke projecting from the frame, a casing within and pivoted to the outer portion of the yoke, a cylinder rotatable within the casing, a piston reciprocating in the cylinder, and separated bending members carried by the piston. 35
248. In a machine for bending material, a movable bending member, means for reciprocating the member into and out of co-operation with the material, means for moving the thus co-operating member toward and from said material, and means for oscillating the member to produce the bending action, said action being effective during the oscillation in both directions. 40
249. In a machine for bending material, a movable bending member, a support therefor, means for moving the bending member on the support, means for rotating the support to oscillate the bending member, and means for reciprocating the support to move the bending member transversely of the plane of oscillation. 45
250. In a machine for bending material, separated movable bending members, means for reciprocating the members into and out of co-operation with the material, means for causing the members to approach or recede from each other, and means for operating the bending members to produce the bending action. 70
251. In a machine for bending material, separated bending members normally situated out of the plane of the material, means for moving the members into the plane of the material, means operable under the power of the machine for causing the members to approach one another into the bending relation, and means for producing a bending movement of the members. 75
252. In a machine for bending material, separated bending members normally situated out of the plane of the material, mechanism operable to both move the members into the plane of the material and cause said members to approach one another into bending relation, and mechanism for oscillating the members. 80
253. In a machine for bending material, a movable bending member, and fluid-pressure mechanism for reciprocating the member into and out of co-operation with the material but free from contact therewith and for oscillating the member into and out of contact with the material in the production of the bending action. 85
254. In a machine for bending material, separated bending members, a reciprocatory support upon which the members are movable, an oscillatory carrier for the support, and means for reciprocating the support and oscillating the carrier. 90
255. In a machine for bending material, separated bending members, a reciprocatory support upon which the members are movable, an oscillatory carrier for the support, and fluid-pressure mechanism for reciprocating the support and oscillating the carrier. 95
256. In a machine for bending material, separated bending members, a reciprocatory support upon which the members are movable, a cylinder by which the support is movably carried, a piston in the cylinder acting upon the support, and fluid-pressure connections to the cylinder. 100
257. In a machine for bending material, separated bending members, a reciprocatory support upon which the members are movable, a cylinder by which the support is movably carried, a piston in the cylinder acting to move the support and provided with guide-surfaces along which the bending members are carried in the travel of the support, and fluid-pressure connections to the cylinder. 105
258. In a machine for bending material, means for restricting the movement of the material, separated bending members co-operating with the restricting means and 110
- 115
- 120
- 125
- 130

situated at opposite sides of the material, means for revolving the members into simultaneous contact with the material to bend it, and means for feeding the material past the restricting means and between the bending members to receive the action of the latter.

259. In a machine for bending material, means for restricting the movement of the material, separated bending members co-operating with the restricting means and situated at opposite sides of the material, means for revolving the members into simultaneous contact with the material to bend it, and a mounting for the members permitting them to yield together during the bending action.

260. In a machine for bending material, spaced abutments between which the material projects for bending, a rotatable carrier, a pair of bending members eccentrically mounted upon the carrier and arranged to lie upon opposite sides of the material as it projects from the abutments, and mechanism for rotating the carrier and thus revolving the members to bend the material.

261. In a machine for bending material, spaced abutments between which the material projects for bending, a rotatable carrier, a mounting for the carrier free to move transversely of the abutments, a pair of bending members eccentrically mounted upon the carrier and arranged to lie upon opposite sides of the material as it projects from the abutments, and mechanism for rotating the carrier and thus revolving the members to bend the material.

262. In a machine for bending material, spaced abutments between which the material projects for bending, a rotatable carrier, a pair of bending members eccentrically mounted upon the carrier and arranged to lie upon opposite sides of the material as it projects from the abutments, mechanism for rotating the carrier and thus revolving the members to bend the material, and mechanism for advancing the material between the abutments and forcing it against the bending members.

263. In a machine for bending material, opposite bending members relatively movable from a separated position into proximity with each other for the bending operation, said members having movable with them portions overlapping in the bending position and arranged to support the material operated upon, and means for turning the members about a vertical axis extending through a supporting portion.

264. In a machine for bending material, overlapping oscillatory plates with separated bending projections rising from the plates, there being upon said plates substantially horizontal material-supporting surfaces bridging the space between the projections, and a member fixed relatively to the plates

and furnishing a continuation of the supporting surfaces.

265. In a machine for bending material, separated members mounted to revolve about an axis located between them and having bending surfaces arranged to act upon opposite sides of the material, said surfaces having depressions to receive the bent material.

266. In a machine for bending material, a movable bending member normally lying out of the plane in which the material is bent, means for producing relative movement of the bending members and material preliminary to the movement of the members for bending said material, and fluid-pressure mechanism for moving the member into the bending plane and for thereafter moving said member into contact with the material.

267. In a machine for bending material, separated bending members normally lying out of the plane in which the material is bent, means for moving the members into and out of said plane, and means acting in such movement for causing the approach and recession of the members.

268. In a machine for bending material, separated bending members normally lying out of the plane in which the material is bent, and fluid-pressure mechanism for moving the member into said plane, said mechanism thereafter causing the approach of the members.

269. In a machine for bending material, a power-cylinder, a support movable therein, a bending member movably mounted upon the support, and a piston in the cylinder acting upon the support and being movable independently thereof.

270. In a machine for bending material, a power-cylinder, a support movable therein, a bending member movably mounted upon the support, a piston for moving the support, and a yieldable member interposed between the piston and support.

271. In a machine for bending material, a cylinder, a reciprocating rod in the cylinder, spaced bending members supported upon the rod, and a piston in the cylinder acting upon the rod but being movable independently thereof.

272. In a machine for bending material, a power-cylinder, a support movable therein, a bending member movably mounted upon the support, and a piston in the cylinder acting upon the support and having a guide-surface contacting with the bending member.

273. In a machine for bending material, a fluid-pressure cylinder, a rod movable in the cylinder, movable bending members pivoted upon the rod, a piston in the cylinder for moving the rod with the members, and connections between the piston and members for moving said members relatively to each other.

274. In a machine for bending material, a

- fluid-pressure cylinder, a rod movable in the cylinder, movable bending members pivoted upon the rod, a piston in the cylinder, and a spring through which the rod is moved by the piston, the piston and members having contacting walls by which the members are oscillated upon their pivot. 275. In a machine for bending material, a fluid-pressure cylinder, a rod movable in the cylinder and being provided at one extremity with a yoke, a pin connecting the arms of the yoke, a pair of bending members having slots to receive the pin, a piston in the cylinder provided with an extension arranged to guide the bending members, and a spring interposed between the piston and yoke. 276. In a machine for bending material, a cylinder, a reciprocating rod in the cylinder having at one extremity a yoke the arms of which are joined by a pin, bending members having slots co-operating with the pin, and a piston in the cylinder having curved guide-surfaces for the bending members, said piston being arranged to move the rod longitudinally and to cause the approach and recession of the said bending members. 277. In a machine for bending material, a fluid-pressure cylinder, a rod movable in the cylinder and being provided at one extremity with a yoke, a pin connecting the arms of the yoke, a pair of bending members having slots to receive the pin, a piston in the cylinder provided with convex surfaces engaging concave surfaces upon the bending members, and a spring interposed between the piston and yoke. 278. In a machine for bending material, a bending member having a plurality of movements; a movable actuating member therefor, and means for stopping one of the movements of the bending member to permit the actuating member to produce the other movement. 279. In a machine for bending material, a bodily movable and oscillatory bending member, a movable actuating member therefor, and means for stopping the bodily movement of the bending member to permit the actuating member to oscillate it. 280. In a machine for bending material, a bodily movable and oscillatory bending member, a movable actuating member therefor, means for stopping one of the movements of the bending member to permit the actuating member to produce the other movement, and adjustable means arranged to vary the extent of one of the movements. 281. In a machine for bending material, a power-cylinder, a support movable therein, a bending member movably mounted upon the support, a piston in the cylinder acting upon the support and being movable independently thereof, and means for stopping the travel of the support and piston at definite points. 282. In a machine for bending material, a power-cylinder, a support movable therein, a bending member movably mounted upon the support, a piston in the cylinder acting upon the support and being movable independently thereof, and contact members variable in position to stop the travel of the support and piston at different points. 283. In a machine for bending material, a fluid-pressure cylinder, a rod movable in the cylinder, movable bending members pivoted upon the rod, a piston in the cylinder, a spring through which the rod is moved by the piston, the piston and members having contacting walls by which the members are oscillated upon their pivot, a stop member carried by the rod, and an adjustable stop member into contact with which the piston moves. 284. In a machine for bending material, a cylinder, a piston movable therein, fluid-pressure connections for rotating one of these elements, and a bending member movable on the rotatable element. 285. In a machine for bending material, a cylinder held against rotation and having abutments, a device rotatable within the cylinder and having abutments co-operating with those of the cylinder, and a bending member carried by the rotatable device. 286. In a machine for bending material, a cylinder held against rotation while permitted to move laterally and having abutments, a device rotatable within the cylinder and having abutments co-operating with those of the cylinder, and a bending member carried by the rotatable device. 287. In a machine for bending material, an outer cylinder held against rotation, an inner cylinder, fluid-pressure connections to the outer cylinder for rotating the inner, and separated bending members movable by the inner cylinder. 288. In a machine for bending material, an outer cylinder held against rotation, an inner cylinder, fluid-pressure connections to the outer cylinder for rotating the inner, a piston in the inner cylinder, and separated bending members movable by the piston. 289. In a machine for bending material, an outer cylinder held against rotation while free to move laterally, an inner cylinder also free for lateral movement, fluid-pressure connections to the outer cylinder for rotating the inner, a piston in the inner cylinder, and separated bending members movable by the piston. 290. In a machine for bending material, an outer cylinder held against rotation and having abutments, a rotatable inner cylinder having abutments co-operating with those of the outer cylinder, these rotatable abutments containing passages leading to the inner cylinder, a piston in the inner cylinder, separated bending members movable by the piston, and connections for applying fluid

pressure to the outer cylinder and to the passages.

291. In a machine for bending material, a cylinder held against rotation, a rotatable cylinder having an extension into the non-rotatable cylinder, said extension serving as a rotatable piston for the non-rotatable cylinder, a reciprocatory piston within the rotatable cylinder, and bending members under the influence of the rotatable cylinder and of the reciprocatory piston.

292. In a machine for bending material, a cylinder held against rotation, a rotatable cylinder having an extension into the non-rotatable cylinder, said extension serving as a rotatable piston for the non-rotatable cylinder, a reciprocatory piston within the rotatable cylinder, a rod movable longitudinally with the rotatable cylinder and extending through and actuated by the reciprocatory piston, bending members mounted upon the rod, and connections between the rotatable cylinder and bending members.

293. In a machine for bending material, a cylinder held against rotation, a rotatable cylinder having an extension into the non-rotatable cylinder, said cylinders having cooperating abutments and there being a passage through an abutment into the rotatable cylinder, a piston in the rotatable cylinder, separated bending members, and actuating connections between the bending members and the piston and rotatable cylinder.

294. In a machine for bending material, a cylinder held against rotation, a rotatable cylinder having an extension into the non-rotatable cylinder, said cylinders having cooperating abutments and there being a passage through an abutment into the rotatable cylinder, a piston in the rotatable cylinder, separated bending members, actuating connections between the bending members and the piston and rotatable cylinder, a pipe extending from the abutment-passage, and a swivel-connection to the pipe for delivering fluid pressure to the rotatable cylinder.

295. In a forming machine, a supporting member, a casing movable thereon, a carrier-cylinder rotatable in the casing and having an extension, forming members mounted on the carrier-cylinder, a cylinder movable upon the supporting member and surrounding the carrier-cylinder-extension, a coupling between the surrounding cylinder and supporting member preventing rotation of the former, and fluid-pressure connections for the cylinders.

296. In a machine for bending material, a frame, a yoke projecting therefrom, a casing pivoted upon the yoke, a bracket projecting from the frame, a cylinder movable upon the bracket, a coupling between the cylinder and bracket preventing rotation of the former, a cylinder rotatable in the casing and having an extension into the non-rotatable cylinder,

which extension serves as a rotary piston, a reciprocatory piston in the rotatable cylinder, bending members, and connections between the bending members and the rotatable cylinder and reciprocatory piston.

297. In a machine for forming material, a movable forming member, power mechanism for moving the member to its operating position, and means acting in event of the member encountering abnormal resistance before reaching its operating position for discontinuing the application of power.

298. In a machine for forming material, a movable forming member, power mechanism for moving the member to its operating position, means acting in event of the member encountering abnormal resistance before reaching its operating position for discontinuing the application of power, and means effective upon the forming member reaching its operating position for preventing the action of the discontinuing means.

299. In a machine for forming material, a movable forming member, fluid-pressure mechanism for moving the member, and means for cutting off the pressure from the mechanism, said means being effective under the influence of a continuing action of the fluid-pressure moving the member.

300. In a machine for forming material, a movable forming member, fluid-pressure mechanism for moving the member, and a valve operable by back pressure of the fluid for cutting off the pressure from the mechanism.

301. In a machine for forming material, a movable forming member, fluid-pressure mechanism for moving the member, a valve operable by back pressure of the fluid for cutting off the pressure from the mechanism, and a latch for holding the valve open.

302. In a machine for forming material, a movable forming member, fluid-pressure mechanism for moving the member, a valve operable by back pressure of the fluid for cutting off the pressure from the mechanism, a latch for holding the valve open, and means operating in the movement of the forming member for rendering the latch effective.

303. In a machine for bending material, a bending member movable to an operating position, fluid-pressure mechanism for moving the member, a conduit for supplying pressure to the mechanism, and an automatic valve controlling the flow through the conduit under the influence of abnormal changes in the fluid-pressure.

304. In a machine for bending material, a bending member movable to an operating position, fluid-pressure mechanism for moving the member, a conduit for supplying pressure to the mechanism, a valve movable by increase of pressure in the conduit to close said conduit, a latch initially ineffective and permitting movement of the valve, and means

operable by the bending member when said bending member reaches its operating position for releasing the latch.

305. In a machine of the class described, a movable operating member, power mechanism for moving the member, a controlling member for the power mechanism movable by the power applied to the operating member, a latch for retaining the controlling member against movement, and a contact member movable with the operating member to release the latch.

306. In a machine of the class described, a movable operating member, power mechanism for moving the member, a controlling member for the power mechanism movable by the power applied to the operating member, a latch for retaining the controlling member against movement, a spring for moving the latch into its retaining position, a plunger resisting movement of the latch, and a contact member movable by the operating member for withdrawing said plunger from the latch.

307. In a machine for forming material, a movable forming member, fluid-pressure mechanism for moving the member, a valve operable by back pressure of the fluid for cutting off the pressure from the mechanism, a latch for holding the valve open, a plunger resisting the latching movement, and a member movable with the forming member and acting upon the plunger to permit the action of the latch.

308. In a machine for forming material in accordance with a pattern, a movable forming member, means arranged to move the forming member at different speeds, and means depending upon the relation between the material and pattern for controlling the speed.

309. In a machine for forming material in accordance with a pattern, a movable forming member, means arranged to move the forming member at a definite speed, and means effective upon the approach of the material and pattern to each other to reduce the speed.

310. In a machine for bending material in accordance with a pattern, a movable bending member, fluid-pressure connections for moving the member, a valve in the connections, and fluid-pressure connections to operate the valve and acting in accordance with the relation between the material and pattern.

311. In a machine of the class described, a plurality of fluid-pressure operating mechanisms, a conduit supplying fluid pressure to the plural operating mechanisms, an exhaust-conduit individual to one of the mechanisms, and a valve in the conduit.

312. In a machine for bending material, a movable bending member, fluid-pressure connections for moving the member and including an exhaust-conduit, a valve controlling

the flow through the exhaust-conduit, and a valve arranged to throttle the flow through said conduit.

313. In a machine for forming material in accordance with a pattern, a movable forming member, means arranged to move the forming member at different speeds, means depending upon the relation between the material and pattern for controlling the speed, and means arranged to vary independently each speed.

314. In a machine for bending material, a movable bending member, fluid-pressure connections for moving the member, a valve in the connections having a plunger maintained normally in one position by the fluid pressure, and an adjustable stop against which the plunger is held.

315. In a machine for bending material, a movable bending member, fluid-pressure connections for moving the member, a valve in the connections having a plunger maintained normally in one position by the fluid pressure, an adjustable stop against which the plunger is held, fluid-pressure connections for moving the plunger in the opposite direction, and an adjustable stop to limit the movement of the plunger in this direction.

316. In a forming machine, a movable forming member, fluid-pressure mechanism for operating the member, a conduit through which the fluid pressure is delivered, and means associated with the conduit and arranged to vary the flow in one direction therethrough while permitting at all times in the opposite direction a flow of the maximum volume.

317. In a forming machine, a movable forming member, fluid-pressure mechanism for operating the member, a conduit through which the fluid pressure is delivered, said conduit having portions furnishing parallel paths to the flow, a valve in one portion, and a check-valve in another portion.

318. In a forming machine, a movable forming member, fluid-pressure mechanism for operating the member, a conduit through which the fluid pressure is delivered, said conduit having two portions furnishing parallel paths to the flow, an operator-controlled valve in one portion, and a check-valve in the other portion arranged to open toward the forming member.

319. In a machine of the class described, a movable operating member, two fluid-pressure chambers, means for alternately delivering fluid to and exhausting it from both chambers, fluid-pressure mechanism for moving the operating member, and connections to the chambers for supplying pressure to said mechanism from one chamber and receiving exhaust in the other chamber.

320. In a machine of the class described, a movable operating member, two fluid-pressure chambers, means for alternately deliver-

- ing fluid to and exhausting it from both chambers, fluid-pressure mechanism for moving the operating member, conduits between said mechanism and both chambers, and check-
5 valves in the conduits.
321. In a machine of the class described, a movable operating member, two fluid-pressure chambers, means for alternately delivering fluid to and exhausting it from both chambers, fluid-pressure mechanism for moving the operating member, conduits between said mechanism and both chambers, check-valves in the conduits, and means connecting the conduits for relieving accumulated pressure.
10
322. In a machine of the class described, a movable operating member, two fluid-pressure chambers, means for alternately delivering fluid to and exhausting it from both chambers, fluid-pressure mechanism for moving the operating member, connections to the chambers for supplying pressure to said mechanism from one chamber and receiving exhaust in the other chamber, and cross-connections between the pressure and exhaust-
20 conduits.
25
323. In a machine of the class described, a movable operating member, two fluid-pressure chambers, means for alternately delivering fluid to and exhausting it from both chambers, fluid-pressure mechanism for moving the operating member, main conduits between said mechanism and both chambers, check-valves in the conduits, a cross-conduit connecting the main conduits, and a check-
30 valve in the cross-conduit.
35
324. In a machine for forming material, a movable carriage, a plurality of movable forming mechanisms mounted upon the carriage, fluid-pressure mechanism for shifting the carriage to bring any one of the forming mechanisms into operating position, and fluid-pressure connections to said carriage-shifting mechanism for operating a forming mechanism.
40
325. In a machine of the class described, a movable carriage, plural operating mechanisms mounted upon the carriage and arranged to be brought into operating position in its movement, two cylinders upon the carriage, connections to both cylinders to which fluid pressure may be applied to move the carriage in opposite directions, and connections to one of the cylinders for actuating an operating mechanism.
50
326. In a machine of the class described, a movable carriage, plural operating mechanisms mounted upon the carriage and arranged to be brought into operating position in its movement, two cylinders upon the carriage, connections to both cylinders to which fluid pressure may be applied selectively to move the carriage in opposite directions, exhaust at the same time occurring from the other cylinder, connections to one of the cylinders for actuating an operating
55
- mechanism by the fluid pressure, and exhaust-connections from the operating mechanism to the other cylinder.
60
327. In a machine of the class described, a movable carriage, plural operating mechanisms mounted upon the carriage and arranged to be brought into operating position in its movement, two cylinders upon the carriage, connections to both cylinders to which fluid pressure may be applied selectively to move the carriage in opposite directions, exhaust at the same time occurring from the other cylinder, connections to one of the cylinders for actuating an operating mechanism by the fluid pressure, exhaust-connections from the operating mechanism to the other cylinder, and means for preventing reversal of pressure in the cylinders from affecting the operating mechanism.
70
75
328. In a machine for bending strip material, a bending member, fluid-pressure mechanism for advancing the material longitudinally and forcing it into contact with the bending member, and fluid pressure mechanism for controlling the advancing mechanism.
80
85
329. In a machine for bending material, a bending member, a member for feeding the material to the bending member, a plurality of fluid-pressure cylinders, a piston in each cylinder, connections between the feeding member and a piston to press said feeding member against the material, and connections to another piston to impart a feeding movement to the member.
90
95
330. In a machine for forming material, a forming member, pairs of jaws arranged to advance material to the member, the jaws of each pair co-operating with opposite sides of said material, and means for reciprocating the pairs of jaws simultaneously in directions opposite to each other.
100
105
331. In a machine for forming material, a forming member, pairs of jaws, the jaws of each pair co-operating with opposite sides of the material, means for reciprocating the pairs of jaws, and means for moving the pairs alternately toward and from each other and for forcing the jaws of the respective pairs toward each other.
110
115
332. In a machine for forming material, a forming member, a pair of reciprocating carriers movable toward and from the forming member, a pair of jaws individual to each carrier and movable thereon toward and from the material, mechanism for oppositely reciprocating the carriers, and mechanism for pressing the jaws toward the material.
120
333. In a machine for forming material, a forming member, a pair of reciprocating carriers movable toward and from the forming member, a pair of jaws movable upon each carrier toward and from the material, hydraulic mechanism for oppositely reciprocating the carriers, and pneumatic mechanism
125
130

for pressing the jaws toward the material.

334. The combination with a pair of material-engaging members, of means for moving the members to advance the material, means for moving the members toward and from the material and for increasing the force of engagement therewith as resistance to its advance increases, and means for forming the material during its advance.

10 335. The combination with a forming member, of a pair of jaws co-operating with the material to be formed, means for moving the jaws to advance the material to the forming member, means tending to move the jaws bodily oppositely to the direction of advance, and a member acting to force each jaw toward the material.

20 336. The combination with a forming member, of a reciprocatory carrier, means for reciprocating the carrier to advance the material to the forming member, a material-gripping member movable upon the carrier in the direction of advance, and a toggle member interposed between the carrier and gripping member and acting to force said gripping member toward the material.

30 337. The combination with a forming member, of a reciprocatory carrier, means for reciprocating the carrier to advance the material to the forming member, a material-gripping member movable upon the carrier in the direction of advance, an abutment upon the carrier, and a cam situated between the abutment and member and arranged to force the gripping member toward the material.

35 338. The combination with a forming member, of a reciprocatory carrier, means for reciprocating the carrier to advance the material to the forming member, a pair of co-operating jaws movable upon the carrier, an abutment fixed to the carrier outside each jaw, and a cam contacting with each abutment and the adjacent jaw.

40 339. The combination with a forming member, of a reciprocatory carrier, means for reciprocating the carrier to advance the material to the forming member, a pair of co-operating jaws movable upon the carrier, an abutment fixed to the carrier outside each jaw, and a cam contacting with each abutment and the adjacent jaw, there being intermeshing projections and depressions connecting the cams with the abutments and jaws.

45 340. The combination with a forming member, of a reciprocatory carrier, means for reciprocating the carrier to advance the material to the forming member, a material-gripping member movable upon the carrier, a toggle member upon the carrier acting upon the gripping member, and a fluid-pressure mechanism mounted upon the carrier for moving the gripping member.

50 341. The combination with a forming mem-

ber, of a reciprocatory carrier, means for reciprocating the carrier to advance the material to the forming member, a pair of co-operating jaws movable upon the carrier in the direction of advance, an abutment fixed to the carrier outside each jaw, a cam contacting with each abutment and the adjacent jaw, a cylinder mounted upon the carrier, a piston operating in the cylinder, connections between the piston and jaws, and connections for supplying fluid pressure to the cylinder.

70 342. The combination with a forming member, of material-gripping members alternately movable in opposite directions to move the material with relation to the forming member, and means for moving the members with an overlap in their travel during which they move in the same direction.

80 343. The combination with a forming member, of two pairs of jaws for feeding material toward or from the forming member, means for reciprocating the pairs of jaws to move them simultaneously in opposite directions, and means for causing the active engagement of one pair of jaws with the material while the other pair is moving idly but with a period during which they are simultaneously effective.

85 344. The combination with a forming member, of two pairs of jaws for feeding material toward or from the forming member, and mechanism for reciprocating the pairs of jaws oppositely at different speeds and for reversing the movement of the more rapidly traveling pair before the other pair has completed its movement.

90 345. The combination with a member for forming material, of a gripping member movable to feed material to the forming member and movable idly in the opposite direction, and means for pressing the gripping member into contact with the material during both its active and idle movements.

100 346. The combination with a forming member, of a reciprocatory carrier, means for reciprocating the carrier toward and from the forming member, a pair of jaws movable upon the carrier, and fluid-pressure mechanism arranged to force the jaws toward the material at all times during the movement of the carrier.

110 347. In a machine for forming material, a forming member, pairs of jaws, the jaws of each pair co-operating with opposite sides of the material, means for reciprocating the pairs of jaws toward and from the forming member, and means for simultaneously forcing the jaws of the respective pairs toward each other during their opposite movements.

120 348. In a machine for forming material, a forming member, a pair of reciprocatory carriers movable toward and from the forming member, a pair of jaws movable upon each carrier toward and from the material, mechanism for oppositely reciprocating the car-

130

riers, and fluid-pressure mechanism mounted upon each carrier and acting constantly during the reciprocation of the carriers to press the jaws of each pair toward each other.

349. The combination with a material-forming device, of reciprocatory material-feeding members, reversible mechanism for reciprocating each member, and means operating in the action of one of the mechanisms for reversing the movement of another.

350. The combination with a material-forming member, of two feeding members, an operating mechanism for each feeding member including a member which controls its movement, and means connected to each operating mechanism for moving the controlling member of the other operating mechanism in opposite directions.

351. The combination with a material-forming member, of reciprocatory feeding members, fluid-pressure operating mechanism connected to each feeding member and including a valve, and connections between each fluid-pressure mechanism and the valve of the associated mechanism for moving said valve to cause the reciprocation of said associated mechanism.

352. The combination with a material-forming member, of two pairs of reciprocatory material-feeding jaws, a fluid-pressure cylinder for each pair of jaws, a piston in each cylinder, operating connections between each piston and the corresponding pair of jaws, a valve controlling the admission of pressure to each cylinder, and connections between each valve and the piston of the associated cylinder.

353. The combination with a material-forming member, of reciprocatory feeding members, an operating mechanism for each feeding member including a controlling member, a lever for shifting each controlling member, and positive and frictional actuating connections between each lever and the operating mechanism for the other feeding member.

354. The combination with a material-forming member, of reciprocatory feeding members, fluid-pressure operating mechanism connected to each feeding member and including a valve, a lever for operating each valve, frictional connections between each lever and the other operating mechanism, and a stop for the lever.

355. The combination with a material-forming member, of reciprocatory feeding members, fluid-pressure operating mechanism connected to each feeding member and including a valve, a lever for operating each valve, and both positive and frictional connections between each valve and the other operating mechanism.

356. The combination with a material-forming member, of reciprocatory feeding members, a fluid-pressure cylinder for each

feeding member having a valve, a piston in each cylinder, operating connections between each piston and a feeding member, a lever connected to each valve, and a member carried by each piston and having a positive contact-surface and a frictional surface acting upon the lever associated with the valve of the other cylinder.

357. The combination with a material-forming member, of two pairs of reciprocatory material-feeding jaws, a fluid-pressure cylinder for each pair of jaws, a piston in each cylinder, a valve controlling the admission of fluid to each cylinder, frictional connections between each valve and the piston of the associated cylinder, said connections acting upon the valve to cause an idle movement of the jaws, and positive connections between each valve and piston to cause the feeding movement of the jaws.

358. The combination with a material-forming member, of two pairs of reciprocatory material-feeding jaws, a fluid-pressure cylinder for each pair of jaws, a piston in each cylinder, a valve controlling the admission of fluid to each cylinder, frictional connections between each valve and the piston of the associated cylinder, said connections acting upon the valve to cause an idle movement of the jaws, positive connections between each valve and piston to cause the feeding movement of the jaws, and a stop variable in position to determine the position of each valve while under the influence of the frictional connections.

359. The combination with a material-forming member, of a reciprocatory feeding member, fluid-pressure mechanism for reciprocating the member, means for supplying the mechanism with fluid under pressure to move the feeding member in one direction, and means for supplying the mechanism with fluid under a different pressure to move the feeding member in another direction.

360. The combination with a material-forming member, of a reciprocatory feeding member organized to advance material to the forming member, fluid-pressure mechanism including a cylinder for reciprocating the material-feeding member, a plurality of sources of fluid pressure, and a valve variable in position to connect to the cylinder any one of the sources.

361. The combination with a material-forming member, of a reciprocatory feeding member, fluid-pressure mechanism including an hydraulic cylinder for reciprocating the member through an active and an idle stroke, a source of high-pressure liquid, a source of low-pressure liquid, and means for connecting the high-pressure source to the cylinder during the active travel and for connecting the low-pressure source during the idle travel.

362. The combination with a material-forming member, of a reciprocatory feeding

member, means for constantly pressing the feeding member into engagement with the material, and means for causing the feeding member to move the material either toward or from the forming member in its reciproca-
5 tion.

363. The combination with a material-forming member, of a reciprocatory feeding member, a pressure member for forcing the feeding member into engagement with the material to cause its feed, and means for changing the direction of application of pressure to the feeding member to reverse the feed.
10

364. The combination with a material-forming member, of a reciprocatory feeding member, a reversible toggle member for forcing the feeding member into engagement with the material to cause its feed in opposite 20 directions, and connections to the feeding member to reverse the toggle member.

365. The combination with a material-forming member, of a reciprocatory carrier, means for reciprocating the carrier toward 25 and from the forming member, separated abutments fixed to the carrier, a pair of material-engaging jaws mounted upon the carrier between the abutments, and a cam member between each jaw and the adjacent abutment, 30 the cam members being movable to force the jaws into feeding engagement with the material in either direction of travel of the carrier.

366. The combination with a material-forming member, of a reciprocatory carrier, 35 means for reciprocating the carrier toward and from the forming member, separated abutments fixed to the carrier, a pair of material-engaging jaws mounted upon the carrier between the abutments, connections to 40 the jaws for moving them in the direction of feed, a cam member between each jaw and the adjacent abutment, and connections between the jaws and cam members to move 45 said cam members in the movement of the jaws.

367. The combination with a material-forming member, of a reciprocatory carrier, means for reciprocating the carrier toward and from the forming member, separated 50 abutments fixed to the carrier, a pair of material-engaging jaws mounted upon the carrier between the abutments, connections to the jaws for moving them in the direction of feed, a cam member between each jaw and 55 the adjacent abutment, and connections between the jaws and cam members, said cam members having pressure surfaces at opposite sides of the connections for contact with the jaws.

60 368. The combination with a material-forming member, of two reciprocatory carriers, means for reciprocating the carriers toward and from the forming member, a pair of material-engaging jaws mounted upon each carrier, means for moving the jaws upon the

carriers, and connections between the pairs of jaws to cause them to move together.

369. The combination with a material-forming member, of two reciprocatory carriers, means for reciprocating the carriers toward and from the forming member, a pair of material-engaging jaws mounted upon each carrier, a fluid-pressure cylinder movable with each carrier, a piston in each cylinder connected to the jaws upon the carrier, and a lever fulcrumed upon one of the carriers and connected to both pairs of jaws.
70

370. The combination with a material-forming member, of a reciprocatory feeding member, means for imparting movements of different character in the opposite travel of the feeding member, and means for reversing these characteristic movements.
75

371. The combination with a material-forming member, of a reciprocatory feeding member, fluid-pressure mechanism for reciprocating the member, means for supplying the mechanism with fluid under pressure to move the feeding member in one direction, means for supplying the mechanism with fluid under a different pressure to move the feeding member in another direction, and means for reversing the connections between the fluid-pressure mechanism and the two supplying means.
80

372. The combination with a material-forming member, of a reciprocatory feeding member, fluid-pressure mechanism including a cylinder and a piston connected to reciprocate the feeding member, a source of high-pressure fluid, a source of low-pressure fluid, a valve variable in position to connect the high-pressure source to the cylinder to move the feeding member in one direction and to connect the low-pressure source to move the feeding member in the opposite direction, and means arranged to position the valve to reverse the connections of the pressure-sources.
95

373. The combination with a forming member, of a reciprocatory member for feeding material to the forming member, a fluid-pressure cylinder, a piston in the cylinder connected to the feeding member, two sources of fluid pressure, and a reversing valve movable to connect the respective sources to the cylinder to cause its opposite movements.
100

374. The combination with a forming member, of a reciprocatory member for feeding material to the forming member, a fluid-pressure cylinder, a piston in the cylinder connected to the feeding member, a valve movable to control the reciprocation of the piston, two sources of fluid pressure, a reversing valve movable to connect the respective sources to the cylinder to cause opposite feeding movements, and means for simultaneously shifting the reversing valve and modifying the action of the controlling valve.
105

375. The combination with a forming member, of a reciprocatory member for feed-

ing material to the forming member, a fluid-pressure cylinder, a piston in the cylinder connected to the feeding member, a valve movable to control the reciprocation of the piston, a variable stop for modifying the action of the valve, two sources of fluid pressure, a reversing valve movable to connect the respective sources to the cylinder to cause opposite feeding movements, fluid-pressure mechanism, and connections to the fluid-pressure mechanism for actuating the stop and the reversing valve.

376. The combination with a material-forming member, of a reciprocatory feeding member movable in one direction in active engagement with the material and idly movable in the opposite direction, means for moving the feeding member more rapidly in its idle than in its active travel, and means for reversing the direction of active engagement and the rate of travel.

377. The combination with a material-forming member, of a reciprocatory feeding member movable in one direction in active engagement with the material and idly movable in the opposite direction, means for moving the feeding member more rapidly in its idle than in its active travel, fluid-pressure mechanism for reversing the direction of active engagement of the feeding member, fluid-pressure mechanism for reversing the rate of travel of the feeding member, and a valve for simultaneously controlling said mechanisms.

378. The combination with a forming member, of a member movable to feed material to the forming member, fluid-pressure mechanism for moving the feeding member, a source of fluid, a conduit connecting the source to the moving mechanism, and a reservoir connected to the conduit.

379. The combination with a forming member, of a member movable to feed material to the forming member, hydraulic mechanism for moving the feeding member, a source of liquid, a conduit connecting the source to the moving mechanism, a reservoir for the liquid communicating with the conduit, and connections for delivering pneumatic pressure above the liquid in the reservoir.

380. The combination with a forming member, of a member movable to feed material to the forming member, a fluid-pressure system for moving the feeding member, and means controlled by the amount of fluid in the system for delivering fluid to said system.

381. The combination with a forming member, of a member movable to feed material to the forming member, a fluid-pressure system for moving the feeding member, a fluid-supply-pipe connected to the system, a valve joined to the pipe and system, and means controlled by the amount of fluid in the system for shifting the valve.

382. The combination with a forming

member, of a member movable to feed material to the forming member, a fluid-pressure system for moving the feeding member including a reservoir, a float in the reservoir, a fluid-supply-pipe delivering to the system, a valve in the pipe, and connections between the float and valve.

383. The combination with a forming member, of a reciprocatory member for feeding material to the forming member, means for starting and stopping the reciprocation of the feeding member, and independent means for changing the rate of movement of the feeding member.

384. The combination with a forming member, of a movable member for feeding material to the forming member, fluid-pressure mechanism for moving the feeding member, a conduit through which pressure is supplied to the moving mechanism, means for opening and closing the passage through the conduit, and means for varying the area of said passage.

385. The combination with a forming member, of a movable member for feeding material to the forming member, fluid-pressure mechanism for moving the feeding member, a conduit through which pressure is supplied to the moving mechanism, valves in the conduit, and fluid-pressure means for actuating the valves.

386. The combination with a forming member, of a movable member for feeding material to the forming member, hydraulic mechanism for moving the feeding member, a liquid-conduit connected to the moving mechanism, two valves in the conduit, and pneumatic connections to actuate both valves.

387. The combination with a forming member, of a movable member for feeding material to the forming member, fluid-pressure mechanism for moving the feeding member, a conduit through which pressure is supplied to the moving mechanism, valves in the conduit, and automatic means for actuating the valves independently of one another.

388. The combination with a forming member, of a movable member for feeding material to the forming member, fluid-pressure mechanism for moving the feeding member, a conduit through which pressure is supplied to the moving mechanism, valves in the conduit, automatic means for actuating the valves, and operator-controlled means for actuating the valves.

389. The combination with a forming member, of a movable member for feeding material to the forming member, hydraulic mechanism for moving the feeding member, a liquid-conduit connected to the moving mechanism, two valves in the conduit, pneumatic connections to actuate both valves, and operator-controlled means for actuating the valves.

390. In a machine for forming material,

a member differently movable to form the material, mechanism for feeding material to the forming member, and means dependent in its action upon the character of the forming operation for stopping the feeding mechanism or allowing it to advance the material during the movement of the members to form said material.

391. In a machine for forming material, a movable member for forming the material, mechanism for feeding material to the forming member, and means dependent in its action upon the extent of movement of the forming member for stopping the feeding mechanism or allowing it to advance the material during the movement of the members to form said material.

392. In a machine for forming material, a movable member for forming the material, mechanism for feeding material to the forming member, and means for stopping the feeding mechanism for a certain extent of movement of the forming member and permitting the feeding mechanism to continue in action for a less extent of movement of the forming member.

393. In a machine for forming material, a plurality of movable members for forming material, mechanism for feeding material to the forming members, and automatic means for stopping the feeding mechanism when one of the forming members is in action and for permitting the mechanism to continue feeding when another forming member is in action.

394. In a machine for forming material, a plurality of movable members for forming material, mechanism for feeding material to the forming members, and automatic means for invariably stopping the feeding mechanism when one of the forming members is in action and for selectively permitting the mechanism to continue or discontinue feeding when another forming member is in action.

395. In a machine for bending material, hot-bending mechanism, cold-bending mechanism, mechanism for feeding material to both bending mechanisms, automatic means for stopping the feeding mechanism when the hot-bending mechanism is in action and for either stopping said feeding mechanism or allowing it to continue to operate when the cold-bending mechanism is in action.

396. The combination with a forming member, of fluid-pressure mechanism for feeding material to the forming member, and fluid-pressure controlling mechanism for the feeding mechanism.

397. The combination with a forming member, of fluid-pressure mechanism for feeding material to the forming member, fluid-pressure controlling mechanism for the feeding mechanism, and automatic and operator-controlled means for governing the ap-

plication of fluid pressure to the controlling means.

398. The combination with a movable forming member, of fluid-pressure mechanism for feeding material to the forming member, means for normally supplying pressure to the feeding mechanism to cause its operation, and means dependent upon the action of the forming member for cutting off the pressure.

399. The combination with a forming member, of fluid-pressure mechanism for feeding material to the forming member, a valve for governing the application of pressure to the feeding mechanism, a fluid-pressure cylinder with its piston connected to the valve, and a valve for governing the admission of pressure to the cylinder.

400. The combination with a forming member, of fluid-pressure mechanism for feeding material to the forming member, a valve for governing the application of pressure to the feeding mechanism, a fluid-pressure cylinder with its piston connected to the valve, a source of pressure connected to the cylinder and constantly tending to open the valve, and variable pressure-connections to the cylinder at the opposite side of the piston.

401. The combination with a forming member, of fluid-pressure mechanism for feeding material to the forming member, a valve for governing the application of pressure to the feeding mechanism, a fluid-pressure cylinder with its piston connected to the valve, fluid-pressure connections to the cylinder at opposite sides of the piston and respectively tending to open and close the valve, and mechanism for controlling the forming member and for applying pressure to the valve-closing connections.

402. The combination with a forming member, of fluid-pressure mechanism for feeding material to the forming member, a valve for governing the application of pressure to the feeding mechanism, a fluid-pressure cylinder with its piston connected to the valve, fluid-pressure connections to the cylinder at opposite sides of the piston and respectively tending to open and close the valve, mechanism for controlling the forming member and for applying pressure to the valve-closing connections, and a normally open fluid-pressure-actuated valve in said valve-closing connections.

403. The combination with a forming member, of fluid-pressure mechanism for feeding material to the forming member, a valve for governing the application of pressure to the feeding mechanism, a fluid-pressure cylinder with its piston connected to the valve, fluid-pressure connections to the cylinder at opposite sides of the piston and respectively tending to open and close the valve, mechanism for controlling the forming member and for applying pressure to the

- the valve-closing connections, a normally open fluid-pressure-actuated valve in said valve-closing connections, and means for applying pressure to close said normally open valve under predetermined conditions in the formation of the material. 70
404. In a machine for forming material, a plurality of movable forming members, fluid-pressure mechanism for feeding material to the forming members, a fluid-pressure-actuated valve for controlling the application of pressure to the feeding mechanism, and means for supplying fluid pressure to the valve over different paths dependent upon the forming member which is in action. 75
405. In a machine for forming material, a plurality of forming members, fluid-pressure mechanism for feeding material to the forming members, a fluid-pressure-actuated valve for controlling the application of pressure to the feeding mechanism, separate conduits supplying pressure for the valve and corresponding to different forming members, and a valve for determining the conduit effectively connected to the valve first mentioned. 80
406. The combination with a forming member, of fluid-pressure mechanism for feeding material to the forming member, a fluid-pressure-actuated valve for controlling the feeding mechanism, a conduit for supplying pressure to the valve, pressure-branches delivering to the conduit, and an automatic device situated at the junction of the branches and conduit and providing for the exclusive delivery from any one of the branches to the conduit. 85
407. The combination with a forming member, of fluid-pressure mechanism for feeding material to the forming member, a fluid-pressure-actuated valve for controlling the feeding mechanism, a conduit for supplying pressure to the valve, two pressure-branches delivering to the conduit, and a double-check-valve connecting the branches to the conduit. 90
408. The combination with a forming member, of mechanism for feeding material to the forming member, fluid-pressure-actuated means for controlling the feeding mechanism, a pressure-supply conduit connected to said means, a source of constant fluid pressure communicating with the supply-conduit, a branch-conduit connected to the supply-conduit, a device in said branch-conduit for intermittently applying fluid pressure, and means at the junction of the supply-conduit and branch-conduit for determining the application of constant or intermittent fluid pressure to the feeding mechanism. 95
409. The combination with a forming member, of fluid-pressure mechanism for feeding material to the forming member, a fluid-pressure-actuated valve for controlling the feeding mechanism, a pressure-supply conduit connected to the valve, a source of constant fluid pressure communicating with the supply-conduit, a branch fluid-pressure conduit, a three-way cock connecting the branch-conduit to the supply-conduit, and means for opening and closing the branch-conduit. 100
410. The combination with a forming member, of fluid-pressure mechanism for feeding material to the forming member, a leakage-valve for governing the admission of pressure to the mechanism, and a leak device controlling the leakage-valve. 105
411. The combination with a forming member, of fluid-pressure mechanism for feeding material to the forming member, a valve for governing the application of pressure to the feeding mechanism, a fluid-pressure cylinder with its piston connected to the valve, a leakage-valve for governing the admission of pressure to the cylinder, a leak device controlling the leakage-valve, and means arranged for actuation by the operator to govern the leak. 110
412. The combination with a controllable forming member, of fluid-pressure mechanism for feeding material to the forming member, a fluid-pressure-actuated valve for controlling the feeding mechanism, a conduit for supplying pressure to close the valve, a normally open valve in the conduit, and means acting in the control of the forming member for closing said normally open valve. 115
413. The combination with a forming member, of fluid-pressure mechanism for feeding material to the forming member, a fluid-pressure-actuated valve for controlling the feeding mechanism, a conduit for supplying pressure to close the valve, a plunger-valve in the conduit, a spring acting to move the plunger in one direction, and fluid-pressure connections for moving the plunger in the opposite direction. 120
414. The combination with a controllable forming member, of fluid-pressure mechanism for feeding material to the forming member, a fluid-pressure-actuated valve for controlling the feeding mechanism, a conduit for supplying pressure to close the valve, a plunger-valve in the conduit, a spring acting to move the plunger in one direction, fluid-pressure connections for moving the plunger in the opposite direction, and means acting in the control of the forming member for applying pressure to the connections. 125
415. The combination with a material-forming member, of mechanism for feeding material to the forming member, a source of power, and automatic means for varying the application of power from the source to the feeding mechanism to move the material with respect to the forming member at different speeds. 130
416. The combination with a material-forming member, of mechanism for feeding material to the forming member, and means

depending in its action upon the relation of the material to the forming member for causing the feeding mechanism to move the material with respect to the forming member at different speeds.

417. In a machine for bending material, a bending member, mechanism for feeding material to the bending member, and means acting as the point at which the material is to be bent approaches the bending member for reducing the rate of feed.

418. The combination with a forming member, of a movable member for feeding material to the forming member, fluid-pressure mechanism for moving the feeding member, a conduit through which pressure is supplied to the moving mechanism, and means for varying the area of the passage through the conduit.

419. The combination with a forming member, of a movable member for feeding material to the forming member, fluid-pressure mechanism for moving the feeding member, a conduit through which pressure is supplied to the moving mechanism, a valve in the conduit, and automatic means for shifting the valve to a predetermined extent.

420. In a machine for bending material, a bending member, fluid-pressure mechanism for feeding material to the bending member, a conduit through which pressure is supplied to the feeding mechanism, a valve in the conduit, and means acting as the point at which the material is to be bent approaches the bending member for partially closing the valve.

421. The combination with a forming member, of a movable member for feeding material to the forming member, fluid-pressure mechanism for moving the feeding member, a conduit through which pressure is supplied to the moving mechanism, a valve in the conduit, a cylinder having a piston connected to the valve, a spring exerting its force to hold the valve normally open to a predetermined extent, and fluid-pressure connections to the cylinder acting to close the valve.

422. The combination with a forming member, of a movable member for feeding material to the forming member, fluid-pressure mechanism for moving the feeding member, a conduit through which pressure is supplied to the moving mechanism, a valve in the conduit, a cylinder having a piston connected to the valve, a spring exerting its force to hold the valve normally open to a predetermined extent, fluid-pressure connections to the cylinder acting to close the valve, and a stop variable in position to determine the extent of closure of the valve by the fluid pressure.

423. The combination with a material-forming member, of mechanism for feeding material to the forming member, and automatic means and operator-controlled means for causing the feeding mechanism to move

the material with respect to the forming member at different speeds.

424. The combination with a forming member, of mechanism for feeding material to be formed, a controlling device for the feeding mechanism movable between extreme positions to cause the operation of the feeding mechanism at different maximum and minimum speeds, and means tending to maintain the device in an intermediate position.

425. The combination with a forming member, of mechanism for feeding material to be formed, a controlling device for the feeding mechanism movable between extreme positions to cause the operation of the feeding mechanism at different maximum and minimum speeds, means for returning the device from the position of minimum speed to an intermediate position, and means tending to return the device from the position of maximum speed to such intermediate position.

426. The combination with a forming member, of fluid-pressure mechanism for feeding material to be formed, a valve for governing the application of fluid pressure to the feeding mechanism, an actuating member for the valve, and yieldable members acting oppositely upon the actuating member.

427. The combination with a forming member, of fluid-pressure mechanism for feeding material to be formed, a valve for governing the application of fluid pressure to the feeding mechanism, an actuating member for the valve, and springs of different strength acting oppositely upon the actuating member.

428. In a machine for forming material, a plurality of independently operating forming mechanisms, automatic means arranged to control any one of the forming mechanisms, and means for operatively associating the controlling means with a particular forming mechanism.

429. In a machine for forming material, a plurality of independently operating forming mechanisms, and mechanism common to plural forming mechanisms and arranged for selective association with any one of said mechanisms to control the form imparted thereby.

430. In a machine for bending material, a hot-bending mechanism, cold-bending mechanism, mechanism arranged to control the extent to which either of said mechanisms bends the material, and means for selectively associating the controlling mechanism with either bending mechanism.

431. In a machine for forming material, a plurality of forming mechanisms arranged to be moved one at a time into operating position, means effective to actuate each forming mechanism only when said mechanism is in operating position, feeding mechanism for advancing the material to the forming mechanisms, and means arranged to control the forming mechanism which is in operating

position and simultaneously therewith the feeding mechanism.

432. In a machine for bending material, a hot-bending mechanism, means for applying heat to the material acted upon by said mechanism, cold-bending mechanism, feeding mechanism for advancing the material to either of the bending mechanisms, and mechanism arranged to control selectively the extent to which either of said mechanisms bends the material and to control simultaneously therewith the feeding mechanism.

433. In a machine for forming material, a movable forming member, mechanism for moving the forming member, and mechanism arranged to control the form imparted by the forming member and the rate of movement of said forming member.

434. In a machine for forming material, a movable forming member, mechanism for moving the forming member, feeding mechanism for advancing the material to the forming member, and mechanism arranged to control the form imparted by the forming member and the rate of advance of the material by the feeding mechanism.

435. In a machine for operating upon material in accordance with a pattern, a plurality of material-forming mechanisms, and feeder mechanism arranged to control any one of the operating mechanisms.

436. In a machine for forming material, a forming member, fluid-pressure mechanism for actuating the forming member, a member for feeding material to the forming member, fluid-pressure mechanism for actuating the feeding member, and controlling mechanism including means for governing the supply of fluid to both actuating mechanisms.

437. In a machine for forming material, a forming member, hydraulic pressure mechanism for actuating the forming member, pneumatic mechanism governing the supply of liquid to the actuating mechanism, and automatic means for controlling the supply of air to the pneumatic mechanism.

438. In a machine for forming material, forming mechanism, a feeding member for advancing the material to the forming mechanism, fluid-pressure mechanism for actuating the feeding member, pneumatic mechanism governing the supply of liquid to the actuating mechanism, and an automatic valve controlling the supply of air to the pneumatic mechanism.

439. In a machine for forming material, a forming member, fluid-pressure mechanism for actuating the forming member, a member for feeding material to the forming member, fluid-pressure mechanism for actuating the feeding member, and controlling mechanism including a valve having a port connected to the actuating mechanism of the forming member and a port connected to the actuating mechanism of the feeding member.

440. In a machine for bending material, a movable bending member, fluid-pressure mechanism for actuating the bending member to produce either a right or left bend, a member for feeding material to the bending member, fluid-pressure mechanism for actuating the feeding member, and an automatic valve having ports connected to the actuating mechanism of the bending member to produce respectively a right or a left bend and a port connected to the actuating mechanism of the feeding member.

441. In a machine of the class described, a movable operating member, fluid-pressure mechanism for actuating the operating member, and fluid-pressure mechanism for controlling the operating member and including a valve having a port connected to the actuating mechanism and a port connected to the controlling mechanism.

442. In a machine for forming material, a movable forming member, and fluid-pressure mechanism including a valve controlling the movement of the forming member and also controlling the fluid-pressure mechanism.

443. In a machine for forming material, a member for operating upon the material, fluid-pressure actuating mechanism therefor, and an automatic device arranged for oscillation to control the actuating mechanism.

444. In a machine for forming material, a member for operating upon the material, fluid-pressure actuating mechanism therefor, a segmental valve for controlling the actuating mechanism, and means for oscillating the valve.

445. In a machine for forming material, a member for operating upon the material, fluid-pressure actuating mechanism therefor, a movable form-determining member, a segmental valve for controlling the actuating mechanism, and connections to the form-determining member for oscillating the valve about the axis of the segment.

446. In a machine for forming material, a member for operating upon material, fluid-pressure actuating mechanism therefor, a form-determining member arranged to oscillate about an axis, an oscillatory valve arranged to control the actuating mechanism and having its axis of oscillation substantially coinciding with that of the form-determining member, and connections for moving the valve from the form-determining member.

447. In a machine for forming material, a member for operating upon material, fluid-pressure actuating mechanism therefor, a form-determining member arranged to oscillate about an axis, an oscillatory valve arranged to control the actuating mechanism and having its axis of oscillation substantially coinciding with that of the form-determining member, and a lever-system joining the valve and form-determining member, the

fulcrum of one of the levers in the system being adjustable.

448. In a machine for forming material, a member for operating upon material, fluid-pressure actuating mechanism therefor, a form-determining member arranged to oscillate about an axis, an oscillatory valve arranged to control the actuating mechanism and having its axis of oscillation substantially coinciding with that of the form-determining member, and a lever-system joining the valve and form-determining member, the connections between the levers of the system being yieldable.

449. In a machine for forming material, an operating member, actuating mechanism therefor, a form-determining member, a movable device arranged to control the actuating mechanism, and co-operating levers connecting the form-determining member and device, one of said levers having a projection and an associated lever being provided with a spring-wall with which the projection contacts.

450. In a machine for forming material, a forming member, fluid-pressure actuating mechanism therefor, an oscillatory form-determining member, an oscillatory valve-segment for controlling the actuating mechanism, lever-arms projecting from the axes of the form-determining member and valve-segment, and a lever connecting said lever-arms.

451. In a machine for forming material, a forming member, fluid-pressure actuating mechanism therefor, an oscillatory form-determining member, an oscillatory valve-segment for controlling the actuating mechanism, lever-arms projecting from the axes of the form-determining member and valve, a lever connecting said lever-arms, and means arranged to adjust the fulcrum of the lever.

452. In a machine of the class described, operating means, fluid-pressure actuating mechanism therefor, a plurality of valves arranged to control different operations, and an automatically movable valve common to said valves and arranged to initiate the movement of all.

453. In a machine of the class described, operating means, fluid-pressure actuating mechanism therefor, a plurality of leakage-valves arranged to control different operations, there being a leak corresponding to each of said valves, and a valve movable to control all of the leaks.

454. In a machine for forming material, means for operating upon the material, fluid-pressure actuating means therefor, a movable form-determining member, a valve movable by the member, and a plurality of fluid-pressure-operated valves movable under the influence of the first-mentioned valve to govern the actuating means.

455. In a machine for forming material,

fluid-pressure-actuated forming mechanism, fluid-pressure-actuated feeding mechanism, a movable controlling member, a fluid-pressure-operated valve arranged to govern the forming mechanism, a fluid-pressure-operated valve arranged to govern the feeding mechanism, and a valve for controlling both fluid-pressure-operated valves under the influence of the controlling member.

456. In a machine for forming material, means for operating upon the material, fluid-pressure actuating means for the operating means, and mechanism arranged to govern the actuating means and including a casing, a plurality of valves movable in the casing and a unitary valve device co-operating with the casing and controlling the plurality of valves.

457. In a machine for forming material, means for operating upon the material, fluid-pressure actuating means for the operating means, a movable form-determining member, a casing, a plurality of leakage-valves movable in the casing and each having a leak-opening therethrough, a valve-segment movable upon the casing to control the leak-openings and connected to the form-determining member, and connections between the leakage-valves and actuating means.

458. In a machine for forming material, means for operating upon the material, fluid-pressure actuating means for the operating means, a movable form-determining member, a casing having an arcuate surface and containing a chamber and a plurality of cylinders surrounding and communicating with the chamber, there being passages from the cylinders through the arcuate surface, a plunger movable in each cylinder, a segment movable by the form-determining member and controlling the openings from the cylinders, and connections between the cylinders and actuating means.

459. In a machine for forming material, means for operating upon the material, fluid-pressure actuating means therefor, an automatic valve arranged to control the actuating means and having a movable casing provided with ports, a movable member governing the ports, and means arranged to adjust the relation of the ports to the member.

460. In a machine for forming material, means for operating upon the material, fluid-pressure actuating means therefor, an automatic valve arranged to control the actuating means and having a movable casing provided with an arcuate surface in which are ports, an oscillatory segment co-operating with the ports, and contact members arranged to change the location of the casing about the segment.

461. In a machine for forming material, means for operating upon the material, fluid-pressure-controlled actuating means for the operating means, and an automatic valve

movable in paths at an angle to each other to control the actuating means.

462. In a machine for forming material, means for operating upon the material, fluid-pressure-controlled actuating mechanism therefor, and an automatic valve arranged for oscillation and reciprocation to control the actuating mechanism.

463. In a machine for forming material, means for operating upon the material, fluid-pressure-controlled actuating mechanism therefor, and a valve-segment arranged for oscillation about its axis and for reciprocation longitudinally of the axis to control the actuating mechanism.

464. In a machine for forming material, means for operating upon the material, fluid-pressure-controlled actuating means for the operating means, a valve movable to control the actuating means, a movable form-determining member, connections between the valve and form-determining member to move said valve in one direction, and means independent of said connections for moving the valve in another direction.

465. In a machine for forming material, means for operating upon the material, fluid-pressure-controlled actuating means for the operating means, a valve movable to control the actuating means, a movable form-determining member, connections between the valve and form-determining member to move said valve in one direction, and a plurality of means independent of said connections and acting successively for moving the valve in another direction.

466. In a machine for operating upon material in accordance with a pattern, means for operating upon the material, a controlling member for the operating means, means acting independently of the pattern for moving the member to determine the beginning of the operation, and means for thereafter governing the operation by the relation between the material and pattern as determined by the controlling member.

467. In a machine for forming material in accordance with a pattern, means for operating upon the material, a movable controlling member for the operating means, means for moving the member toward the pattern to determine the beginning of the operation, and means operating under the influence of the pattern upon the controlling member to govern the forming operation.

468. In a machine for operating upon material in accordance with a pattern, means for operating upon the material, a controlling member for the operating means, means for moving the member to determine the beginning of the operation, and means for moving the member to avoid its interference with the operation.

469. In a machine for forming material in accordance with a pattern, means for oper-

ating upon the material, a movable controlling member for the operating means, means for moving the member toward the pattern to determine the beginning of the operation, means for withdrawing the member from engagement with the pattern to permit the operation to proceed, and means operating under the influence of the pattern upon the controlling member to govern the forming operation.

470. In a machine for bending material in accordance with a pattern, a movable bending member, and a controlling member therefor co-operating with the pattern and being movable to positions varying between opposite extremes to determine corresponding positions of the bending axis, said member being further movable to determine the character of the bending movement.

471. In a machine for bending material in accordance with a pattern, a movable bending member, a controlling member therefor, and means for moving the member to determine the bending axis, the member thereafter being movable under the influence of the pattern to determine the direction and extent of bending.

472. In a machine for forming material in accordance with a pattern, fluid-pressure-actuated means for operating upon the material, a valve movable to govern the fluid pressure, a controlling member co-operating with the pattern and connected to the valve, and mechanism for moving the controlling member toward the pattern to shift the valve and initiate the forming operation, said member thereafter being moved by the pattern to control the valve for the forming operation.

473. In a machine for forming material in accordance with a pattern, fluid-pressure-actuated means for operating upon the material, a valve movable in a plurality of directions for governing the fluid pressure, a controlling member co-operating with the pattern and connected to the valve, and mechanism for shifting the valve in one direction to initiate the forming operation, the controlling member thereafter being moved by the pattern to shift the valve in another direction to control the forming operation.

474. In a machine for forming material in accordance with a pattern, a movable forming member, fluid-pressure actuating mechanism for moving the member, an oscillatory and reciprocatory valve for governing the fluid pressure, a controlling member co-operating with the pattern and connected to the valve, and mechanism for moving the controlling member toward the pattern to shift the valve in its reciprocatory path, the valve thereafter being oscillated by contact of the controlling member with the pattern.

475. In a machine for forming material in accordance with a pattern, fluid-pressure-ac-

tuated means for operating upon the material, a valve movable to govern the fluid pressure, a controlling member co-operating with the pattern and connected to the valve, and fluid-pressure mechanism governed by the valve for moving the controlling member toward the pattern to shift the valve and initiate the forming operation, said member thereafter being moved by the pattern to control the valve for the forming operation.

476. In a machine for forming material in accordance with a pattern, fluid-pressure-actuated means for operating upon the material, a valve movable to govern the fluid pressure, a controlling member co-operating with the pattern and connected to the valve, mechanism for moving the controlling member toward the pattern to shift the valve and initiate the forming operation, and means for moving the controlling member from the pattern to avoid its interference with the forming operation.

477. In a machine for forming material in accordance with a pattern, fluid-pressure-actuated means for operating upon the material, a valve movable to govern the fluid pressure, a controlling member co-operating with the pattern and connected to the valve, mechanism for moving the controlling member toward the pattern to shift the valve and initiate the forming operation, means for moving the controlling member from the pattern to avoid its interference with the forming operation, and a retaining member for the valve acting during the last-mentioned movement.

478. In a machine for forming material in accordance with a pattern, fluid-pressure-actuated means for operating upon the material, a valve movable to govern the fluid pressure, a controlling member co-operating with the pattern and connected to the valve, mechanism for moving the controlling member toward the pattern to shift the valve and initiate the forming operation, and mechanism acting to free the controlling member from said moving mechanism.

479. In a machine for forming material in accordance with a pattern, fluid-pressure-actuated means for operating upon the material, a valve movable to govern the fluid pressure, a controlling member co-operating with the pattern and connected to the valve, mechanism for moving the controlling member toward the pattern to shift the valve and initiate the forming operation, and mechanism acting to free the controlling member from said moving mechanism and to retain the valve against reverse movement.

480. In a machine for forming material in accordance with a pattern, fluid-pressure-actuated means for operating upon the material, a valve movable to govern the fluid pressure, a controlling member co-operating with the pattern and connected to the valve, mech-

anism for moving the controlling member toward the pattern to shift the valve and initiate the forming operation, and fluid-pressure mechanism governed by the valve and acting to free the controlling member from said moving mechanism.

481. In a machine for forming material in accordance with a pattern, fluid-pressure-actuated means for operating upon the material, a valve movable to govern the fluid pressure, a controlling member co-operating with the pattern and connected to the valve, fluid-pressure mechanism governed by the valve for moving the controlling member toward the pattern to shift the valve and initiate the forming operation, and fluid-pressure mechanism governed by the valve and acting to free the controlling member from said moving mechanism.

482. In a machine for forming material in accordance with a pattern, forming means, means for advancing the material to the forming means at different rates, and means under the control of the pattern to govern the forming means and to change the rate of advance.

483. In a machine for forming material in accordance with a pattern, a movable operating member, fluid-pressure actuating mechanism therefor, a valve arranged to oscillate about an axis and to move longitudinally of the axis to control the actuating mechanism, and a member movable under the control of the pattern to govern both movements of the valve.

484. In a machine for forming material in accordance with a pattern, a movable forming member, fluid-pressure actuating mechanism therefor, a movable member for advancing material to the forming member, fluid-pressure actuating mechanism for the advancing member, a valve arranged to oscillate to govern the actuation of the forming member and reciprocate to control the actuation of the advancing member, and a member movable under the control of the pattern to govern both movements of the valve.

485. In a machine for forming material in accordance with a pattern, a movable forming member, means for moving the forming member, and controlling means for the moving means including a plurality of members arranged for contact with the pattern.

486. In a machine for forming material in accordance with a pattern, a movable forming member, fluid-pressure actuating mechanism for moving the forming member, and controlling mechanism for the fluid-pressure mechanism including a valve and a plurality of members arranged by their contact with the pattern to impart different movements to the valve.

487. In a machine for bending material in accordance with a templet, a movable bending member, means for moving the bending member, and controlling means for the mov-

ing means including members arranged to contact respectively with the edge and face of the templet.

488. In a machine for bending material in accordance with a templet, a movable bending member, means for moving the bending member, and controlling means for the moving means including a member arranged to be pressed against the face of the templet.

489. In a machine for forming material in accordance with a pattern, a movable forming member, means for moving the forming member, means for feeding the material with the pattern for the forming operation, and controlling means for the machine including a member arranged to be pressed against the pattern and to be freed therefrom in the travel of said pattern and to thereupon exercise its control.

490. In a machine for bending material in accordance with a templet, a movable bending member, fluid-pressure mechanism for moving the member, a valve for controlling the fluid pressure, and a member connected to the valve and arranged to contact with the face of the templet.

491. In a machine for forming material in accordance with a pattern, a movable forming member, fluid-pressure actuating mechanism for moving the forming member, fluid-pressure mechanism for feeding the material with the pattern for the forming operation, a valve for controlling the fluid pressure, a contact member arranged to be pressed against the pattern and to move past said pattern in its travel, and connections for moving the valve from the contact member.

492. In a machine for forming material in accordance with a pattern, a movable forming member, fluid-pressure actuating mechanism for moving the forming member, fluid-pressure mechanism for feeding the material with the pattern for the forming operation, a valve for controlling the fluid pressure, a contact member arranged to be pressed against the pattern and to move past said pattern in its travel, and a lever acting to shift the valve under the influence of the contact member when said member is released by the pattern.

493. In a machine for forming material in accordance with a pattern, a movable forming member, means for moving the forming member, means for feeding the material with the pattern for the forming operation, controlling means for the machine including a member arranged to be pressed against the pattern and to be freed therefrom in the travel of said pattern and to thereupon exercise its control, and means arranged to vary the extent of movement of the thus freed member.

494. In a machine for forming material in accordance with a pattern, a movable forming member, fluid-pressure actuating mecha-

nism for moving the forming member, fluid-pressure mechanism for feeding the material with the pattern for the forming operation, a valve for controlling the fluid pressure, a contact member arranged to be pressed against the pattern and to move past said pattern in its travel, a lever acting to shift the valve under the influence of the contact member when said member is released by the pattern, and an adjustable stop against which the lever is forced by the contact member.

495. In a machine of the class described, a movable operating member, fluid-pressure actuating mechanism therefor, a valve for governing the fluid pressure, and oscillatory and reciprocatory controlling members acting upon the valve.

496. In a machine for forming material in accordance with a pattern, a movable forming member, fluid-pressure actuating mechanism therefor, a valve for governing the fluid pressure, a carrier-frame, and two members arranged respectively to oscillate and reciprocate upon the frame under the influence of the pattern and being connected to the valve.

497. In a machine for forming material, a movable forming member, fluid-pressure actuating mechanism therefor, a plurality of valves movable independently of one another and arranged to control different forming operations, and an automatically movable valve common to said operation-controlling valves and arranged to govern all.

498. In a machine of the class described, a movable bending member, fluid-pressure mechanism for moving said member, a valve for governing the fluid pressure, and means under the control of the valve for moving said valve to initiate the bending action.

499. In a machine of the class described, a movable operating member, fluid-pressure mechanism for moving said member, a valve for governing the fluid pressure, and fluid-pressure mechanism having an element movable into engagement with the valve for shifting said valve, pressure being applied to said mechanism under the control of the valve.

500. In a machine for forming material, a movable forming member, a movable member for controlling the movement of the forming member, and fluid-pressure mechanism having an element movable into contact with the controlling member for shifting said member.

501. In a machine for forming material in accordance with a pattern, a movable forming member, a movable member for controlling the movement of the forming member, fluid-pressure mechanism for moving the controlling member toward the pattern, and a spring for moving said member from the pattern.

502. In a machine for bending material in accordance with a pattern having an angular portion, a movable bending member,

mechanism for feeding the material for the bending operation, actuating mechanism therefor, a movable member for controlling the actuating mechanism, and means for moving the controlling member to the rear of the angular portion of the pattern in its advance.

503. In a machine for bending material in accordance with a pattern having an angular portion, a movable bending member, mechanism for feeding the material for the bending operation, actuating mechanism therefor, a movable member for controlling the actuating mechanism, means for moving the controlling member to the rear of the angular portion of the pattern in its advance, and means for moving the controlling member into contact with the advancing pattern.

504. In a machine for bending material in accordance with a pattern having an angular portion, a movable bending member, mechanism for feeding the material for the bending operation, actuating mechanism therefor, a movable member for controlling the actuating mechanism, means for moving the controlling member to the rear of the angular portion of the pattern in its advance, and means acting as a result of such movement for moving the controlling member into contact with the advancing pattern.

505. In a machine for bending material in accordance with a pattern having an angular portion, a movable bending member, mechanism for feeding the material for the forming operation, actuating mechanism therefor, a movable member for controlling the actuating mechanism, a spring for moving the controlling member to the rear of the angular portion of the pattern in its advance, and fluid-pressure mechanism for moving the controlling member into contact with the advancing pattern.

506. In a machine for forming material in accordance with a pattern, a movable forming member, fluid-pressure actuating mechanism therefor, a valve for governing the pressure, a controlling member movable under the influence of the pattern and connected to the valve, and means governed by the valve for moving the controlling member.

507. In a machine for forming material, a movable forming member, fluid-pressure actuating mechanism therefor, a valve for governing the pressure, a movable form-determining member connected to the valve, a cylinder having a piston acting upon the form-determining member, and fluid-pressure connections to the cylinder governed by the valve.

508. In a machine for operating upon material in accordance with a pattern, operating mechanism, fluid-pressure actuating mechanism therefor, controlling mechanism for the actuating mechanism including a valve, a

member movable in contact with the pattern and connections for moving the valve in the movement of the contact member, and means for imparting to the valve movement independent of the contact member.

509. In a machine for operating upon material in accordance with a pattern, operating mechanism, fluid-pressure actuating mechanism therefor, controlling mechanism for the actuating mechanism including a valve, a carrier, a member movable upon the carrier for contact with the pattern and connections for moving the valve in the movement of the contact member, and fluid-pressure mechanism controlled by the valve for moving said valve.

510. In a machine for operating upon material in accordance with a pattern, operating mechanism, fluid-pressure actuating mechanism therefor, controlling mechanism for the actuating mechanism including a valve, a carrier, a member movable upon the carrier for contact with the pattern and a lever fulcrumed upon the carrier, and means acting upon the lever for moving the valve and contact member.

511. In a machine for operating upon material in accordance with a pattern, operating mechanism, fluid-pressure actuating mechanism therefor, controlling mechanism for the actuating mechanism including a valve and a movable member, and fluid-pressure mechanism acting upon the valve to move said valve to an extent determined by the contact of the member with the pattern.

512. In a machine for operating upon material in accordance with a pattern, operating mechanism, fluid-pressure actuating mechanism therefor, controlling mechanism for the actuating mechanism including a valve, a carrier, a member movable upon the carrier for contact with the pattern and a lever fulcrumed upon the carrier, and means acting upon the lever for moving the valve and contact member, there being connections between the lever and contact member arranged to vary the time of movement of the latter.

513. In a machine for operating upon material in accordance with a pattern, operating mechanism, fluid-pressure actuating mechanism therefor, controlling mechanism for the actuating mechanism including a valve, a carrier, a member movable upon the carrier for contact with the pattern, a lever fulcrumed upon the carrier and co-operating with the valve and an adjustable contact device for imparting movement of the lever to the contact member, and automatic mechanism for moving the lever.

514. In a machine for operating upon material in accordance with a pattern, operating mechanism, fluid-pressure actuating mechanism therefor, controlling mechanism for the actuating mechanism including a valve, a carrier, a member movable upon the carrier

for contact with the pattern, a lever fulcrumed upon the carrier in cooperation with the valve and having a projection and opposite screws adjustable in position upon the contact member and with which the lever projection may contact, and automatic mechanism for moving the lever.

515. In a machine of the class described, a movable operating member, fluid-pressure mechanism for moving said member, a valve movable in one direction to govern the fluid pressure, and means to which the thus governed fluid pressure is delivered for moving the valve in a different direction.

516. In a machine for bending material, a member movable to bend the material in opposite directions, means for controlling the direction of the bending movement, and means governed in the movement of the bending member in one direction for governing the controlling means.

517. In a machine for bending material, a member movable to bend the material in opposite directions, fluid-pressure actuating mechanism for the bending member, a valve for controlling the fluid pressure to determine the direction of the bending movement, and mechanism supplied with fluid pressure through the valve upon its control of the bending movement in one direction for moving said valve.

518. In a machine for bending material, a member movable to bend the material in opposite directions, fluid-pressure actuating mechanism for the bending member, a valve for controlling the fluid pressure to determine the direction of the bending movement, and mechanism supplied with fluid pressure through the valve upon its control of the bending movement in one direction for moving said valve and retaining it against reverse movement during the continuance of the bending.

519. In a machine for forming material, operating mechanism, fluid-pressure actuating mechanism therefor, and controlling mechanism for the actuating mechanism including a valve, a fluid-pressure cylinder and a piston movable in said cylinder, the piston in its movement acting directly upon the valve.

520. In a machine for forming material, operating mechanism, fluid-pressure actuating mechanism therefor, and controlling mechanism for the actuating mechanism including a valve, a fluid-pressure cylinder and a piston movable in said cylinder, the piston having movable with it an inclined surface acting to shift the valve.

521. In a machine for forming material, operating mechanism, fluid-pressure actuating mechanism therefor, and controlling mechanism for the actuating mechanism including a casing, a valve movable therein, a cylinder mounted upon the casing and a piston operating in the cylinder and having its

rod extending into the casing for contact with the valve.

522. In a machine of the class described, a movable operating member, fluid-pressure mechanism for moving said member, a valve for governing the fluid pressure, means under the influence of the thus governed fluid pressure for moving the valve, and means arranged to vary the extent of movement of the valve.

523. In a machine for forming material, operating mechanism, fluid-pressure actuating mechanism therefor, and controlling mechanism for the actuating mechanism including a valve, a fluid-pressure cylinder, a piston operating therein to shift the valve, a rod projecting from the piston and a member adjustable upon the rod to vary the extent of movement of the valve.

524. In a machine for forming material in accordance with a pattern, forming means, means for advancing the material to the forming means at different rates, and means movable by the pattern to control the forming means and to control the advancing means to determine the rate at which the material is advanced.

525. In a machine for forming material in accordance with a pattern, forming means, means for advancing the material and pattern to the forming means, and means including a member movable by the pattern laterally of the direction of advance to control the forming means and in the direction of advance to control the advancing means.

526. In a machine for forming material in accordance with a pattern, a movable operating member, fluid-pressure actuating mechanism therefor, a valve movable in a plurality of directions to control the actuating mechanism, and a member movable by the pattern to move the valve in such plural directions.

527. In a machine for forming material in accordance with a pattern, a movable operating member, fluid-pressure actuating mechanism therefor, a valve arranged to oscillate about an axis and to move longitudinally of the axis to control the actuating mechanism, and a member movable by the pattern to govern both movements of the valve.

528. In a machine for forming material in accordance with a pattern, a movable operating member, fluid-pressure actuating mechanism therefor, a movable member for advancing material to the forming member, fluid-pressure mechanism for the advancing member, a valve arranged to oscillate to govern the actuation of the forming member and reciprocate to control the actuation of the advancing member, and a member movable by the pattern to govern both movements of the valve.

529. In a machine for forming material in accordance with a pattern, operating mecha-

nism, fluid-pressure actuating mechanism therefor, and controlling mechanism for the actuating mechanism including a valve, a movable carrier, a member movable upon the carrier by engagement with the pattern and connections between the member and valve.

530. In a machine for forming material in accordance with a pattern, operating mechanism, fluid-pressure actuating mechanism therefor, and controlling mechanism for the actuating mechanism including a valve, a carrier movable under the influence of the pattern, a member movable upon the carrier by engagement with the pattern and connections arranged to communicate the movements of the carrier and member to the valve.

531. In a machine for forming material in accordance with a pattern, fluid-pressure forming mechanism, fluid-pressure mechanism for feeding material with the pattern to the forming mechanism, and controlling mechanism for the forming and feeding mechanisms including a valve, a member for engagement with the pattern and being yieldable in the direction of feed and connections for transmitting this yielding movement to the valve.

532. In a machine for forming material in accordance with a pattern, fluid-pressure forming mechanism, fluid-pressure mechanism for feeding material with the pattern to the forming mechanism, and controlling mechanism for the forming and feeding mechanisms including a valve, a movable carrier, a member movable upon the carrier for engagement with the pattern, a spring acting to force the member upon the carrier in the opposite direction to that of the feed, the pattern engaging the member to draw it in the direction of feed and connections for transmitting the movements of the carrier and member to the valve.

533. In a machine for bending material in accordance with a pattern, a movable bending member, a member movable by the pattern, and mechanism controlled by the member and arranged to vary the bending axis and the character of the bending movement.

534. In a machine for bending material in accordance with patterns having portions of different character, a movable bending member, and mechanism for controlling the bending member and including a member co-operating with the pattern to determine the bending axis and adjustable means co-operating with said member to independently vary the position of the bending axis in accordance with the character of the pattern.

535. In a machine for bending material in accordance with patterns having external and internal angles, a movable bending member, and mechanism for controlling the bending member and including a member co-operating with the pattern, said member being movable by the pattern to determine the bending

axis for internal angles, mechanism for moving the member to determine the bending axis for external angles and independently adjustable means for varying the effect of the movement of the member upon the controlling mechanism for internal and external angles.

536. In a machine for bending material in accordance with patterns having external and internal angles, fluid-pressure bending mechanism, and controlling mechanism for the bending mechanism including a valve, a member movable by the pattern to shift the valve to start the bending of internal angles and mechanism for moving the member into contact with the pattern to start the bending of external angles, there being connections between the member and valve having independently adjustable members to determine the time of bending of the respective angles.

537. In a machine for bending material in accordance with patterns having external and internal angles, fluid-pressure bending mechanism, and controlling mechanism for the bending mechanism including a valve, a member movable by the pattern to shift the valve to start the bending of internal angles and mechanism for moving the member into contact with the pattern to start the bending of external angles, there being connections between the member and valve including a lever and opposite contact-screws between which the lever is free to move.

538. In a machine for operating upon material in accordance with a pattern, a plurality of operating mechanisms, and controlling mechanism for the operating mechanisms, said controlling mechanism including a member movable under the influence of the pattern in three zones, in each of which the operating mechanisms are differently affected.

539. In a machine for forming material in accordance with a pattern, forming mechanism, feeding mechanism, and controlling mechanism for the forming and feeding mechanisms, said controlling mechanism including a member movable under the influence of the pattern in three zones, in each of which the forming and feeding mechanisms are differently affected.

540. In a machine for forming material in accordance with a pattern, forming mechanism including a movable member, controlling mechanism for the forming mechanism, said controlling mechanism including a member movable under the influence of the pattern in a neutral zone, an intermediate zone and an outer zone, and connections between the controlling mechanism and forming mechanism arranged to stop movement of the forming member in the neutral zone to produce a relatively slow forming movement in the intermediate zone and to produce a relatively rapid forming movement in the outer zone.

541. In a machine for forming material in accordance with a pattern, forming mechanism, feeding mechanism, controlling mechanism for the forming and feeding mechanisms, said controlling mechanism including a member movable under the influence of the pattern in a neutral zone, an intermediate zone and an outer zone, and connections between the controlling mechanism and feeding mechanism arranged to cause a feeding action in the neutral and intermediate zones and to stop the feeding action in the outer zone.

542. In a machine for forming material in accordance with a pattern, forming mechanism including a movable member, feeding mechanism, controlling mechanism for the forming and feeding mechanisms, said controlling mechanism including a member movable under the influence of the pattern in a neutral zone, an intermediate zone and an outer zone, and connections between the controlling mechanism and the forming and feeding mechanisms arranged to stop movement of the forming member and cause the feeding action in the neutral zone, to produce a relatively slow forming movement and cause the feeding action in the intermediate zone, and to produce a relatively rapid forming movement and to stop the feeding action in the outer zone.

543. In a machine for bending material in accordance with a pattern, a movable bending member, mechanism for actuating the bending member at different rates, and controlling mechanism for the actuating mechanism including a member movable under the influence of the pattern and arranged to cause the movement of the bending member at different rates depending upon the degree of separation between the material and pattern.

544. In a machine for bending material in accordance with a pattern, a movable bending member, mechanism for actuating the bending member at different rates, and controlling mechanism for the actuating mechanism including a member movable under the influence of the pattern and arranged to cause an increase in the rate of movement of the bending member as the separation between the material and pattern increases.

545. In a machine for bending material in accordance with a pattern, bending mechanism, feeding mechanism for advancing material to the bending mechanism, and controlling mechanism for the feeding mechanism including a member movable under the influence of the pattern and arranged to cause the feeding mechanism to advance the material when said material substantially coincides with the pattern and to either permit or stop the feeding action for different degrees of separation between the material and pattern.

546. In a machine for bending material in

accordance with a pattern, bending mechanism including a movable bending member, feeding mechanism for advancing material to the bending mechanism, and controlling mechanism for the bending and feeding mechanisms including a member movable under the influence of the pattern and arranged to cause the feeding mechanism to advance the material when said material substantially coincides with the pattern, to either permit or stop the feeding action for different degrees of separation between the material and pattern and to increase the rate of movement of the bending member when the separation between the material and pattern increases.

547. In a machine of the class described, a movable operating member, fluid-pressure actuating mechanism therefor, and mechanism for governing the actuating mechanism including a primary valve and a secondary valve having a portion movable with and modifying the effect of the primary valve.

548. In a machine of the class described, a movable operating member, fluid-pressure actuating mechanism therefor, and mechanism for governing the actuating mechanism including a primary valve and a secondary valve having a portion movable with and arranged to nullify the effect of the primary valve in a predetermined zone of action.

549. In a machine for operating upon material in accordance with a pattern, a movable operating member, fluid-pressure actuating mechanism therefor, and mechanism for governing the actuating mechanism including a contact member movable under the influence of the pattern and a plurality of valves movable by such contact member.

550. In a machine for operating upon material in accordance with a pattern, a movable operating member, fluid-pressure actuating mechanism therefor, and mechanism for governing the actuating mechanism including a contact member movable under the influence of the pattern, a primary valve movable by said contact member, a leakage-valve and a leak device operable by the contact member.

551. In a machine for operating upon material in accordance with a pattern, a movable operating member, fluid-pressure actuating mechanism therefor, and mechanism for governing the actuating mechanism including a contact member movable under the influence of the pattern, a primary valve movable by said contact member, a leakage-valve and a leak device operable by the contact member and arranged to cause the opening of the leakage-valve at a predetermined point in the movement of the primary valve.

552. In a machine of the class described, fluid-pressure operating mechanism, and a controlling mechanism for the operating mechanism including a member movable in

predetermined zones, a primary valve for governing the fluid pressure movable by the member and a valve device for modifying the action of the primary valve, said device having a port and a finger movable by the member to cover the port in a plurality of zones and to open said port in another zone.

553. In a machine for bending material in accordance with a pattern, a movable bending member, fluid-pressure actuating mechanism therefor, fluid-pressure feeding mechanism, and mechanism for governing the actuating and feeding mechanisms including a contact member movable under the influence of the pattern, a valve movable by the contact member to start the actuating mechanism and stop the feeding mechanism and a valve movable by the contact member to permit the stopping of the feeding mechanism in a predetermined zone of action.

554. In a machine for bending material in accordance with a pattern, a movable bending member, fluid-pressure actuating mechanism to move the bending member at different rates, fluid-pressure feeding mechanism, and mechanism for governing the actuating and feeding mechanisms including a contact member movable under the influence of the pattern, a valve movable by the contact member to start the actuating mechanism and stop the feeding mechanism and a valve movable by the contact member to permit the stopping of the feeding mechanism in a predetermined zone of action and to simultaneously increase the rate of movement of the bending member.

555. In a machine for forming material in accordance with a pattern, forming mechanism, fluid-pressure mechanism for feeding material to the forming mechanism, controlling mechanism for the machine including a member governed by the pattern and a valve-system, an intermediate valve interposed between the feeding mechanism and controlling mechanism, fluid-pressure connections through the intermediate valve from the valve-system of the controlling mechanism to the feeding mechanism to cause a particular condition of said feeding mechanism, and connections to said intermediate valve to modify such condition.

556. In a machine for forming material in accordance with a pattern, forming mechanism, fluid-pressure mechanism for feeding material to the forming mechanism, controlling mechanism for the machine including a member governed by the pattern and a valve-system, an intermediate valve interposed between the feeding mechanism and controlling mechanism, fluid-pressure connections through the intermediate valve from the valve-system of the controlling mechanism to the feeding mechanism to prevent the action of said feeding mechanism, and fluid-pressure connections from the valve-system

of the controlling mechanism to the intermediate valve to nullify the feed-preventing effect.

557. In a machine for forming material in accordance with a pattern, forming mechanism, fluid-pressure mechanism for feeding material to the forming mechanism, controlling mechanism for the machine including a member governed by the pattern and a valve-system, an intermediate valve interposed between the feeding mechanism and controlling mechanism, fluid-pressure connections through the intermediate valve from the valve-system of the controlling mechanism to the feeding mechanism to prevent the action of said feeding mechanism, a spring holding said intermediate valve normally open, and fluid-pressure connections from the valve-system of the controlling mechanism to the intermediate valve to close such valve.

558. In a machine for forming material in accordance with a pattern, forming mechanism, fluid-pressure mechanism for feeding material to the forming mechanism, controlling mechanism for the machine including a member governed by the pattern, a primary valve and a secondary valve, an intermediate valve interposed between the feeding mechanism and controlling mechanism, fluid-pressure connections through the intermediate valve from the primary valve of the controlling mechanism to the feeding mechanism to prevent the action of said feeding mechanism, and fluid-pressure connections from the secondary valve of the controlling mechanism to the intermediate valve to nullify the feed-preventing effect.

559. In a machine for forming material in accordance with a pattern, forming mechanism including a movable member, fluid-pressure mechanism for feeding material to the forming mechanism, controlling mechanism for the machine including a member governed by the pattern and a valve-system, an intermediate valve interposed between the feeding mechanism and controlling mechanism, fluid-pressure connections through the intermediate valve from the valve-system of the controlling mechanism to the feeding mechanism to prevent action of said feeding mechanism, connections from the valve-system to the intermediate valve to nullify the feed-preventing effect, a fluid-pressure device acting upon the forming mechanism to change the rate of movement of the forming member, and fluid-pressure connections from the valve-system to said device.

560. In a machine for forming material in accordance with a pattern, forming mechanism including a movable member, fluid-pressure mechanism for feeding material to the forming mechanism, controlling mechanism for the machine including a member governed by the pattern, a primary valve and a secondary valve, an intermediate valve in-

- terposed between the feeding mechanism and controlling mechanism, fluid-pressure connections through the intermediate valve from the primary valve of the controlling mechanism to the feeding mechanism to prevent the action of said feeding mechanism, fluid-pressure connections from the secondary valve of the controlling mechanism to the intermediate valve to nullify the feed-pre-
 10 venting effect, a fluid-pressure device acting upon the forming mechanism to change the rate of movement of the forming member, and fluid-pressure connections from the secondary valve to said device.
- 15 561. In a machine for operating upon material in accordance with a pattern, operating means, controlling means for the operating means including a member movable in opposite directions under the influence of the pattern, and means acting upon the controlling means in anticipation of reverse movement of the member.
- 20 562. In a machine for forming material, forming mechanism including a member movable in opposite directions to form the material, a form-determining member movable similarly to the forming member, a controlling device movable under the influence of the form-determining member to control the opposite movements of the forming member, and means acting upon the controlling device to anticipate reverse movement of the form-determining member.
- 25 563. In a machine for forming material in accordance with a pattern, fluid-pressure mechanism for operating upon the material, controlling mechanism for the operating mechanism including a member movable oppositely under the influence of the pattern and a valve governed by the member, and mechanism acting upon movement of the valve by the member for moving said valve in a manner tending to reverse the effect of the movement by the controlling member.
- 30 564. In a machine for forming material in accordance with a pattern, fluid-pressure mechanism for operating upon the material, controlling mechanism for the operating mechanism including a member movable oppositely under the influence of the pattern and a valve governed by the member, and fluid-pressure mechanism governed by the valve for moving said valve in a manner tending to reverse the effect of the movement by the controlling member.
- 35 565. In a machine for operating upon material in accordance with a pattern, operating means, controlling means for the operating means including a member movable in opposite directions under the influence of the pattern, means acting upon the controlling means in anticipation of reverse movement of the member, and means arranged to vary the extent of reverse movement.
- 40 566. In a machine for forming material in accordance with a pattern, fluid-pressure mechanism for operating upon the material, controlling mechanism for the operating mechanism including a member movable oppositely under the influence of the pattern and a valve governed by the member, fluid-pressure mechanism governed by the valve for moving said valve in a manner tending to reverse the effect of the movement by the controlling member.
- 45 567. In a machine for bending material in accordance with a pattern, a movable bending member, fluid-pressure actuating mechanism for moving the bending member, controlling mechanism for the actuating mechanism including a member movable under the influence of the pattern and a valve movable by the controlling member, a fluid-pressure device co-operating with the controlling member to move the valve and thereby move the bending member, and a fluid-pressure device acting upon the valve and tending to reverse the movement of the bending member.
- 50 568. In a machine for bending material in accordance with a pattern, a movable bending member, fluid-pressure actuating mechanism for moving the bending member, controlling mechanism for the actuating mechanism including a member movable under the influence of the pattern and a valve movable by the controlling member, a fluid-pressure device co-operating with the controlling member to move the valve and thereby move the bending member, a fluid-pressure device acting upon the valve and tending to reverse the movement of the bending member, and connections under the control of the valve for supplying fluid pressure to both of said devices.
- 55 569. In a machine for forming material, fluid-pressure forming mechanism, mechanism for feeding material to the forming mechanism, a fluid-pressure device for controlling the feeding mechanism, mechanism including a valve for controlling the application of fluid pressure to the forming mechanism, a fluid-pressure device for shifting the valve, and connections from the valve for supplying fluid pressure simultaneously to the feed-controlling device and the valve-shifting device.
- 60 570. In a machine of the class described, operating means, a fluid-pressure system for controlling the operating means, a conduit for supplying fluid to the controlling system, an automatic valve in the conduit arranged for operation by the fluid, and a manually operable device for governing the automatic valve.
- 65 571. In a machine of the class described, operating means, a fluid-pressure system for

controlling the operating means, a conduit for supplying fluid to the controlling system, an automatic valve in the conduit arranged for operation by the fluid, and an automatic device for governing the automatic valve.

5 572. In a machine of the class described, operating means, a fluid-pressure system for controlling the operating means, a conduit for supplying fluid to the controlling system, a leakage-valve in the conduit, and a plurality of leak devices for governing the leakage-valve.

10 573. In a machine of the class described, operating means, a fluid-pressure system for controlling the operating means, a conduit for supplying fluid to the controlling system, a valve-casing situated in the conduit and having a leak-opening, means for closing the leak-opening, and a plunger movable in the 15 casing and arranged to be held by the pressure in the conduit at opposite extremes of its travel when the leak-opening is respectively open and closed.

20 574. In a machine of the class described, operating means, a fluid-pressure system for controlling the operating means, a conduit for supplying fluid to the controlling system, a valve-casing situated in the conduit and having a leak-opening near one extremity, 25 means for closing the leak-opening, and a plunger movable in the casing and having heads of different diameter, the larger being at the end toward the leak-opening.

30 575. In a machine of the class described, operating means, a fluid-pressure system for controlling the operating means, a conduit for supplying fluid to the controlling system, a valve-casing situated in the conduit and having a leak-opening near one extremity, 35 means for closing the leak-opening, and a plunger movable in the casing and having opposite heads, there being spiral grooves about the peripheries of the heads.

40 576. In a machine of the class described, operating means, a fluid-pressure system for controlling the operating means, a conduit for supplying fluid to the controlling system, a valve-casing situated in the conduit and having a leak-opening, means for closing the 45 leak-opening, a plunger movable in the casing and arranged to be held by the pressure in the conduit at opposite extremes of its travel when the leak-opening is respectively open and closed, and a finger-piece projecting from the plunger outside the casing.

55 577. In a machine of the class described, operating means, a fluid-pressure system for controlling the operating means, a conduit for supplying fluid to the controlling system, 60 an automatic valve in the conduit, a reservoir, a float in the reservoir, and a device controlled by the float for governing the automatic valve.

65 578. In a machine of the class described, hydraulic operating means, a pneumatic sys-

tem for controlling the supply of liquid to the operating means, a reservoir for liquid, a float under the influence of the liquid in the reservoir, a conduit for supplying air to the controlling system, a leakage-valve in the conduit, and a leak device for the leakage-valve operable by the float.

70 579. In a machine for operating upon material in accordance with a pattern, operating mechanism, controlling mechanism for the operating mechanism including a member co-operating with the pattern, and a carrier-frame upon which the controlling member is movable, said carrier-frame being mounted to oscillate and thereby move the controlling member into and out of operative relation with the pattern.

75 580. In a machine for operating upon material in accordance with a pattern, a main frame, operating mechanism mounted thereon, controlling mechanism for the operating mechanism including a member co-operating with the pattern, a carrier-frame for the controlling member trunnioned upon the main frame to move the controlling member toward and from the pattern, and a latch for the carrier-frame retaining the controlling member out of its co-operative relation with the pattern.

80 581. In a machine for operating upon material in accordance with a pattern, a main frame, operating mechanism mounted thereon, controlling mechanism for the operating mechanism including a member co-operating with the pattern, a carrier-frame for the controlling member trunnioned upon the main frame to move the controlling member toward and from the pattern, a spring connecting the carrier-frame and main frame and acting to force the controlling member into engagement with the pattern, and a latch for the carrier-frame retaining the controlling member out of its co-operative relation with the pattern.

85 582. In a machine for operating upon material in accordance with a pattern, operating mechanism, controlling mechanism for the operating mechanism including members contacting respectively with the material and pattern, and a mounting for the material-contacting member arranged to permit the adjustment of said member transversely of the edge of the pattern.

90 583. In a machine for operating upon material in accordance with a pattern, operating mechanism, controlling mechanism for the operating mechanism including members contacting respectively with the material and pattern, a carrier-frame, and an arm pivoted upon the carrier-frame and upon which the material-contacting member is mounted, said arm being free to be turned upon the carrier-frame.

95 584. In a machine for operating upon material in accordance with a pattern, operat-

- ing mechanism, controlling mechanism for the operating mechanism including members contacting respectively with the material and pattern, a carrier-frame, and an arm pivoted upon the carrier-frame and upon which the material-contacting member is mounted, the contact-end of the member lying in proximity to the axis of the arm and being curved about said axis as a center.
- 5 585. In a machine for operating upon material in accordance with a pattern, operating mechanism, controlling mechanism for the operating mechanism including members contacting respectively with the material and pattern, a carrier-frame, an arm pivoted upon the carrier-frame, and a rod clamped upon the arm and having the material-contacting member fixed upon it.
- 10 586. In a machine for forming material, a movable forming member contacting with the material, actuating mechanism for the forming member, an electrical circuit for heating the material and including the forming member, controlling mechanism for the actuating mechanism including a member contacting with the material, a mounting for the member, and insulating material interposed between the controlling member and the mounting.
- 15 587. In a machine for forming material in accordance with a pattern supported thereon, a movable forming member contacting with the material, actuating mechanism for the forming member, an electrical circuit for heating the material and including the forming member, controlling mechanism for the actuating mechanism including a member contacting with the pattern and a member contacting with the material, a mounting for each controlling member, and insulating material interposed between the controlling members and their mountings.
- 20 588. In a machine for operating upon material in accordance with a pattern, operating mechanism, controlling mechanism for the operating mechanism including a member for contact with the pattern, a carrier, a stem projecting from the carrier, a holder for the controlling member arranged to turn upon the stem, and a clamping device for fixing the holder at different angles upon the stem.
- 25 589. In a machine for operating upon material in accordance with a pattern, operating mechanism, controlling mechanism for the operating mechanism including a member for contact with the pattern, a carrier, a stem projecting from the carrier, a holder for the controlling member arranged to turn upon the stem, a clamping device arranged to retain the controlling member in different positions in the holder, and a clamping device for fixing the holder at different angles upon the stem.
- 30 590. In a machine for operating upon material in accordance with a pattern, operating mechanism, controlling mechanism for the operating mechanism including a member for contact with the pattern, a carrier, a stem movable in the carrier, and a holder for the controlling member fixed upon the stem.
- 35 591. In a machine for operating upon material in accordance with a pattern, operating mechanism, controlling mechanism for the operating mechanism including a member for contact with the pattern, a frame, a carrier mounted to oscillate upon the frame, a stem mounted to reciprocate in the carrier, and a holder for the controlling member fixed to the stem.
- 40 592. In a machine for operating upon material in accordance with a pattern, operating mechanism, and controlling mechanism for the operating mechanism including a member for contact with the pattern, said member being rhomboidal in transverse section.
- 45 593. In a machine for operating upon material in accordance with a pattern, forming mechanism, mechanism for feeding the material and pattern in co-operation with the forming mechanism, and controlling mechanism for the machine including a member contacting with the pattern and having sides converging in the direction of advance of the material and making an acute angle with each other.
- 50 594. In a machine for operating upon material in accordance with a pattern, forming mechanism, mechanism for feeding the material and pattern in co-operation with the forming mechanism, controlling mechanism for the machine including a member contacting with the pattern and having sides converging in the direction of advance of the material and making an acute angle with each other, and means arranged to permit the angular relation of the controlling member to the pattern to be varied.
- 55 595. In a machine for operating upon material in accordance with a pattern, forming mechanism, mechanism for feeding the material and pattern in co-operation with the forming mechanism, controlling mechanism for the machine including a member contacting with the pattern and having sides converging in the line of feed of the material and making an acute angle with each other, and means for bringing the pattern and this angular portion of the controlling member into contact with each other to initiate the forming operation.
- 60 596. In a machine for operating upon material in accordance with a pattern, forming mechanism, mechanism for feeding the material and pattern in co-operation with the forming mechanism, controlling mechanism for the machine including a member contacting with the pattern and having sides converging in the line of feed of the material

and making an acute angle with each other, and mechanism for pressing the angular portion of the controlling member into contact with the pattern to stop the feeding mechanism and start the forming mechanism.

597. In a machine for operating upon material in accordance with a pattern, operating means, controlling mechanism for the operating means including a member co-operating with the pattern, and automatic means for varying the relation between the controlling member and the operating means.

598. In a machine for operating upon material in accordance with a pattern, fluid-pressure operating means, controlling mechanism for the operating means including a member co-operating with the pattern, and means under the influence of the fluid pressure for varying the relation between the controlling member and the operating means.

599. In a machine for operating upon material in accordance with a pattern, a plurality of mechanisms for operating upon the material, controlling mechanism for the operating mechanisms including a member co-operating with the pattern, and means depending upon the operating mechanism thus controlled for moving the controlling member.

600. In a machine for operating upon material in accordance with a pattern, a plurality of mechanisms for operating upon the material, fluid-pressure controlling mechanism for the operating mechanisms including a member co-operating with the pattern, and mechanism to which the fluid pressure is differently applied in accordance with the operating mechanism under control for moving the controlling member to different positions.

601. In a machine for bending material, plural bending members operating about different bending axes, a form-determining member for controlling the bending members, and means for positioning the form-determining member to correspond to the bending axis of the particular bending member in use.

602. In a machine for bending material in accordance with a pattern, hot-bending mechanism, cold-bending mechanism, fluid-pressure controlling mechanism for both bending mechanisms including a member co-operating with the pattern, and means operable by the fluid pressure applied to the controlling mechanism for differently positioning the controlling member, the position depending upon which bending mechanism is in use.

603. In a machine for bending material in accordance with a pattern, hot-bending mechanism, cold-bending mechanism, said mechanisms operating about different bending axes, fluid-pressure controlling mechanism for both bending mechanisms including a member co-operating with the pattern, and

fluid-pressure mechanism for moving the controlling member to correspond to the bending axis of the bending member which is in use.

604. In a machine for bending material in accordance with a pattern, hot-bending mechanism, cold-bending mechanism, fluid-pressure controlling mechanism for both bending mechanisms including a member co-operating with the pattern, a cylinder having a piston connected to the controlling member, and fluid-pressure connections for the controlling mechanism to opposite ends of the cylinder, such opposite connections receiving pressure during the respective control of the hot and cold-bending mechanisms.

605. In a machine for operating upon material in accordance with a pattern, operating mechanisms, controlling mechanism for the operating mechanism having a member co-operating with the pattern, a movable carrier-frame upon which the controlling member is movable under the influence of the pattern, and means for moving the carrier-frame to change its relation to the operating mechanism.

606. In a machine for operating upon material in accordance with a pattern, operating mechanism, controlling mechanism for the operating mechanism having a member co-operating with the pattern, a movable carrier-frame, a carrier for the controlling member movable upon the carrier-frame under the influence of the pattern, means for moving the carrier-frame to change its relation to the operating mechanism, and mechanism depending in its action upon the condition of the controlling mechanism for moving the carrier-frame.

607. In a machine for operating upon material in accordance with a pattern, operating mechanism, controlling mechanism for the operating mechanism having a member co-operating with the pattern, an oscillatory carrier for the controlling member, and means for moving the carrier longitudinally of its axis of oscillation.

608. In a machine for operating upon material in accordance with a pattern, operating mechanism, fluid-pressure controlling mechanism for the operating mechanism having a member co-operating with the pattern, an oscillatory carrier for the controlling member, a cylinder receiving fluid pressure applied to the controlling mechanism, and a piston operating in the cylinder and connected to the carrier.

609. In a machine for forming material in accordance with patterns having contours of different degrees of curvature, forming means, controlling mechanism for the forming means having a member for co-operation with the patterns, and means arranged to position the controlling member in accordance with the curvature of the pattern with which it is to co-operate.

610. In a machine for forming material in accordance with a pattern, a movable forming member, controlling mechanism for the forming member having a member co-operating with the pattern, means for forcing the controlling member into position for the forming operation, and means arranged to vary the extent of this movement.

611. In a machine for forming material in accordance with a pattern, a movable forming member, fluid-pressure controlling mechanism for the forming member having a member co-operating with the pattern, mechanism receiving fluid pressure with the controlling mechanism to force the controlling member into position for the forming operation, and an adjustable stop to limit the movement of the controlling member.

612. In a machine for operating upon material in accordance with a pattern, operating means, controlling mechanism for the operating means including a member co-operating with the pattern, automatic means for varying the relation between the controlling member and the operating means, and operator-controlled means for varying such relation.

613. In a machine for operating upon material in accordance with a pattern, a plurality of mechanisms for operating upon the material, controlling mechanism for the operating mechanisms including a member co-operating with the pattern, means depending upon the operating mechanism thus controlled for moving the controlling member, and means acting in one of the positions to which the controlling member is thus moved for further adjusting such position.

614. In a machine for bending material in accordance with a pattern, hot-bending mechanism, cold-bending mechanism, said mechanisms operating about different bending axes, fluid-pressure controlling mechanism for both bending mechanisms including a member co-operating with the pattern, fluid-pressure mechanism for moving the controlling member to correspond to the bending axis of the bending member which is in use, and a stop acting upon the controlling member when the cold-bending mechanism is in use, said stop being adjustable in accordance with the curve into which the material is to be bent.

615. In a machine for operating upon material in accordance with a pattern, operating mechanism, controlling mechanism for the operating mechanism having a member co-operating with the pattern, a movable carrier-frame, a carrier for the controlling member movable upon the carrier-frame under the influence of the pattern, and an adjustable stop for the carrier-frame.

616. In a machine for operating upon material in accordance with a pattern, operating mechanism, controlling mechanism for

the operating mechanism having a member co-operating with the pattern, an oscillatory carrier for the controlling member, means for moving the carrier longitudinally of its axis of oscillation, and a stop adjustable to limit such axial movement.

617. In a machine for operating upon material in accordance with a pattern, operating mechanism, fluid-pressure controlling mechanism for the operating mechanism having a member co-operating with the pattern, an oscillatory carrier for the controlling member, a cylinder receiving fluid pressure applied to the controlling mechanism, a piston operating in the cylinder and connected to the carrier, and an operator-controlled stop for the carrier.

618. In a machine for forming material, forming means, cutting mechanism movable from a position removed from the forming means into proximity therewith, an actuating member connected to the cutting mechanism to effect such movement, and means operating after the termination of the positioning movement and upon continued travel of the member for actuating the cutting mechanism.

619. In a machine for forming material, forming means, cutting mechanism movable from a position removed from the forming means into proximity therewith, and fluid-pressure mechanism for thus moving the cutting mechanism and actuating it to sever the formed material.

620. In a machine for forming material, forming mechanism including separated members for restricting the movement of the material, cutting blades situated normally below the restricting members and in open relation, and means for elevating the cutting blades into proximity with the restricting means and for closing said blades.

621. In a machine for forming material, forming mechanism including separated abutments between which the material projects during its formation, cutting members movable toward and from each other and also movable together from a position separated from the abutments into proximity and at opposite sides of said abutments, and mechanism for thus moving the members.

622. In a machine for forming material, forming mechanism including separated abutments between which the material projects during its formation, cutting members movable toward and from each other and also movable together, and fluid-pressure mechanism for first moving the members in open relation from a position separated from the abutments to opposite sides thereof and thereafter closing said members to sever the formed material.

623. In a forming machine, material-forming means, a support, a carrier movable upon the support adjacent to the form-

- ing means, a pair of blades movable upon the carrier and normally separated from the forming means, and mechanism for moving the carrier to cause the approach of the blades to the forming means and for oscillating the blades upon the carrier to sever the formed material. 624. In a forming machine, material-forming means, a movable support, a carrier movable upon the support adjacent to the forming means, a pair of cutting members movable upon the carrier, and means for moving the carrier toward and from the material and for actuating the members to sever the material, the support being free to move during the actuation of the members. 625. In a machine for forming material, forming mechanism including separated abutments between which the material projects during its formation, a support pivoted adjacent to the abutments, a carrier movable upon the support, blades movable upon the carrier, and mechanism for moving the carrier and for opening and closing the blades. 626. In a forming machine, forming means, a carrier movable toward and from the forming means, cutting members movable upon the carrier, and an actuating member connected directly to the cutting members to move said members and through said connections to move the carrier. 627. In a forming machine, forming means, a carrier movable toward and from the forming means, cutting members movable upon the carrier, and a member contacting with the cutting members when these are in fixed relation to each other to move the carrier, said member being movable in contact with the cutting members to open and close said members. 628. In a forming machine, forming means, a carrier movable toward and from the forming means, cutting members movable upon the carrier, a fluid-pressure cylinder, and a piston operating in the cylinder and having a contact-portion engaging the members and movable relatively thereto. 629. In a forming machine, forming means, a carrier movable toward and from the forming means, cutting members movable upon the carrier and having adjacent slots, and an actuating member entering the slots of the cutting members. 630. In a forming machine, forming means, a carrier movable toward and from the forming means, cutting members movable upon the carrier and having adjacent slots with normally parallel portions and curved ends, a fluid-pressure cylinder, and a piston operating in the cylinder and having a portion entering the curved ends of the slots and movable along said slots to oscillate the cutting members. 631. In a forming machine, forming means, a carrier movable toward and from the forming means, cutting members movable upon the carrier, a reciprocating actuating member connected to the cutting members to move said members and with them the carrier, and means made active during a portion only of the travel of the actuating member to cause reverse movement. 632. In a forming machine, forming means, a carrier movable toward and from the forming means, cutting members movable upon the carrier, a reciprocating actuating member connected to the cutting members to move said members and with them the carrier, and a spring arranged for compression during a portion of the travel of the actuating member, said spring expanding to initiate reverse movement. 633. In a forming machine, forming means, a carrier movable toward and from the forming means, cutting members movable upon the carrier, and an actuating member connected to the cutting members to move said members and with them the carrier, there being co-operation between the cutting members and relatively fixed points during the movement of the carrier to prevent movement of the cutting members upon said carrier. 634. In a forming machine, material-forming means, a support, a carrier movable upon the support adjacent to the forming means, a pair of blades movable upon the carrier and normally separated from the forming means, and mechanism for moving the carrier to cause the approach of the blades to the forming means and for oscillating the blades upon the carrier to sever the formed material, the blades co-operating with the support during the movement of the carrier to prevent their oscillation. 635. In a machine for operating upon material, cutting mechanism movable into and out of operating position, and means for moving the cutting mechanism at different rates in different portions of its advance to the operating position and for actuating the mechanism at such position to produce the cut. 636. In a machine for forming material, forming means, cutting means movable into and out of co-operation with the forming means, mechanism for moving the cutting means, and means for reducing the rate of movement as the cutting means approaches the end of its travel. 637. In a machine for operating upon material, operating mechanism including a member for engagement with the material, said mechanism being movable to carry the member into and out of operating position, fluid-pressure mechanism for moving the operating mechanism, and automatic means for controlling the fluid-flow to change the

rate of movement of the operating mechanism.

638. In a machine for operating upon material, operating mechanism including a member for engagement with the material, said mechanism being movable to carry the member into and out of operating position, fluid-pressure mechanism for moving the operating mechanism, and means controlled in the operation of the fluid-pressure mechanism for throttling the fluid-supply thereto.

639. In a machine for forming material, a movable operating member, a cylinder having an opening through which fluid pressure is delivered, and a piston operating in the cylinder and acting upon the operating member, there being a surface movable with the piston and co-operating with the opening.

640. In a machine for forming material, forming means, cutting mechanism movable into and out of co-operation with the forming means, a cylinder, a piston operating in the cylinder and acting upon the cutting mechanism, and a conduit having an opening through which fluid pressure is delivered to the cylinder, there being a surface movable with the piston for closing the opening.

641. In a machine for forming material, a movable operating member, a cylinder having an opening through which fluid pressure is delivered, and a piston operating in the cylinder and acting upon the operating member and arranged to gradually reduce the area of the opening as the operating member approaches the end of its travel.

642. In a machine for forming material, forming means, cutting mechanism movable from a position removed from the forming means into proximity therewith, fluid-pressure mechanism for thus moving the cutting mechanism and actuating it to sever the formed material, and an operator-controlled valve to govern the fluid pressure.

643. In a forming machine, material-forming means, a movable support, a carrier movable upon the support adjacent to the forming means, a pair of cutting members movable upon the carrier, fluid-pressure mechanism for moving the carrier toward and from the material and for actuating the members to sever the material, the support being free to move during the actuation of the members, and a valve mounted upon the support to govern the fluid pressure.

644. In a machine for forming material, a movable operating member, a cylinder having an opening through which fluid pressure is delivered, a piston operating in the cylinder and acting upon the operating member, and a valve arranged to be opened by the operator to supply fluid pressure to the cylinder and including means to effect its closure under the influence of the fluid pressure.

645. In a machine for forming material,

forming means, cutting mechanism movable into and out of co-operation with the forming means, a cylinder, a piston operating in the cylinder and acting upon the cutting mechanism, a conduit through which fluid pressure is delivered to the cylinder, and a valve including a plunger arranged to be moved by the operator to admit pressure to the cylinder, said plunger being constantly under the influence of fluid pressure tending to shut off admission to the cylinder.

646. In a machine for forming material, forming means including an hydraulic-pressure chamber, cutting mechanism co-operating with the forming means and including a movable cutting blade, hydraulic mechanism for moving the blade, a conduit of substantial length and of relatively small transverse section connecting the pressure chamber with the hydraulic mechanism, and a valve arranged to open and close the conduit.

647. In a machine for forming material, forming means, cutting mechanism co-operating with the forming means and including a movable cutting blade, hydraulic mechanism for moving the blade, connections including a coil of pipe for delivering liquid to the hydraulic mechanism, and a valve arranged to open and close the pipe.

648. In a forming machine, forming means, cutting mechanism normally separated from the forming means, fluid-pressure mechanism for moving the cutting mechanism into co-operation with the forming means with an increasing resistance to fluid-flow in such movement, and means for decreasing this resistance upon reverse movement.

649. In a machine of the class described, fluid-pressure operating mechanism, a conduit joined to the operating mechanism and through which both supply and exhaust of fluid occurs, a branch connecting the operating mechanism with the conduit, and means for limiting the flow in the branch to one direction.

650. In a machine of the class described, a movable operating member, fluid-pressure mechanism for actuating the member and including a cylinder and a piston connected to said member, and fluid-pressure connections to the cylinder, said connections including a contracted combined delivery and exhaust-opening and an exhaust-opening of greater area than said contracted opening.

651. In a machine of the class described, a movable operating member, fluid-pressure mechanism for actuating the member and including a cylinder and a piston connected to said member, a conduit connected to the cylinder by a contracted opening, a branch from the conduit to the cylinder of greater effective area than the opening, and a check-valve in the branch, said valve opening in a direction from the cylinder.

652. In a machine for forming material, a forming member, a cutting device co-operating with the forming member, fluid-pressure actuating mechanism for the cutting device, a valve, supply and exhaust-conduits connected to the valve, a combined delivery and exhaust-conduit connecting the valve and actuating mechanism, a branch-conduit from the actuating mechanism to said combined conduit, and a check-valve in the branch-conduit.

653. In a machine for forming material, a forming member, a support situated adjacent to the forming member and being movable with relation thereto, means for fixing the support in different positions, and cutting mechanism mounted upon the support.

654. In a machine for forming material, forming mechanism including abutments between which the material projects during its formation, a plate movable adjacent to the abutments, means for fixing the plate in different positions transversely of the abutments, and cutting mechanism mounted upon the plate.

655. In a machine for forming material, a forming member, a support situated adjacent to the forming member and being movable with relation thereto, means for fixing the support in different positions, and cutting mechanism pivoted upon the support to assume different positions with respect to the forming mechanism.

656. In a machine for forming material, forming mechanism including abutments between which the material projects during its formation, a plate movable adjacent to the abutments, means for fixing the plate in different positions transversely of the abutments, and cutting mechanism mounted upon the plate to yield transversely of the abutments.

657. In a machine for forming material, forming means acting to change the angular relation of the material, mechanism co-operating with the forming means to cut the formed material, and a mounting for the cutting mechanism arranged to yield in accordance with the angle of the material during the cutting operation.

658. In a machine for forming material, forming mechanism, cutting mechanism including a pair of cutting members arranged to open and close, the cutting mechanism being normally separated from the forming mechanism with the members open, and means for moving the cutting mechanism into proximity with opposite sides of the formed material and closing the members to sever the material, said cutting mechanism being arranged to yield during the cutting operation.

659. In a machine for forming material, forming mechanism including abutments between which the material projects during its

formation, and cutting mechanism acting upon the material projecting from the abutments, said cutting mechanism being arranged to yield transversely of the abutments.

660. In a machine for forming material, forming means, a casing pivoted adjacent to the forming means, cutting members movable in the casing, and springs acting to yield abutment position the casing.

661. In a machine for forming material, forming mechanism including abutments between which the material projects during its formation, a plate movable adjacent to the abutments, means for fixing the plate in different positions transversely of the abutments, a casing pivoted upon the plate, cutting members mounted upon the casing, and springs acting to hold the cutting members normally in a predetermined relation to the abutments.

662. In a machine for forming material, forming mechanism including abutments between which the material projects during its formation, a casing pivoted adjacent to the abutments, cutting members mounted upon the casing, springs acting to hold the cutting members normally in a predetermined relation to the abutments, and means arranged to vary the normal relation of the cutting mechanism to the abutments.

663. In a machine for forming material, forming mechanism including abutments between which the material projects during its formation, a casing pivoted beneath the abutments, cutting members mounted upon the casing, springs acting to hold the cutting members normally in a predetermined relation to the abutments, and means arranged to adjust the angle of the casing upon its pivots.

664. In a machine for forming material, forming means, a casing pivoted adjacent to the forming means, cutting members mounted upon the casing, an abutment angularly adjustable about the pivot of the casing, and a spring-pressed member carried by the casing and contacting with the abutment.

665. In a machine for forming material, forming means, a casing pivoted adjacent to the forming means, cutting members mounted upon the casing, an abutment situated adjacent to the casing, rods movable in the casing at opposite sides of the pivot and contacting with the abutment, springs forcing the rods toward the abutment, and means arranged to vary the force exerted by the springs.

666. In a machine for forming material, forming means, cutting mechanism co-operating with the forming means and including a casing, and a pair of blades movable upon the casing and furnishing by their contact with the walls of the casing close joints serving to exclude foreign matter.

667. In a machine for forming material,

- forming means, cutting mechanism co-operating with the forming means and including a carrier-casing, a bearing-casing movable in the carrier-casing, a pair of blades movable in the bearing-casing, and means for moving the carrier-casing and blades. 668. In a machine for forming material, forming means, cutting mechanism co-operating with the forming means and including a carrier-casing, a bearing-casing movable in the carrier-casing, a pair of blades movable in the bearing-casing, and an actuating member movable upon the carrier-casing and extending into the bearing-casing to engage the blades. 669. In a machine for forming material, forming means, cutting mechanism co-operating with the forming means and including a carrier-casing, a bearing-casing movable in the carrier-casing, a pair of blades movable in the bearing-casing, and fluid-pressure actuating mechanism mounted upon the carrier-casing and extending into the bearing-casing to engage the blades. 670. In a machine for forming material, a frame, a forming member movable thereon, a support movable on the frame, means for fixing the support in different positions with respect to the forming member, and abutments mounted upon the support to receive the material and present it to the forming member. 671. In a machine for forming material, a frame, a forming member movable thereon, a support movable on the frame, means for fixing the support in different positions with respect to the forming member, abutments movable upon the support and receiving the material to present it to the forming member, and means for fixing the abutments in different positions. 672. In a machine for forming material, a frame, a forming member movable thereon, a support movable on the frame, means for fixing the support in different positions upon the frame transversely of the forming member, abutments movable upon the support and receiving the material to present it to the forming member, and means for fixing the abutments in different positions upon the support toward and from the forming member. 673. In a machine for bending material, separated abutments, a movable bending member co-operating with one extremity of the abutments, and means arranged to fix the abutments at different distances from the field of action of the bending member. 674. In a machine for bending material, separated abutments, a movable bending member co-operating with one extremity of the abutments, and operator-controlled means for moving the abutments toward and from the field of action of the bending member. 675. In a machine for bending material, separated abutments, a support therefor, screws extending through the support into the abutments, oppositely inclined screws threaded through the support and contacting with the abutments, and a bending member co-operating with one extremity of the abutments. 676. In a machine for bending material, a frame, a bending member movable thereon, a support separable from the frame, abutments movable upon the support and having a channel to receive material for presentation to the bending member, and means for advancing material through the channel. 677. In a machine for bending material, a frame, a bending member movable thereon, a plate separable from the frame and having an upwardly extending wall, abutments mounted upon the wall and having a channel through which the material is presented to the bending member, adjusting screws extending through the wall into engagement with the abutments, and feeding mechanism delivering to the channel. 678. In a machine for bending material, a movable bending member, abutments having a channel through which the material is presented to the bending member, a portion of said channel being straight and a portion curved laterally, and mechanism for forcing material through the channel to receive the action of the bending member. 679. In a machine for bending material, a movable bending member, abutments having a channel through which the material is presented to the bending member, and feeding mechanism for forcing the material through the channel toward the bending member, the portion of said channel receiving the material from the feeding mechanism being straight and the portion delivering to the bending member being curved. 680. In a machine for bending material, bending means, means for advancing material to the bending means, a movable carrier, and a plurality of devices mounted upon the carrier, one of said devices being arranged to receive and retain the extreme forward end of the material and another of said devices furnishing a material-engaging clamp. 681. In a machine for bending material, bending means, means for advancing material to the bending means, a pivoted arm, a yoke pivoted on the arm, and devices mounted upon opposite extremities of the yoke, one of said devices being provided with a slot arranged to receive the advancing end of the material and the other device furnishing a material-engaging clamp. 682. In a machine for bending a strip of material, bending mechanism, mechanism for advancing the strip to the bending mechanism, a movable carrier, a device mounted

upon the carrier for engagement with one end of the strip, and a device mounted upon the carrier for engagement with the side of the strip, both of said devices being movable with the strip to support it in its advance.

683. In a machine for bending a strip of material, bending mechanism, mechanism for advancing the strip to the bending mechanism, a movable carrier, and a member movable upon the carrier and having a substantially vertical slot to engage the end of the strip and support it in its advance.

10 In testimony whereof I have signed my name to this specification.

15 CUTLER D. KNOWLTON.
